APPARATUS FOR MINING COAL

Edmund C. Morgan, Chicago, Ill.; Olive Eugenie Morgan, executrix of the estate of Edmund C. Morgan, deceased, assignor to American Morgan Company, a corporation of Delaware

Application June 23, 1913, Serial No. 775,173

437 Claims. (Cl. 262—28)

My invention relates to method of and apparatus for mining coal or other materials, and more particularly to such as are characterized by the cutting of a plurality of kerfs for the purpose of enabling the coal or other materials to be removed in blocks or substantially regular and uniform masses.

The methods herein disclosed are described and claimed in my co-pending divisional applications 10 Ser. No. 520,071, filed March 4, 1931, for Method of mining coal and Ser. No. 607,344, filed April 25, 1932, for Method of mining coal.

One of the objects of my invention is to generally improve and simplify the mining of coal or other materials and to generally simplify and improve the apparatus for carrying on such methods. Other objects of my invention will appear hereinafter.

Referring to the accompanying drawings:

20 Figure 1 is a general view in side elevation of a mining machine embodying my invention.

Fig. 1^a represents a fragmentary view partly in elevation and partly in central vertical section, of Fig. 1 to show the pivotal connection between 25 the turn table and the truck.

Figure 2 is a general top plan view of the machine shown in Figure 1.

Fig. 2^a is a plan view of a portion of Fig. 2 to show the power transmission between the motor 30 on the main frame and the advancing and reTRACTING beam.

Figure 3 is an enlarged elevational view of a cutting mechanism or cutter bar embodying my invention.

35 Figure 3^a is a transverse sectional view of the cutting mechanism on the line 3^a—3^a of Figure 3.

Figure 4 is a rear end elevation of the machine shown in Figures 1 and 2.

Figure 5 is an enlarged sectional view on the 40 line 5—5 of Figure 6 of the mechanism for transmitting power to the cutting mechanism and for actuating the cutting mechanism.

Figure 6 is a longitudinal sectional view on the line 6—6 of Figure 5.

45 Figure 7 is an enlarged detail view of the mechanism for retaining the control levers in their various positions.

Figure 8 is a fragmentary view in side elevation similar to the corresponding portion of the structure shown in Figure 1 but illustrating a modified construction.

Figure 9 is a top plan view of the mechanism shown in Figure 8.

Figure 10 is a sectional view on the line 10—10 55 of Figure 11, similar to Figure 5 but showing the

details of the modified construction illustrated in Figures 8 and 9.

Figure 11 is a longitudinal sectional view on the line 11—11 of Figure 10.

Figures 12 and 13 are diagrammatic views illustrating a method of mining coal. 60

Figure 14 is a diagrammatic view illustrating the manner in which my improved mining machine may be employed for cutting kerfs in the 65 coal.

Figure 15 is a view similar to 14 showing the vertical kerf cut by my improved machine.

Figure 16 is a diagrammatic view in section showing a number of vertical kerfs angularly disposed with relation to each other and cut in 70 the manner shown in Figures 14 and 15.

Figures 17 to 24 inclusive are diagrammatic views illustrating several modifications of my improved method of mining.

Fig. 25 is a view similar to Fig. 1 showing the 75 kerf-cutter adjusted to a cutting position in a horizontal plane intermediate the floor and roof for the cutting of the intermediate horizontal kerf shown in Figs. 23 and 24.

In mining various materials, and particularly 80 coal, it is extremely desirable and important that the coal be mined with as small amount of cuttings as possible and that it be mined in large regular shaped blocks or masses so that it may be conveniently handled, not only in removing 85 it from the mine but for shipping it and transporting it. The desirability and advantage of taking coal out of the mines in as large blocks as possible is apparent when it is realized that the transportation of coal is not only greatly facilitated by the ease and convenience with which the large blocks may be packed for shipment in the cars, but because of the fact that large unbroken masses of coal retain their efficiency much longer

than coal which is broken into relatively small 90 particles when exposed to the influences of the weather. In the drawings, and particularly in Figures 12, 13, and 17 to 22, inclusive, I have diagrammatically illustrated my improved method

of mining coal by which all of these advantages 95 are obtained. Figure 13 illustrates diagrammatically a longitudinal vertical section through a vein of coal, and Figure 12 diagrammatically illustrates the forward end of the vein, that is the end of the vein at which the mining operations

take place. In carrying out my improved method 100 I prefer, first, to make a plurality of vertical parallel cuts or kerfs X which preferably extend

in vertical planes from the lower faces X¹ of the vein and the upper faces X² thereof. That is,

105

Figure 12 illustrates the forward end of the vein, that is the end of the vein at which the mining operations take place. In carrying out my improved method I prefer, first, to make a plurality of vertical parallel cuts or kerfs X which preferably extend in vertical planes from the lower faces X¹ of the vein and the upper faces X² thereof. That is, 110

vertical kerfs or cuts extend between what is generally known as the points of cleavage between the stratum or vein of coal and the earth or ground between which the vein of coal is confined. These cuts or kerfs X are preferably as thin as possible so as to avoid any more cuttings than is necessary, and they extend longitudinally into the vein at a distance which is found suitable or advisable under the particular circumstances and requirements. The kerfs X are likewise spaced apart at such distances as found to be best adapted to the particular conditions and requirements. I also make a plurality of long horizontal kerfs X^3, X^3' preferably extending from one side of the vein of coal to the other side thereof so as to divide the vein into a plurality of large blocks X^4, X^5, X^6 . These horizontal kerfs, as shown in Figure 13, lie in planes which are disposed at an angle to the longitudinal axis of the vein. They preferably begin at points X^7, X^8 below or above the longitudinal center of the vein and extending angularly upward and downwardly from said respective points preferably to the roof and floor of the mine entry, although I have found that these horizontal kerfs need not extend all of the way to the roof or floor of the mine entry under certain circumstances. For instance, in Figures 17 and 18 it will be noted that the horizontal kerfs X^3 , which incline upwardly toward the roof of the mine entry, may terminate short of the roof and leave an uncut portion X^9 which must be broken when blocks of coal are dislodged, while the kerfs X^3' , which incline downwardly toward the floor of the entry, may, if desired, extend all the way to the floor or line of cleavage. These uncut portions X^9 , however, are preferably not sufficiently thick to prevent the blocks of coal being readily dislodged or broken away after the kerfs are cut. As shown in Figures 13 and 18, the series of horizontal kerfs X^3 are preferably parallel with respect to each other, and likewise the series of horizontal kerfs X^3' lie in planes parallel with respect to each other. In consequence there are left uncut portions X^{10} and X^{11} between said kerfs along the lines of cleavage both at the roof and floor of the mine, and after the kerfs have been made these blocks may be dislodged or broken away from these lines of cleavage in any suitable manner under the particular circumstances, or they may be severed by horizontal kerfs. In practice I prefer to make a series of vertical kerfs first and after these vertical kerfs are cut I then cut the horizontal kerfs because it can readily be seen that if the horizontal kerfs X^3 were made first there would be a large mass or long slab of coal suspended from the roof of the mine which, under the conditions in some mines, would be likely to fall owing to the fact that the adhesion of the slab of coal to the roof of the mine along the cleavage line X^{10} would not be sufficient to support the slab of coal. Often this is true even when the vertical kerfs are made first and the horizontal kerfs afterward but in such cases, as the horizontal kerf advances across the vein intersecting the vertical kerfs and forming the complete blocks X^4 , I prefer to jack up or support the blocks X^4 until the horizontal kerfs are completed clear across the vein. Any suitable means for supporting these cut blocks may be employed, such, for instance, as jacks X^{12} of the character illustrated in Figures 12 and 13. These jacks are provided with broad bases X^{13} and with standards which are inclined substantially parallel to the planes of the horizontal kerfs, and the heads X^{14} of these jacks are formed as supporting members, as shown in Figure 13, for engagement with the lower corners of the blocks. These jacks are preferably provided for each block X^4 of coal as the block is cut and after the complete series of blocks have been formed the jacks may be removed and the blocks allowed to drop or be dislodged for removal from the mine. The advantage of supporting the blocks X^4 in position until all of them have been cut is that the machine, if the machine is used, which cuts the kerfs may be moved out of the way in order to permit the convenient removal of the blocks. The cutting of the horizontal kerfs X^3 and X^3' is preferably done alternately with respect to each other. That is to say, after the vertical kerfs are cut a horizontal upwardly inclined cut X^3 is cut. The blocks X^4 may be dislodged and removed from the mine entry, thus leaving the face of the coal clear so that the next horizontal cut X^3' which begins at point X^8 and inclines downwardly may be cut, thus leaving the lower blocks X^5 in condition to be broken along the lower cleavage line X^{11} and removed from the mine. I have not found it necessary to support the lower blocks X^5 by means of jacks or otherwise, because they are resting upon the floor of the mine, so to speak, and there is not the tendency for them to fall away or break along their lines of cleavage without the aid of a slight additional dislodging force being applied to them. Of course the vertical kerfs X should be made deep enough in advance of the cutting of the horizontal kerfs so that the blocks will be cut on all sides except along the lines of cleavage and at the portions X^9 (Figure 18) when the kerfs X^3 are not extended all the way to the roof of the mine. It is to be understood, however, that the horizontal kerfs may be made before the vertical kerfs because in some mines there is found no tendency of the slabs of coal to fall of their own weight, but this, of course, is to be determined by the conditions in the particular mine in which the coal is being cut. Figures 20 and 22 diagrammatically illustrate a modification in the angular relations of the cuts. In these figures it will be noticed that the horizontal kerfs X^3 and X^3' begin at points X^{15} above and below the longitudinal center of the vein; that is to say, the cuts X^3 and X^3' are disposed entirely above and below the longitudinal center of the mine respectively. It will also be noted that these kerfs X^3 and X^3' do not incline at as great an angle with respect to the longitudinal axis of the mine as they do in Figure 13. In consequence, this allows center blocks X^6 to be cut in addition to the upper and lower blocks X^4 and X^5 . In Figure 20 the center blocks X^6 are cut on all sides except for a small portion X^{17} at the ends of the blocks which must be broken to dislodge the blocks, but of course this portion X^{17} should not be of sufficient thickness as to prevent the blocks being readily broken by relatively slight force. In Figure 20 the horizontal cuts X^3 and X^3' do not reach entirely to the lines of cleavage as is the case with the kerfs X^3 of Figure 18, but as shown in Figure 22, these cuts may extend entirely to the line of cleavage, if desired. In Figure 22 it will be noticed that the center blocks are completely cut on all sides; that is to say, the kerfs X^3 and X^3' are extended into the center blocks X^6 until they intersect or meet at the point X^{18} , thereby making complete cuts on all sides of the blocks. Figures 23 and 24 are diagrammatic views illustrating my improved method wherein I cut a plurality of horizontal parallel kerfs X^{19} . These kerfs lie in planes

spaced apart but substantially parallel with the longitudinal center of the vein. Any number of these kerfs may be cut, depending, of course, upon the size of the vein and the particular operating conditions, although in the drawings I have illustrated only three horizontal kerfs, one being located at the upper line of cleavage of the vein, another being located at the lower line of cleavage and a third substantially in the center of the vein. The cutting of the horizontal intermediate kerf X^{19} shown in Figs. 23 and 24 may be effected by swinging the flat chain kerf-cutter 90° from its position shown in dotted lines in Fig. 1 so that its upper surface will be parallel to the roof. Then by means of the worm gearing shown in Fig. 6 the kerf-cutter may be swung on the axis 81 to a position parallel to the mine track. While the arms of the support E extend upwardly as shown in dotted line positions in Fig. 1 the motor will be upright and the shaft 81 of Fig. 6 will be vertical. The kerf-cutter will then occupy a top position in a horizontal plane parallel to the mine track. Now by means of the worm gearing 63, 64 the motor and kerf-cutter may be inverted and the latter may then be swung into the rib or upright wall of the entry and the intermediate kerf X^{19} of Figs. 23 and 24 may be produced by a longwall operation. That is to say, while the kerf-cutter is horizontal and parallel to the bearing 52 and approximately in alignment with the lower surface thereof the whole machine may be moved along the mine track by means of the rope gearing illustrated in Fig. 2. In the same manner the motor F may be inverted from its full line position in Fig. 1 and the kerf-cutter positioned in a horizontal plane parallel to the horizontal axis of the support E and approximately in alignment with the upper surface of the bearing 52. The kerf-cutter may therefore be adjusted to four horizontal parallel positions, one at the floor, one at the roof and two adjacent the horizontal axis of the support E. Furthermore, in any horizontal position whether at the floor or at the roof or intermediate the floor and the roof the self-locking worm gearing may be used to tilt the kerf-cutter on the axis 62; the screw 12 may be relied on to adjust the elevation of the kerf-cutter within the vertical limits of the turntable gear 16 it being understood that the worm 15 should remain in mesh with the turntable gear 16 to hold the supporting framework locked to the truck during the longwall operation, while the flanged wheels 1 of the truck serve to laterally brace the mining machine in co-operation with the rails 3 of the mine track. It should also be noted that when the axis 62 of Fig. 1 is vertical various shearing positions may be obtained by turning the motor F end for end and also turning the kerf-cutter end for end thereby positioning the latter intermediate the ribs or side walls of the mine entry. In other words, a kerf may be cut parallel to the horizontal axis 52 either outside of the axis 62 or inside of the same irrespective of the position of the support E on the bearing 52. I also cut a plurality of preferably parallel vertical kerfs X^{20} extending longitudinally into the vein and intersecting the horizontal kerfs X^{19} so as to cut the blocks of coal on all sides except at their inner end portions X^{21} , which portions are left uncut. Under ordinary circumstances these uncut portions X^{21} will be broken by the weight of the blocks themselves and the blocks will drop one upon the other in stacks, so to speak. In the event that the conditions in the particular mine are such that the uncut portions will not be broken by the weight of the blocks themselves, then they may be broken in a suitable manner by applying the suitable force thereto to break along the uncut positions. It will be noted that I incline the vertical kerfs X^{20} at a slight angle with respect to a vertical line, and my object in doing this is to facilitate the cutting of the kerfs by mining machines. By inclining the vertical kerfs to a slight degree it will be noted that the breaking of the uncut portions X^{21} by the weight of the blocks and the dropping of the blocks will not interfere in any way with the cutting mechanism of the mining machine. In other words, the blocks will drop directly away from the cutting mechanism and allow the cutting mechanism to be withdrawn after the kerfs are made. In the method shown in Figures 23 and 24 the horizontal kerfs X^{19} are preferably cut first and then the upright kerfs are cut one by one in sequence beginning with the right hand kerf and proceeding with the cutting of these kerfs entirely across the end of the vein. In Figures 1 to 11, inclusive, I have shown a mining machine by means of which the various kerfs at the various angles as above described, may be readily and conveniently accomplished.

In the structure which I have shown in the drawings I prefer to use a flat elongated cutting bar or cutting mechanism A, shown best in Figures 1, 2 and 3 and in detail in Figures 3 and 3a, because I am thereby enabled to cut comparatively thin kerfs or cuts without any considerable amount of cuttings. The details of my preferred cutting mechanism structure will be described hereinafter. It is sufficient at this time to say that the cutting mechanism is in the form of a long flat comparatively thin structure having a cutting chain B traveling preferably in one direction around its periphery so as to form a peripheral edge, so to speak. This cutter bar is preferably comparatively narrow in width and is preferably made of such length as to meet the desired requirements as to depth of cut, etc. This cutter bar or cutting mechanism is mounted and arranged so that it may be bodily shifted or positioned so as not only to present it edge-wise and enter it at any angle with respect to the material to be cut, but it may also be rotated bodily to such adjusted position and then swung bodily in either direction in such adjusted position so that it may sweep through a large area in a given plane. I will proceed, therefore, to describe a mechanism by which these positions and cutting movements are brought about.

The entire machine is preferably mounted upon a wheeled truck C, the wheels 1 of which are preferably mounted up suitable axles 2 and adapted to run on rails 3 laid along the floor of the mine or entry or other line of movement along which the machine is to operate. The rails 3 are preferably supported by metal ties 4 transversely arranged at intervals and having up-turned ends 5. The rails are laid on the ties adjacent the up-turned ends 5 of the ties and are prevented from spreading or shifting by means of blocks 6 disposed between the rails and the up-turned ends 5 of the ties and by means of spikes or other suitable fastening devices 7 arranged to engage the base of the rails, as shown more clearly in Figures 1 and 4. The truck is shown as having a large flat platform or table 8 upon which the mining machine is mounted. This truck platform has a large depending socket or dish-shaped depression 9 as shown in Figs. 1 and 1a. Above the platform, and preferably disposed parallel with respect thereto is a large circular table or plat-

form 10 which serves as a widely expanded turn-table having a diameter approximately equal to the width of the truck and which has a central vertically disposed shaft or bearing member 11 (Figure 1) rotatably sunk into the socket or bearing member 9 of the truck platform, whereby the turn-table 10 may be rotated about the vertical axis of its shaft or pivot member 11. The entire mining machine is preferably mounted upon or supported by this turn-table so that it may be bodily swung or rotated about a vertical axis to position the cutting mechanism with respect to the material to be cut. I prefer that the turn-table with the mining machine mounted thereon shall be capable of bodily vertical adjustment, and for this purpose any suitable mechanism may be provided. In the drawings (Figures 1 and 4) I illustrate a screw member 12 threaded through the bottom of the bearing member 9 and operating against the lower end of the shaft or pivot member 11 whereby the turn-table may be raised or lowered with respect to the truck, as desired. The turn table is provided with power actuated means comprising the worm gear 15 and the large gear 16 and for the sake of simplicity in illustration, I have shown the worm gear 15 operated by a hand wheel 17 although it should be understood that it may be operated by means of any desired mechanism. As shown in Fig. 4 the worm gear 15 is connected to a shaft 13 which is suitably journaled in an upstanding arm or bearing 14 on the truck and having at one end a worm wheel 15 which meshes with gear teeth 16 on the periphery of the turn-table 10, and having at its other end a suitable hand wheel 17 by which the shaft may be conveniently rotated by an operator or attendant standing at the side of the machine. A pair of open, preferably rectangular, frames D are rigidly mounted upon the turn-table 10 in any suitable manner. These frames are parallel and are spaced apart. The upper and lower bars or members D¹, D² respectively, of each of these frames are parallel and are adapted to form guides or tracks for a pair of sliding standards 19 and 20, respectively. These sliding standards are suitably formed at their upper and lower ends to embrace the track bars D¹ and D² of the frames to prevent displacement of the standards in any direction except along the track members of the frame. These standards are rigidly connected together at their bases by a platform member 21 so that they, in conjunction with the platform 21, constitute a sub-frame which may be rigidly shifted horizontally in the main frames D, as above described, and by means of this arrangement the entire cutting mechanism may be bodily shifted to any position within the limits of this shifting or sliding adjustment. The shifting of this sub-frame and the mechanism supported thereby may be accomplished in any suitable manner consistent with the conditions and requirements. In the drawings I have shown power operating mechanism for this purpose. On the sub-frame platform 21 I mount an electric motor 22, the electric connections for which may be brought to the motor in the usual manner and which need not be described. The motor shaft is supported in a bearing 23 and carries at its outer end a pinion 24 which drives a larger spur gear 25, the spur gear being mounted upon to drive a counter-shaft 26 supported in bearing standards 27. This counter-shaft carries a rotatable sleeve 28 which is provided with a worm gear 29 and which may be connected with or disconnected from the counter-shaft 26 by any suitable clutch mechanism such, for instance, as I have shown in the drawings. It will be seen that the inner end 30 of the sleeve is provided with notches or teeth so as to form one member of the clutch. The other member 31 of the clutch is mounted upon the shaft 26 to rotate therewith and to slide longitudinally thereof, and this member 31 may be thrown into or out of engagement with the clutch member 30 by the hand-operated lever 32 pivoted at one end to the platform 21. Hence, by operating this hand-lever the worm wheel 29 may be connected with the shaft 26 to be driven thereby or disconnected from said shaft at will. The worm gear 29 meshes with and drives a worm gear 33 which is mounted upon a vertical shaft journaled in a bearing mounted upon the platform 21. The vertical shaft carries a horizontally disposed winding drum or capstan 34, and as this capstan may be used as a means for shifting the sub-frame in the main frame, as shown in Figures 2 and 4, a jack 35 may be placed at a proper position in the mine entry and a rope or cable 36 hooked thereto and run to the capstan or drum so that by permitting the cable to wind upon the drum the sub-frame may be shifted in the main frame. Any suitable anchor may be used for the end of the rope, but I prefer to use a jack 35, such as shown in Figure 4, because it may be conveniently handled and moved about from place to place. The upper portions of the standards 19 of the sub-frame carry a large heavy bar or member 40 preferably of rectangular cross section and arranged to slide or shift longitudinally in suitable bearing members 41 of the sub-frame standards. This bar is preferably of considerable length so that it will have quite a long range of movement. It will be noted that the line of movement of this bar 40 is disposed at right angles or transversely to the line of bodily movement of the shifting sub-frame so that by reason of this construction, in conjunction with the sub-frame, the cutting mechanism may be bodily shifted or adjusted in two directions at right angles to each other thereby allowing a wide range of bodily adjustment for the cutting mechanism. The shifting of this bar 40 is accomplished through the medium of gear mechanism interposed between the bar 40 and the driving motor 22. As shown more clearly in Figures 1, 2 and 4, it will be seen that the entire under side of the bar or member 40 is provided with a series of gear teeth 42 thereby constituting a rack bar. A driving pinion 43 meshes with these rack teeth for imparting longitudinal movement to the shifting bar 40, and the pinion 43 is mounted upon a shaft 44 which is journaled in bearings 45 depending from one of the rack bar bearings 41. The end of the shaft 44 carries a large worm wheel 46 which meshes with and is driven by a worm gear 47 similar to the worm gear 29, and which is carried upon a rotatable sleeve 48 on shaft 26 similar to the sleeve 28. This sleeve like sleeve 28, forms one member of a clutch, the other member 49 of which is rotatable with shaft 26 but slideable thereon, and this clutch member 49 is adapted to be shifted into and out of engagement with the sleeve 48 by the hand lever 50. Thus the movement of the shifting rack bar 40 may be controlled at will, and by reason of the worm gearing just described the rack bar will remain locked in any position to which it is moved without the necessity of additional locking means. At one end of this rack bar 40 I provide an arm or member 51 which is disposed downwardly for

a portion of its length and then turned horizontally into substantial parallel relation with the longitudinal axis of the rack bar 40. The longitudinally disposed portion of this depending 5 arm forms a pivot member or stud 52 upon which a trunnion or support E is rotatably mounted. By reference to Figures 1 and 2 it will be noted that the trunnion member E has a centrally disposed bearing portion or stem E¹ which is rotatable upon the pivot member 52, and which may be held in place upon this pivot member against an annular shoulder 53 on the arm 51 by means of a removable cap 54 which is fastened to the end of the stud member 52 by means of a screw 10 or bolt 55. Thus by this construction the trunnion member or fork support E is capable of rotary movement upon an axis which is substantially parallel with the longitudinal axis of movement of the rack bar 40 and which is substantially transverse to the vertical axis of rotation of the turn-table upon which the machine is mounted. For the purpose of rotating this trunnion member E about its horizontal axis in a convenient manner I provide a worm wheel 56 on 20 the bearing portion E¹ of the trunnion member and this worm wheel is driven by a worm gear 57 which is mounted upon a shaft 58 supported in a suitable bearing 59 outstanding from the end of the rack bar 40. The shaft 58 has a hand wheel 60 by which it may be conveniently actuated by the operator to manipulate the position of the trunnion member E. It will be noted that by reason of the worm gear arrangement the trunnion member will be automatically locked to any 30 position in which it is rotated without the need of additional locking mechanism. An electric motor F is rotatably supported in this trunnion or forked support E. In the drawings I have shown a pair of brackets 61 bolted to the motor 40 casing F on diametrically opposite sides thereof, and these brackets carry outstanding stud or pivot members 62 arranged in alignment and suitably journaled in the outer or free ends of the blocks or arm members E² of the trunnion 45 member E so that the motor may be rotated about an axis which, as will be noted, is disposed substantially at right angles to the axis of rotation of the trunnion member E. It will be noted that the arms E² of the trunnion member E are curved 50 so that the axis of rotation of the motor F in the trunnion members is off-set to a considerable extent with respect to the axis of rotation of the trunnion member. This construction, while not necessary to some operations of the mining machine, is of advantage in that it will enable the cutting mechanism to operate through a greater range than otherwise. One of the brackets 61 carries a rigid segmental worm gear 63 which meshes with and is driven by a worm 64. The 60 worm 64 is mounted upon a small shaft 65 which is carried in a journal bearing 66 extending from one of the arms E² of the trunnion member E, and the shaft 65 also carries a hand wheel 67 by which it may be manipulated to rotate the motor about its axis. The worm gearing, like in the other cases heretofore mentioned, makes it possible to eliminate special locking means for holding the motor in any position in which it is rotated. 70 The cutting mechanism comprising the cutter bar A is carried by a frame or casing member which is rotatable on an axis transverse or at right angles to the axis of rotation of the motor in the trunnion member, whereby the cutting mechanism may be rotated in the plane of itself through a considerable range and thus permit a much wider cut or kerf to be made than if the cutting mechanism were fixed with respect to the motor which drives it. As shown in the drawings, the frame or casing 70 has an internal peripheral groove 71 formed at its edge and this groove fits an annular flange 72 on the motor casing so that a bearing is provided upon which the casing 70 may rotate. A removable flange or cap ring 73 is bolted to the casing 70 to permit the parts to be readily disassembled. This casing, together with the motor casing, as will be noticed, forms a complete enclosure for the various gears and operating parts contained therein, leaving none of these operating parts exposed to the grit and dust which necessarily results from the cutting operation. Referring more particularly to Figures 5 and 6 it is to be understood that F¹ represents the field magnets of any standard or suitable motor, and F² the armature thereof, the armature being mounted upon the motor shaft F³ and journaled in ball-bearings F⁴ in the head or end of the motor casing F. The motor shaft F³ projects beyond the bearing and carries a spur pinion 75 which drives a larger spur gear 76 carried by a shaft 77, the shaft having its bearing 78 in a bracket preferably formed integrally with the casing 70. This shaft also carries a spur pinion 79 which drives the large spur gear 80, which latter gear is mounted upon and adapted to drive a shaft 81 journaled in the frame or casing 70. The purpose of operating this train of gears thus described is to reduce the relative speed of the shaft 81. The shaft 81, as will be noticed, is lined up with the motor shaft F³ and carries at its outer end a sprocket 82 around which the cutter chain travels and by which said cutter chain is driven, as will be hereinafter described. The inner end of the shaft 81 carries a beveled gear 83 which is adapted to drive two small radially disposed shafts 84 and 85 through the medium of two small beveled pinions 86 which are carried by the shafts 84 and 85 and which mesh with the beveled gear 83. The other ends of the shafts 84 and 85 carry beveled pinions 87 and 88 respectively, which are mounted upon sleeves so that the gears may rotate with respect to their shafts. These sleeves are notched at their ends 89, 90 to form clutch members and are arranged to be connected with their shafts for rotation therewith by means of sliding clutch members 91 and 92, respectively. The beveled gears 87 and 88 mesh with corresponding beveled gears 93 and 94 carried at opposite ends of a shaft 95 upon which the worm gear 95 is mounted, the shaft which carries this worm gear being suitably journaled in bearings in the casing 70. This worm gear meshes with an annular series of gear teeth 96 formed upon the motor casing F. Hence by driving the worm gear 95 in either direction the casing 70 may be rotated relatively to the motor on an axis which in this case is coincident with the axis of rotation of the motor shaft, and since the cutter bar A is mounted upon this casing 70 the cutter bar will be given a bodily rotation about an axis which is permanently at right angles to the plane thereof. Thus by reason of this construction the kerf-cutter comprising the cutter bar and the endless chain 145 cutter thereon may be swung in the plane of itself in either direction while the cutting elements on the cutter chain continue to travel around the cutter bar in the same direction. By simply shifting one or the other of the clutch 150

members 91 and 92 it is obvious, of course, that the gears 87 or 88 may be thrown into or out of operation to drive the worm gear 96 in whichever direction is desired while the motor continues to rotate in the same direction. In Figure 5 I have shown a device by which either of these clutch members may be shifted from either of two different points. I provide a rigid lever which is centrally pivoted at 97 to the casing 70 and which has two bent arms which are connected to the clutch members 91 and 92. These bent arms 98 project through openings 99 in the casing or frame 70 in position to be actuated by an operator for controlling the clutches. The advantage of providing two integrally connected arms 98, 98, as shown in Fig. 5, for operating these clutches, lies in the fact that the clutches can be operated only alternatively for reversing the swinging feeding movement of the kerf-cutter on its right angle axis 81. One of the edges of each of the openings 99 in the casing 70 has three depressions 100 (see Figure 7) corresponding to the different positions to which the respective arm is shifted, and the arms are each provided with a slight enlargement 101 adapted to enter these notches or depressions in the edges of the casing and hold the arms in the positions to which they are shifted, the arms being made to spring slightly so that they will be held in the notches by the tension thereon.

Referring more particularly to Figures 1, 2, 3, 3^a and 6, the details of the kerf-cutter A, B will now be described. This kerf-cutter comprises a flat elongated frame 105 around the edge or periphery of which the cutter chain travels. The cutter frame 105, as will be noticed, lies in substantially the plane of the sprocket 82 so that the sprocket and frame will be properly lined up to accommodate the chain. The end of the cutter frame 105 nearest the sprocket 82 has an off-set tail or extension 106 which is disposed substantially parallel with the frame itself but is adapted to slide in the guideway 107 formed in the frame or casing 70, this tail piece or extension being provided with a slot 108 for the accommodation of the bearing portion or journal 109 of the shaft 81; the purpose of this construction being to allow the frame 105 to be adjusted longitudinally in either direction relatively to the sprocket 82, for the purpose of tightening or loosening the cutter chain or for the purpose of shortening or lengthening this chain, as will be hereinafter described. The journal or bearing portion 109 of the frame 70 carries a headed bolt or screw 110, the head 111 of which is positioned in a slot in the hub portion 109 so as to prevent movement of the bolt in either direction. This bolt extends through an opening in the end 112 of the tail piece 106 and is provided with two nuts 113, the purpose of the bolt and nuts being to hold the cutter frame 105 in any position to which it is longitudinally shifted. As shown more particularly in Figures 3 and 3^a it will be seen that the cutter chain is composed of a plurality of bit holding or center links 115 and a plurality of intermediate side links 116. The bit holding or center links 115 are preferably provided with removable cutting elements or cutter bits 117, and are adapted to be guided along the peripheral edge 118 of the cutter frame. The side links 116 project beyond the bit holding or center links so as to form, in a sense, a continuous channel on the inside of the chain, and the cutter frame has shoulders 119 formed near its edge to accommo-

date the side links 116. In this manner the chain is, in a sense, interlocked with the cutter frame 105 and may travel around the edge of said cutter frame without danger of being displaced laterally. It will be noted that the faces of the cutter frame 105 are substantially flush with the outer faces of the side links 116 so as to provide a structure of uniform thickness capable of entering the kerfs. Of course the cutter bits are arranged on the chain to cut a kerf slightly wider than the thickness of the frame and chain. I find it desirable to allow the cutter chain to travel around the outer end of the cutter frame, this being a sufficient support for the chain without adding any undue friction, but, if desired, a sprocket wheel 120 may be provided at the outer end of the cutter frame, as shown in Figures 3 and 3^a.

That the mining apparatus described and shown is universal in its adjustments and operations notwithstanding the use of only one elongated kerf-cutter in a compact unitary track-mounted machine, may readily be understood by considering some of the operations which may be performed in a coal mine. Not only may long-wall operations be performed to cut the horizontally extending kerfs shown in Figs. 17 to 24 but also vertical kerfs of various heights may be cut as illustrated in Fig. 14. The same method of operation illustrated in Fig. 14 may be used in horizontal planes at various elevations including the intermediate horizontal kerf X¹⁹ shown in Fig. 24, by means of the same operator-controlled self-contained power-operated mechanism that is used for cutting vertical kerfs. The operation illustrated in Fig. 14 may also be used in various angular or intersecting planes parallel to the horizontal axis of the turnover support E.

When the axis 62 is in the position shown in Fig. 1 it is in a horizontal plane extending through the turntable 10 and when the kerf-cutter is in a horizontal plane at the mine bottom the axis 81 is vertical and variably spaced horizontally from the vertical axis of the turntable. The machine may therefore be used to cut horizontal kerfs in an upright working face in advance of the space between the front end of the mine track and the mine vein in entries varying greatly in width. In the wider entries rectilinear sumping and withdrawal cuts may be connected by arcuate and transverse rectilinear cuts while the guides D¹, D² of Fig. 4 are at right angles to the mine track.

Since the axis 62 is always parallel to the plane of the cutter bar it will be vertical when the vertical kerfs of Fig. 16 are cut. These kerfs are cut by means of operator-controlled self-contained power-operated mechanism while the track and supporting framework thereon are stationary on the mine track. Radial kerfs in a horizontal plane spaced above a continuous under-kerf may also be cut by the same operator-controlled self-contained power-operated mechanism to insert incisions each no larger in cross-section than the cross-sectional dimensions of the kerf-cutter. Such incisions may suffice to dislodge the coal veins in which the coal is almost ready to drop down of its own weight after the under kerf has been cut. When the coal is so hard as to require blasting the machine may be adapted to many different methods of blasting because of the great variety of kerfs that may be cut from either side of the machine or in advance thereof at various elevations, slants and inclinations either horizontally or vertically or in intersecting planes.

On account of the axis 62 being in an offset position relative to the horizontal axis of the turnover support E it will occupy a relatively low position when below the axial line of such horizontal axis as shown in Fig. 1 and the machine may therefore be used to cut a kerf in the floor of the mine entry when the axis 81 is horizontal. In a similar manner when the axis 62 is in its dotted line position in Fig. 1 and the axis 81 is horizontal kerfs may be cut in the roof of the mine entry. Such floor and roof-kerfs may be cut on either side of the mine track and parallel thereto.

The machine may be used as a top cutting machine when the support E is in its dotted line position of Fig. 1 with the kerf-cutter in a horizontal plane spaced above all other parts of the machine. However, where the overhead room in a mine vein is limited kerfs at different elevations in horizontal planes all below a horizontal plane extending through the top of the machine may be cut by inverting the motor F as illustrated in Fig. 25.

In Figures 8, 9, 10 and 11 I illustrate a modification of my improved machine wherein I eliminate the motor F, which is positioned in the trunnion member E in Figs. 1 and 2, and substitute power transmission gearing therefor, which gearing is driven by the motor 22 mounted upon the sub-frame. By this arrangement I may use one motor of a larger capacity for the purpose of driving and feeding kerf cutting mechanism and also for bodily shifting the parts. The shaft of the motor 22 carries a pinion 125 which drives a large gear 126 mounted upon a suitable shaft which is supported in the bearing standards 127 on the sub-frame platform 21. This large gear 126 in turn meshes with and drives one of two intermeshing gears 128 of equal size, these gears 128 being mounted on separate parallel shafts 129 and 130 which are supported in suitable bearings 131 on the platform 21. These shafts also carry worms 132 and 133 which drive two large worm gears 134 and 135, respectively, mounted to rotate upon the shaft 44 which carries the pinion 43 for shifting the rack bar 40, the shaft 44 being supported in suitable bearings which are altered in accordance with the changes of construction in this modification. The gears 128 rotate in opposite directions and in consequence drive the large worm wheels 134 and 135 in opposite direction, these gears being free to rotate upon the shaft 44. Between the two gears 134 and 135 I provide a shiftable clutch member 136 which may be shifted on the shaft in either direction in the usual manner to connect one or the other of the gears 134 and 135 with the shaft 44 to drive said shaft in either direction and thereby reciprocate or shift the rack bar 40 in either direction without reversing the motor 22. The shaft 140 upon which the large gear 126 is mounted, is preferably of substantially the length of the shifting or reciprocating rack bar 40 and parallel therewith. This shaft is arranged so that it will slide longitudinally with respect to its bearings and the gear 126 in accordance with the movement of the rack bar. It is preferably squared or otherwise formed, so that it will be rotated by the gear 126 at any position in which it is shifted. This shaft which is made round at this point, extends through a bearing formed in the horizontal or pivot portions 52 of the depending arm 51 and projects into the space between the two arms or parts E² of the rotary trunnion member 50 and carries a beveled pinion 141 on this project-

ing end. It also carries a collar 142 which takes the place of the cap member 54 to prevent the trunnion from being displaced with respect to the pivot portion 52 but to allow it to be rotated about its axis in the same manner and preferably by similar hand-operated means to that shown in Figures 1 and 2. The beveled pinion 141 meshes with and drives a larger beveled gear 143 which is rotatably mounted upon a fixed shaft 144, the longitudinal axis of which lies at right angles to the axis of rotation of the rotary trunnion member in the same manner that the axis of rotation of the motor E of Figure 1 bears with respect to said trunnion axis. This shaft has its bearings 145 in the ends of the trunnion arms E². Between the beveled gear 143 and one of the journals 145 is an arm 146 having its hub 147 pivotally mounted upon the shaft 144 so that the arm 146 may be swung or rotated about the axis of the shaft 144. This arm 146 and its manner of mounting may be said to correspond to the motor F (Figure 1) in so far as the movements thereof on rectangularly related axes are concerned. The outer end of this pivoted arm has a bearing 148 and a large head or flange 149 (Fig. 11) which may be said to correspond to the flange 72 of the construction shown in Figures 5 and 6. The casing 70' is mounted to rotate upon the flange or head 149 in the same manner as in the construction shown in Figures 5 and 6 and 100 the details of this casing and its cutter mechanism carried thereby are similar to the construction previously described and the descriptions thereof need not be repeated. The shaft 81' which carries the cutter chain sprocket 82' is 110 similar to the corresponding shaft of Figures 5 and 6 except that it is not driven from a series of reducing gears within the casing 70 but instead it passes directly through the head 149 and is journaled in the bearing 148. On its inner end 115 it carries a beveled pinion 150 which meshes with and is driven by the large beveled gear 143 and in this way receives its motion direct from the main motor 22 on the sub-frame platform. The arrangement of the beveled gears 141, 143 and 150 120 125 130 135 140 145 150 shown in the preceding Figures for rotating or positioning the arm 146, except that the segmental gear in this case is mounted upon the hub 147 of the arm 146. The operation of the mechanism for rotating the casing 70' and the cutter mechanism about its axis is identical in principle and the arrangement of the parts similar to the construction shown in Figures 5 and 6, except that I employ worm and spiral gearing on the shafts 81', 84' and 85' instead of the beveled 135 gears 83, 86, 87, 88, 93 and 94 of Fig. 5. The annular series of gear teeth 96 in Figs. 10 and 11, with which the worm gear 95 meshes, is mounted on the face of the head of the flange member 149. Both in the form shown in Figs. 1 and 2 and 140 in the form shown in Figs. 8 and 9, the elongated chain kerf-cutter is connected on rectangularly related axes 81 and 62 to the outer end of the support or head E which is adapted to be turned over on the horizontal axis of the bearing 52. The axis 81 is permanently at right angles to the plane of the cutter bar. In Figs. 1 and 8 the axis 62 is permanently at right angles to the horizontal axial line of the turnover support E but in Fig. 1 the axis 62 is spaced from such axial 150

line while in Fig. 8 the axis 62 intersects such axial line. The said horizontal axis is confined to a fixed elevation relative to the supporting framework mounted on the turntable. The axis 5 62 is confined to adjustment in a vertical plane spaced from the boundaries of the truck and the supporting framework.

When the kerf-cutter is adjusted to a plane parallel to the horizontal axis of turnover of the 10 support E the axis 81 will be at right angles to such horizontal axis. When the kerf-cutter is in such parallel plane it may be operated by operator-controlled self-contained power-operated mechanism solely supported by the truck 15 for sumping the kerf-cutter rectilinearly, feeding the same arcuately and withdrawing the same rectilinearly to cut a parallel ribbed kerf having a depth substantially equal to the active length of the kerf cutter. Such kerfs may be cut in horizontal planes, vertical planes and inclined planes 20 in the upright face of the mine vein from either side of the mine track and in advance thereof while the truck is held stationary on the mine track by any suitable and well-known means.

25 I have previously mentioned that the above described apparatus or machine is capable of and adapted to cut the various kerfs at their various angles in order to carry out my improved method of mining above described. In Figure 14 30 I have diagrammatically illustrated the manner in which the machine may be manipulated to produce the vertical kerfs heretofore described. When it is desired to cut a vertical kerf in the vein of coal the cutter bar A, by reason of its 35 numerous adjustments, may be positioned so that it will lie in a vertical plane. When the kerf-cutter is in a vertical plane or shear cutting position self-contained power-operated mechanism comprising the rack bar 40 may be relied 40 on to feed the kerf-cutter rectilinearly in various directions into the ribs of the mine entry or into the face extending across the space in advance of the mine track. It should be particularly noted that the structure shown in Figs. 1 and 2 45 is such that adjustments may be so made on spaced apart vertical axes, one of which is at the center of the turntable and the other of which is located at 62, that shearing kerfs may be cut parallel to the mine track throughout a 50 wide range between the ribs and parallel thereto. To secure such adjustments in parallelism the turntable may be rotated in one direction and the kerf-cutter swung transversely of its plane on the axis 62 in the opposite direction. 55 Such shearing positions include a vertical plane midway of the mine track rails and parallel thereto. The range of such adjustments in parallelism and in parallelism to the mine track and the ribs may be increased by turning over 60 the kerf-cutter on the horizontal axis of the bearing 52. Since the height of the vein of coal is generally considerably greater than the width of the cutter bar, I prefer to start the kerf by positioning the cutter bar so that it lies in a 65 vertical plane but inclined upwardly at such an angle that its outer end coincides with the roof of the entry or the upper line of cleavage. The cutter bar is diagrammatically illustrated in Figure 14 by the dotted lines Y. The outer end of 70 the cutter bar in this position is presented edge-wise to the end of the face of the wall or end of the vein into which it is to operate and the cutter mechanism advances into the vein in the direction of the arrow Y¹ and while in its angularly 75 adjusted position. The advancement of the cut-

ting mechanism is preferably accomplished by shifting the rack bar 40, as previously described. The advancement in this direction is continued until the cutter bar has entered the vein to the required depth or distance, and since its chain is traveling during this advancement it cuts along the upper line of cleavage. When it has reached the limit of its advancement the cutter bar may be swung or rotated downwardly in the direction of the arrow Y² but still in the plane of itself until its outer end reaches the lower line of cleavage, whereupon with a suitable cutting speed it may be withdrawn from the vein while in this last mentioned adjusted position, the direction of withdrawal being that indicated by the arrow Y³. In other words, to cut a vertical kerf of greater height than the width of the cutter mechanism the cutter mechanism may be moved in three or more directions all in the same plane. It will be observed that I have provided a mining machine construction wherein the cutting mechanism is universally movable or adjustable; that is to say, it may be placed in any position at any angle at which it is desired to cut a kerf.

It should also be understood that when the trunnion arms E² are in the position shown in full lines in Fig. 1, the casing 70 may be swung on the trunnion 62 by operating the wheel 67. In this way, the cutting mechanism or cutter bar 105 A may be swung around so as to occupy a position in a horizontal plane at or near the floor of the mine. After the cutter bar has been brought to this position in the horizontal plane, it may be swung on its pivotal connection with the casing 70 110 by operating the electric motor within the casing F. Power may be transmitted from this motor to swing the cutter bar in one direction or the other on its pivotal connection with the casing 70 by operating the lever 98 at one side or the other 115 of the casing 70, as shown in Fig. 5. It is also evident that the feeding mechanism for moving the trunnion arms E² operates independently of the mechanism for controlling the lateral swinging movements of the cutter bar A. By throwing 120 in the clutch 49, the electric motor 22 may be connected to the feed mechanism at will, and by reversing the electric motor the feed mechanism may be reciprocated whenever desired. Obviously, therefore, the cutter bar A, while occupying a 125 horizontal position, may be swung at an angle and then moved bodily forward by the feed mechanism while the cutter chain is in operation, thereby producing a cut in the mine wall. Furthermore, after this cut has been produced to 130 the required depth, the cutter bar may be swung laterally while the cutter chain is operating, and at the same time the rear portion of the cutter bar may be retracted until the cutter bar occupies a position substantially at right angles to the 135 body of the truck on which the mining machine is mounted. Upon continued swinging movement of the cutter bar, the feed mechanism may be reversed so that the rear portion of the cutter bar will be fed forward during continued operation. By means of this operation, the forward portion of the cutter bar travels over a path which is approximately a straight line.

After the cutter bar has been swung in the opposite direction as far as desired, the swinging movement may be discontinued, and, while the cutter bar still occupies the position at an angle to its pivotal connection to the casing 70, the motor 22 may be reversed so as to cause the feeding mechanism to be drawn back while the cutter bar 145 150

is still operating. It will thus be seen that a square or rectangular cut can be produced in the mine wall, each side of which is approximately a straight line, as well as the base of the cut. The 5 forward end of the cutter bar, during the swinging movement, tends to move over an arc of a circle determined by the angle of the swing, but the reciprocation of the pivot of the cutter bar causes a resultant movement of the outer end of 10 the cutter bar along the chord of such arc of a circle.

The cut at or near the floor of the mine has been referred to merely by way of illustration, and it should be understood that a similar cut can be 15 made at or near the roof of the mine and also at each side wall of the mine, or even at any angle to such cuts, with the exception that whenever such cuts are produced each must be in a plane parallel to the line of the path of travel of the 20 feed bar 40, so as to prevent binding of the cutter bar in the cut.

It should be noted that the mining apparatus above described and shown in the drawings is track mounted and when the rails are extended 25 up to a position near the face of the mine wall the mining apparatus may be swung around by the turntable mechanism to a position where the cutter B may cut a horizontal kerf extending across the front of the mining apparatus from 30 one side of the track to the other. The truck frame 8 constitutes a rigid base frame having supporting wheels which rest upon and are braced by the track, as shown in Fig. 1. The base frame carries a laterally movable cutter arm 35 which extends from the base frame in elevated horizontal planes above the other parts of the apparatus. When the frame E is swung to the dotted line position shown in Fig. 1, the kerf cutter may easily be swung to horizontal position 40 in a plane elevated with respect to the other parts of the apparatus. There may be a plurality of such elevated horizontal planes because the screw threaded bolt 12 may be used to lift and lower the frame D on the truck frame 8. 45 When the kerf cutter is in such horizontal plane its endless cutter chain is movable along the cutter arm in a path horizontal throughout. Furthermore, when the kerf cutter is in its highest position, the motor F is a chain driving motor 50 positioned below the cutter arm and fixedly connected thereto to move bodily therewith whenever the adjusting mechanism 63, 64, is operated. Also, when the kerf cutter is in its uppermost position the power transmission between the 55 kerf cutter and the motor constitutes power actuated means below the arm or frame of the chain cutter for causing such arm and the chain cutter to move laterally to cut a horizontal kerf in the elevated plane extending transversely from one 60 side to the other of the track. Although the track mounted mining apparatus cuts a horizontal kerf extending across its front from one side of the track to the other, the supporting wheels 1 which rest upon the track are braced 65 by the track by means of the tendency of the feed to twist the frame. The flanges of the wheels however, resist this twisting tendency and therefore the feeding operation can be effected. Of course the kerf cutter B may be moved to a 70 horizontal position from its full line position shown in Fig. 1 so as to occupy its lowermost plane. But whether the kerf cutter is in a relatively low cutting plane or in a relatively high plane, the bolt 12 constitutes means for adjusting 75 the cutter arm vertically in parallelism, and such

bolt 12 in combination with the gearing mechanism 63, 64, 56, 57, constitutes means for bodily adjusting the cutter arm vertically in parallelism to move the cutter chain from one set of relatively low cutting planes to another set of relatively high cutting planes. It is also obvious that the power actuated means shown in Figs. 5 and 6 is constructed and arranged to cause the arm and the chain to move laterally to cut a horizontal kerf at any one of several elevations and extending transversely from one side to the other of the track. When the kerf cutter is in its uppermost horizontal plane or in its lowermost horizontal plane the bolt 12 may be relied upon for vertically adjusting the motor and the cutting mechanism in horizontal parallelism and to hold it either where it will form a kerf in relatively low horizontal planes or where it will form a kerf in other horizontal planes relatively higher than those aforesaid. In other words, the bolt 12 constitutes means for adjusting the motor and the cutter frame vertically for the forming of horizontal kerfs in either of several different horizontal planes. The forward feed of the mining machine along the track to new positions may be 100 effected by the power driven reel shown at 34 in Fig. 4, this reel being then movable horizontally with the cutter frame. The cable 36 when anchored, as shown in Fig. 4, and connected to the reel is adapted to cause the forward movement, bodily, of the cutting apparatus.

It should also be observed that the mining machine illustrated in the drawings may make horizontal kerfs at the floor of the mine chamber and horizontal kerfs at the roof of the mine chamber while being moved along the track as a long wall mining machine, the parts being arranged as shown in Fig. 1 except that the cutter B is moved to its lowermost horizontal position and uppermost horizontal position. Kerfs may also be 110 made spaced back from the face of a long wall by adjusting the plane of the kerf cutter to a vertical plane. The machine may also be operated by making vertical kerfs at right angles to the face of the mine wall in which horizontal kerfs 120 and kerfs spaced back from the mine wall have already been produced thereby cutting out large blocks of material from the wall in their entirety.

The operations illustrated in Fig. 14 may also be made substantially horizontally either at or 125 near the floor of the mine chamber or at or near the roof thereof. By referring to Fig. 1 it will be seen that the cutter chain B may be adjusted to a new position at or near the floor. By means of the motor 17 the moving frame 130 mounted on the truck may be given an annular motion in a plane substantially parallel with the surface upon which the machine is supported; that is to say, the cutter chain may be given a movement in a plane substantially parallel with 135 the floor and over a long arc so that the inner end of the cut near the arrow Y² of Fig. 14 may be straighter than when the cutter is swung on the shaft 81 of Fig. 6 as a pivot. When it is desired to feed the cutter along such 140 straighter path, the cutter chain on the projecting cutter arm may be driven by the separate motor F while the worm gearing shown at 95, 96 locks the cutting element against lateral movement relatively to said moving frame. The cutting element is reversible by reason of the worm gearing 56, 57 and whether the cutting element is supported near the roof or near the floor, it may be adjusted to different elevations by means of the bolt 12 shown in Fig. 1. The cutter 150

B which forms a part of the cutting element projects eccentrically from the cutting element because when in horizontal position it is in a plane spaced from the horizontal axis of reversing movement; that is to say, parallel to the axis of the bearing 52. Since the cutter projects eccentrically it may be quickly adjusted from a low position near the floor to a high position near the roof, and further adjustment secured 10 by the bolt 12.

It should therefore be noted that when the cutter arm is in its uppermost position it projects from the top of the cutting element, assuming that the cutter is in its horizontal position near the roof. It will be observed that the framework mounted on the truck is supported at various places and said framework may be moved up and down along said supports to vary the point at which the cutter B engages 15 the material to be cut, particularly when the cutter is in a horizontal position. The cutting element, as above explained, may be inverted to a position near the floor so that the cutter arm then projects from the bottom of the cutting 20 element.

It should also be noted that the machine shown in Fig. 1 includes a feeding mechanism comprising the flexible element 36 which may be anchored outside of the moving frame, as shown 25 in Fig. 4. By means of this feeding mechanism the cutter may be moved forward substantially parallel to itself when it occupies a horizontal position ahead of the track on which the truck is mounted. Another feeding mechanism for the 30 cutter comprises the rack and pinion 42, 43 of Fig. 1, which may be used to move the cutter forward along the line Y¹ of Fig. 14 so as to bring the cutter into new angular positions until it occupies the proper angular position for movement of the cutter along the direction Y². The 35 single motor 22 operates both of these feeding mechanisms.

When the structure shown in Figs. 8 and 9 is substituted for that shown in Fig. 1 and the 40 rack bar 40 is turned so as to extend parallel to the track, the part designated E' may be considered as constituting a rotatable neck which is horizontal and parallel to the machine path. The wheel 60 and the worm gearing to which 45 it is connected constitutes means for actuating said neck. The mechanism comprising the worm 64 constitutes screw mechanism acting on the axis of the shaft 65 transversely to the axial line of the neck E' for supporting the cutting 50 tool A on the neck E' for movement on the latter toward and from the axial line of the neck E'. The cutting tool may also be swung to a horizontal position parallel to the floor where the 55 upright axis 81 shown in Fig. 6 will be forward of the neck E' and perpendicular to the neck axis. Fig. 6 also shows the means for actuating the cutting tool, including not only the driving of the cutting chain B, but also the swinging thereof on the axis 81 by means of the feeding 60 mechanism comprising the worm 95. By referring to Figs. 8 and 9 it will be seen that the rotatable neck E' has an axis which is fixed in elevation relative to the frame D, and horizontal and parallel to the machine path, when the cutter 65 105 is extended in advance of the mine track. The screw mechanism comprising the worm 64 is carried by the neck and acts transversely to the axial line of the neck for supporting and at the will of the operator moving the cutting 70 tool 105 on the neck E' toward and from the

axial line of the neck; that is, from the floor to the position shown in Fig. 8. The motor 22 is seated on the body of the machine and mechanism provided for transmitting motion from this motor to the tool comprising the cutter bar 105 and the driving sprocket shown in Fig. 8. In the construction shown in Fig. 1 the cutter may be swung on an upright axis which is forward of the neck E' and perpendicular to the neck axis when the cutter is in a plane parallel to the axis of the neck. In both the construction shown in Fig. 1 and in the construction shown in Figs. 8 and 9 the cutter may have a swinging movement on the upright axis of the turntable mechanism which is mounted on the truck. 80 85 90

In the construction shown in Figs. 8 and 9 there is a group of members bodily rotatable on the main horizontal relatively stationary axis of the neck E'. This group of members comprises a head 148 journaled on an axis which is perpendicular to the main horizontal axis. A transmission shaft is connected to the chain driving sprocket. The casing for supporting the shaft carrying the sprocket wheel constitutes guiding and supporting means distinct from and parallel 100 and adjacent to the perpendicular axis. The cutting means is applied to this guiding and supporting means and is adjusted thereon toward and from the main horizontal axis by being capable of being swung by means of the wheel 67. 105 The actuating means for the cutting mechanism comprises the beveled gears 141, 143 and 150.

It should also be noted that both in the construction shown in Fig. 1 and in the construction shown in Figs. 8 and 9 the cutter may be 110 swung bodily by means of the wheel 60 and the gearing connected thereto. In this manner the cutting tool may be carried through an orbital path by rotation of the neck E'. By means of the wheel 67 the cutter may be adjusted to various distances from the axis of the neck E', the maximum distance being when the cutter is in horizontal position. That is to say, by movement of the cutting tool toward and from the axial line the distance of the cutting tool from 120 the axial line may be varied and therefore the radius of the orbital path of the cutting tool will be varied. In the structure shown the elongated cutting tool may be carried from the position parallel to the axial line of the neck E' for 125 orbital movement around said line and also for movement from and toward said line, and said cutting tool may also be swung in a plane which is parallel to said axial line when the cutter is in a position parallel to said axial line. 130

The turntable together with the frame D constitutes a body turntable horizontally by means of the wheel 17 as shown in Fig. 1. The support for the cutting tool A is rotatable on a horizontal axis at the center of the cylindrical bearing 52. 135 By means of the worm gearing 63, 64 the cutting tool is movable toward and from such axial line. By referring to Fig. 8, it will be seen that the worm gear 63 extends along a sufficient arc to permit movement of the driving sprocket to a position where its axis will be vertical and since the cutter may be moved through a complete circle, it may be located in an elevated position extending forwardly. With the gear 63 of Fig. 1 extended sufficiently and while the arms E² 140 are depended the cutting tool may occupy a position intermediate the floor and the roof to cut the kerf in the approximate mid-position shown in Figs. 23 and 24.

Figs. 23 and 24 also show the cutting of a kerf 150

at the level of the floor on which the track is laid. By referring to Fig. 1 it will be seen that the machine includes a wheeled track guided truck provided with a base with a pivotal mounting thereon for a cutter bar, this mounting being pivoted to swing on the center of the turntable. Both in the form shown in Fig. 1 and in the form shown in Figs. 8 and 9 the cutter bar is pivoted on this mounting to swing about the vertical axis of the shaft 81, when the kerf cutter is in a horizontal position at the level of the floor. By referring to Fig. 14 and considering the same as a plan view it will be seen that the cutter bar may be disposed in a transverse plane beneath the top of the mine track 3. The turntable permits a wide lateral swinging movement of the supporting framework for the cutter so that it may occupy a position wholly at either side of the mine track for rectilinear feeding movement parallel to the mine track and so that when desired it may be fed arcuately across the end of the track as indicated by the arrow Y² in Fig. 14. By reason of the worm gearing 95, 96 the cutter bar may be held with its longitudinal axis in a vertical plane that includes the vertical axis of the turntable. When held in such position a sumping cut may be made by a rectilinear feeding movement as indicated by the arrow Y¹ in Fig. 14.

The chain cutter comprises cutting elements 117 which circulates around the cutter bar in an orbit within which the pivot 81 is disposed. The upright pivotal support 81 may be shifted laterally by the apparatus for turning the turntable, and such apparatus as above stated may be power operated. That is to say, the upright axis 81 may be swung laterally relatively to the truck on the upright axis at the center of the turntable. The worm gearing 63, 64 holds the pivot 81 in upright position when the kerf cutter is operating at the floor level. The worm gearing 56, 57 holds the tool support against movement in an orbit around the horizontal axis of the bearing 52.

It should be understood that power may be connected to swing the cutter bar on the axis 81, and such connection may be controlled by operating either lever 98 connected to the clutches 91. The angular relation between the cutter bar and the supporting framework may therefore be adjusted whenever desired. For instance, while the tip or extreme outer end of the cutter bar remains stationary the vertical axis 81 may be swung laterally by the turntable and the means for swinging the cutter bar on the axis 81 operated at the same time to effect such a relation of the cutter bar to the framework that its major axis will make a less angle with the line of the track than is made by a line extending from the center of the turntable to the outer end of the major axis. This arrangement is particularly desirable when operating in a narrow entry so that a sumping cut may be made by rectilinear-forward movement parallel to the track, while the kerf cutter is at the floor level and the rear end of the cutter bar is wholly at one side of the track.

That is to say, a sumping cut may be made in a narrow entry by a rectilinear forward feed while the kerf cutter cuts at the mine floor level with the pivot 81 at one side of the mine track. Lateral swinging feeding movement may then be effected while the kerf cutter is at the floor level in advance of the mine track. The cutter bar may then again be adjusted in its angular relation by simultaneously operating the turntable

and the worm gearing 95, 96 to bring the vertical pivot 81 entirely to the other side of the mine track. Reverse rectilinear feeding movement may then be made along such other side of the mine track. It should also be understood that the overhanging arm of the structure may occupy a central position in advance of the mine track and the kerf cutter so adjusted in angular position that it may first be given a rectilinear forward feeding movement as indicated at Y¹ in Fig. 14, then the cutter may be swung across the end of the track as indicated by the arrow Y², and finally withdrawn rectilinearly as indicated by the arrow Y³, which is a reverse feeding movement parallel to the mine track.

Obviously those skilled in the art may make various changes in the details and arrangement of parts without departing from the spirit and scope of the invention as defined by the claims hereto appended, and I wish, therefore, not to be limited to the precise construction herein disclosed.

Having thus shown and described an embodiment of the invention what is desired to be secured by Letters Patent of the United States is:

1. In a mining machine, the combination with an elongated traveling chain cutter, of a support therefor around which said chain cutter travels, a motor, means for carrying said support entirely from said motor, mechanism carried entirely by said support for transmitting power from said motor to said chain cutter, and a universally adjustable support for the self-contained kerf cutting unit comprising said motor, said chain cutter, said first named support, and said intermediate power transmitting mechanism.

2. In a track mounted mining apparatus adapted to cut a horizontal kerf extending across its front from one side of the track to the other, the combination with a rigid base frame, of supporting wheels therefor resting upon and braced by the track, a laterally movable cutter-arm carried by the base frame and extending horizontally therefrom, an endless chain-cutter movable along the cutter-arm in a horizontal path, a chain driving motor connected to said cutter-arm to move bodily therewith, means for bodily moving the said arm to a cutting plane near the upper portion of the apparatus and for moving the arm to a relatively low cutting plane near the lower portion of the apparatus, means for bodily adjusting the elevation of the upper cutting plane and to adjust the elevation of the relatively low cutting plane, and power-actuated means constructed and arranged to cause the arm and the chain to move laterally to cut a horizontal kerf at any one of several elevations near the upper portion of the apparatus and to cut a horizontal kerf at any one of several elevations near the lower portion of the apparatus, such kerfs extending transversely from one side to the other of the track.

3. In a mining machine, the combination with kerf-cutting mechanism, of means for actuating said kerf-cutting mechanism in the plane of itself, means for supporting said cutting mechanism for rotary adjustment on one axis and also rotary adjustment toward and from said axis but on another and transverse axis to enable said cutting mechanism to be presented for operation on an upright mine wall in any angular position relatively thereto from a position perpendicular to the mine wall to a position approaching parallelism therewith, and means comprising a motor for effecting arcuate feed of said

cutting mechanism in any of the planes in which it is positioned.

4. In a mining machine, the combination with a chain kerf cutter, of a support therefor, a motor connected directly to the latter to drive said cutter and carry the chain support entirely, and a universally positioned support for the motor operable to adjust the position of the cutting mechanism so that its plane of operation will lie 10 at any angle with respect to the material to be cut.

5. In a mining machine, the combination with a main frame, of a supplemental frame, an elongated chain kerf-cutter, means for supporting 15 said kerf-cutter on said supplemental frame in planes substantially at right angles to the upright face of the mine wall, means for rotating said supporting means on said supplemental frame to vary the inclination of the plane 20 of said kerf-cutter while remaining substantially at right angles to the mine wall, means for advancing and retracting said supplemental frame relatively to said main frame to effect a rectilineal movement of said kerf-cutter in a 25 plane substantially at right angles to the mine wall, and means for feeding said kerf-cutter in an arc after being fed into the mine wall, said retracting means effecting a withdrawal of the kerf-cutter from the mine wall while being fed 30 in a rectilineal path spaced from the first-named rectilineal movement.

6. In a mining machine, the combination with a main frame, of a supplemental frame, a traveling chain kerf-cutter, a support for said kerf-cutter rotatably mounted on said supplemental 35 frame and holding the kerf-cutter in planes distant from the line of movement of said supplemental frame but parallel to such line of movement, means for adjusting the position of said 40 support to vary the inclination of said kerf-cutter while remaining in planes substantially perpendicular to an upright mine wall, means for advancing and retracting said supplemental frame relatively to said main frame and in a 45 straight line movement to effect rectilineal feeding movements of said kerf-cutter, means for feeding said kerf-cutter in an arc in its own plane, and means for actuating said traveling chain kerf-cutter during rectilineal feed thereof 50 and during arcuate feed thereof.

7. In a coal cutting machine, the combination with a movable base frame, of supporting track wheels therefor, cutter apparatus movable as a unit with respect to the base frame about a normally vertical axis and comprising a motor and a continuously acting kerf-cutting mechanism 55 driven by the motor and extending outward beyond the base frame along normally horizontal lines, means for adjusting the position of said 60 kerf-cutting mechanism to extend along such horizontal lines near the uppermost plane of the machine and near the lower portion of the machine, the said cutter mechanism being movable across one end of the machine about the said 65 vertical axis through an arc extending at each side beyond the vertical plane of the corresponding track wheels, means for locking the cutter apparatus to the base frame at any of several angles, and continuously operable devices connected with the motor for turning the cutter apparatus about the said vertical axis while in operation, or for moving the machine bodily on its wheels while the cutting apparatus is in operation and locked against turning.

75 8. In a mining machine, the combination with

a flat elongated cutter frame, of a traveling endless chain cutter mounted upon and disposed within the plane of said frame, a rotary support rigidly connected to said cutter frame, an additional support to which said rotary support is pivotally connected on an axis substantially perpendicular to the plane of said cutter-frame, automatic means for rotating said rotary support on said additional support to effect arcuate feed of said chain-cutter, means for actuating said chain-cutter during the feed thereof, a bifurcated frame pivotally connected to said additional support on an axis transverse relatively to said first-named axis, and means for adjusting the position of said additional support relatively to said bifurcated frame to vary the angular relation of said cutter-frame and chain-cutter with respect to the material to be cut.

9. In a mining machine, the combination of a cutting mechanism comprising an elongated frame and an endless chain cutter disposed in a plane of said frame, a support upon which said frame is rotatable in the plane of said chain cutter, an additional frame pivotally connected to said support, a longitudinally shiftable frame, a connection between said additional frame and said longitudinally shiftable frame, said additional frame being rotatable about its longitudinal axis by reason of such connection, said frame support being rotatable upon an axis transverse 100 to said longitudinal axis, and means for moving said longitudinally shiftable frame for adjusting the cutting mechanism.

10. In a mining machine, the combination with an elongated kerf-cutter, of a frame connected thereto to move bodily therewith, a rotary support upon which said frame and said cutter are rotatable in the plane of said frame, automatic mechanism carried by said support for actuating said cutter and for feeding the 110 same, means for bodily rotating said support about an axis angularly disposed with respect to the axis of rotation of said frame to adjust said cutter arcuately transversely to its plane, a portable base frame, and a longitudinally shiftable 120 mounting thereon for said support to adjust the cutter rectilinearly relative to said base frame.

11. The combination of an elongated frame, a cutting mechanism mounted thereon and arranged in the plane thereof, a rotary support 125 upon which said frame and cutting mechanism are rotatable in the plane of said frame, driving mechanism carried by said support for actuating said cutting mechanism, means for bodily rotating said support about an axis angularly disposed with respect to the axis of rotation of said frame, a second rotary support for said first rotary support, means for rotating said second support about an axis angularly disposed with respect to the axis of rotation of said first support, and a longitudinally shiftable mounting for said supports to advance the cutting mechanism 130 along the vein.

12. The combination of a traveling truck, a turn-table mounted upon said truck, a longitudinally and transversely shiftable frame supported by said turn-table and rotatable therewith, a rotary supporting device mounted on said frame, a supplemental device mounted upon said supporting device for bodily rotation therewith and arranged for rotary movement upon an axis disposed at an angle with respect to the axis of rotation of said supporting device, and an elongated cutting mechanism carried by said supplemental device and rotatable about an axis 145 150

- angularly disposed with respect to said axis of rotation of the supplemental device.
13. In a wheel-supported coal mining machine adapted to be transported over mine tracks to cut a horizontal kerf while supported on a track extending longitudinally toward the face of the coal, the combination with a base frame, of track wheels for supporting said frame, a rotary frame carried by said base frame and mounted to turn in relation thereto in normally horizontal planes, a shiftable supplemental frame mounted on said rotary frame, continuously acting cutter devices carried by said supplemental frame and adapted when said rotary frame turns to cut a horizontal kerf extending transversely across the track on which the machine stands, means for turning the rotary frame, a motor for actuating the turning means, said motor being mounted to move bodily with the turning means, and means for shifting said supplemental frame to secure rectilinear feed of said cutter devices relatively to said base frame and the track on which said wheels are mounted.
14. In a mining machine, the combination with a flat elongated kerf-cutter, of a rotary frame for supporting said kerf-cutter, a second frame for pivotally supporting said rotary frame, automatic mechanism for rotating said first-named frame relatively to said second frame to feed said cutter in the plane of itself, driving mechanism associated with said first-named frame for actuating said cutting mechanism during such feed thereof, spaced-apart trunnions mounted on said second-named frame to have an axis of rotation independent of the axis of rotation of said first-named frame relatively to said second-named frame and substantially parallel to the plane of said kerf-cutter, and a third frame pivotally connected to said trunnions.
15. In a mining machine, the combination with an elongated chain kerf-cutter, of driving mechanism therefor, a frame for supporting said chain kerf-cutter, means for pivotally supporting said frame on an axis parallel to the plane of said chain kerf-cutter and spaced therefrom, means for supporting and adjusting said axis of rotation for movement bodily in an arc spaced from the axis of the adjusting means, and means for adjusting said kerf-cutter on said first-named axis to intersect a line extending through the axis of said adjusting means.
16. In a mining machine, the combination with an elongated chain kerf-cutter, of means for operating the same including feed thereof in its own plane, a frame for supporting said chain kerf-cutter, a rotary support for pivotally supporting said frame on an axis parallel to the plane of said chain kerf-cutter and spaced therefrom, means for positively rotating said rotary support to bodily shift said frame and said chain kerf-cutter to various positions, and means for adjusting said frame and said chain kerf-cutter on said first-named rotary support for varying the angle at which said cutter is presented to the material to be cut including positions where the path of feeding movement of said cutter or the kerf produced by said cutter intersects a line extending through the axis of said shifting means.
17. In a mining machine, the combination with an electric motor, of kerf-cutting mechanism, power transmission mechanism between said electric motor and said cutting mechanism for operating said kerf-cutting mechanism including feeding movement thereof in an arc in its own plane, and a universally adjustable support for said motor to enable the plane of operation of said cutting mechanism to be varied from positions perpendicular to the face of an upright mine wall, substantially parallel thereto and at any angle between such perpendicular and parallel positions.
18. In a mining machine, the combination with an elongated chain kerf-cutter, of means for operating the same including arcuate feed thereof on an axis of rotation near the rear end of said kerf-cutter, a portable frame, a supplemental frame movably mounted on said portable frame, a reciprocable support for said kerf-cutter and mounted on said supplemental frame, means for moving said supplemental frame relatively to said portable frame to adjust the said reciprocable support in parallelism with the walls of a mine chamber, and means for controlling the reciprocation of said support to effect rectilinear feed of said kerf-cutter relatively to said portable frame.
19. In a system of coal mining devices of the class described, the combination with a wheeled truck, of a cutter frame extending forward from the truck and adapted to swing across the front end thereof, a cutter driving motor supported on the swinging cutter frame, means for adjusting the motor and cutter frame vertically for the forming of horizontal kerfs in either of several different horizontal planes adjacent the floor of a mine chamber, means for adjusting the cutter frame for the forming of horizontal kerfs in either of several different horizontal planes adjacent the roof of the mine chamber, a power driven reel movable horizontally with the cutter frame, and a cable connected thereto and adapted to cause the forward movement, bodily, of the cutting apparatus along such horizontal planes.
20. In a mining machine, the combination with a main frame, of track supporting wheels therefor, a chain kerf-cutter, means for operating said kerf-cutter, a frame for supporting said chain kerf-cutter on an axis parallel to the plane of said cutter and spaced therefrom, means for rotating said frame on an axis transverse to said parallel axis, a supplemental frame mounted on said main frame and carrying said transverse axis, and means for moving said supplemental frame relatively to said main frame to secure rectilinear movement of said kerf-cutter in a direction parallel to said transverse axis.
21. In a track mounted mining machine adapted to cut a horizontal kerf extending across its front from one side of the track to the other, the combination with a rigid supporting frame, of supporting wheels therefor resting upon and braced by the track, a laterally movable cutter arm carried by the supporting frame and adjustable to positions extending from said frame in elevated horizontal planes spaced above a horizontal plane extending along the top of said frame and also adjustable to positions extending from said frame in horizontal planes below the plane extending through the top of the said frame, an endless chain-cutter movable along said cutter-arm in a path horizontal throughout, a chain driving motor connected to said cutter arm to move bodily therewith, and power-actuated means for causing said arm and said chain-cutter to move laterally to cut a horizontal kerf in one of said elevated planes extending transversely from one side to the other of the track and for causing said arm and said chain-cutter to move laterally to cut a horizontal kerf in a

plane below the top of said frame when adjusted to such plane.

22. In a mining machine, the combination with a truck, of a turn table mounted on said truck, 5 a main frame mounted on said turn table, a longitudinally shiftable bar supported by said main frame, a motor, means driven by said motor and under control of the operator for advancing and retracting said bar, cutting mechanism, means for 10 universally supporting said cutting mechanism from said bar radially distant from the line of movement thereof, and means for operating said cutting mechanism.

23. In a mining machine, the combination with 15 a wheel supported base frame, of a supplemental frame rotatably mounted thereon, a reciprocable frame mounted on said supplemental frame for rectilinear movement relatively thereto, elongated kerf-cutting mechanism supported by said 20 reciprocable frame, means for operating said kerf-cutting mechanism including arcuate feed thereof relatively to said reciprocable frame, means for advancing and retracting said reciprocable frame to secure rectilinear feed of said 25 kerf-cutting mechanism, means for adjusting the elevation of said supplemental frame on said base frame to effect an adjustment in elevation of said kerf-cutting mechanism, and means for rotating said supplemental frame together with 30 said reciprocable frame and said kerf-cutting mechanism relatively to said base frame to enable said kerf-cutting mechanism to operate on a mine wall on either side of the track on which the machine is mounted or in advance of such 35 track.

24. In a mining machine, the combination with cutting mechanism, of a motor, a frame for said cutting mechanism and pivotally connected to said motor whereby said cutting mechanism and 40 said frame derive their sole support from said motor, operating gearing between said motor and said cutting mechanism, additional gearing connected to said first-named gearing to effect the feeding of said cutting mechanism by rotary 45 movement of said frame on its pivotal connection to said motor, and a support for said motor to hold the same relatively stationary during the operation of said cutting mechanism.

25. In a mining machine, the combination with 50 cutting mechanism, of a motor, a gear secured to the frame of said motor concentric with the armature shaft thereof, means connected between the motor armature and said gear for effecting feeding movement of said cutting mechanism, and a support for said motor.

26. In a mining machine, the combination with a main frame, of a supplemental frame, means for moving the said supplemental frame relatively to said main frame, a third frame pivoted to said 60 supplemental frame, means for adjusting the position of said third frame relatively to said supplemental frame, a motor pivoted to said third frame, a kerf cutter pivotally connected to said motor, power transmission mechanism between 65 said motor and said kerf cutter, and means for effecting a feeding motion of said kerf cutter.

27. In a mining machine, the combination with an electric motor, of a casing pivoted to the periphery of the frame of said electric motor, a 70 frame for said cutting mechanism and connected rigidly to said casing, power transmission gearing between the armature of said electric motor and said kerf cutting mechanism and enclosed by said casing, a gear fixed to the frame of said electric motor within said casing, reversing gearing 75

connected between said power transmission gearing and the said gear fixed to the frame of said motor for effecting a feeding operation of said kerf cutting mechanism in either direction, and manually operated devices for controlling the 80 directions of the feeding operation.

28. In a mining machine, the combination with a truck, of a main frame pivotally mounted on said truck, turn table mechanism for rotating said frame on said truck, a motor mounted on said main frame, a supplemental frame slidably mounted on said main frame, power transmission gearing between said motor and said supplemental frame, means for controlling the said gearing to effect advancing and retracting movements of said supplemental frame, a bifurcated frame pivoted to said supplemental frame, means for adjusting the position of said bifurcated frame relatively to said supplemental frame, a motor pivoted between the arms of said bifurcated frame, 90 means for adjusting the position of said last named motor relatively to said bifurcated frame, a casing pivoted to said last named motor, a kerf cutter, a frame for said kerf cutter fixed to said casing, power transmission mechanism between 95 said last named motor and said kerf cutter, means mounted within said casing for effecting a feeding operation of said kerf cutter by moving said casing on its pivotal connection with said last named motor, and means for controlling without 100 said casing the operation of said feeding means.

29. In a mining machine, the combination with universally adjustable supporting mechanism, of a kerf cutter, a frame for said kerf cutter and pivotally connected to said supporting mechanism, 110 means for driving said kerf cutter, means connected to said kerf cutter operating means for feeding said kerf cutter in its own plane by moving said frame on its pivotal connection with said supporting mechanism, and means for bodily 115 moving said support and mechanism to secure a linear feed of said kerf cutter also in the plane thereof.

30. In a track-mounted mining apparatus adapted to cut a horizontal kerf extending across 120 its front end from one side of the track to the other or to cut a horizontal kerf on either side of the track and extending transversely thereof, the combination with a rigid base frame, of supporting wheels therefor resting upon and braced by 125 the track, a laterally movable cutter arm carried by said base frame and extending therefrom in elevated horizontal planes above the other parts of the apparatus, an endless chain-cutter movable along said cutter arm in a path horizontal 130 throughout, a chain driving motor positioned below the cutter arm and fixedly connected thereto to move bodily therewith, power-actuated means below said arm for causing it and the chain-cutter to move laterally to cut a horizontal kerf in the 135 aforesaid elevated planes extending transversely from one side to the other of the track, mechanism for effecting rectilinear feed of said cutter-arm and chain-cutter transversely of said base frame to cut kerfs on either side of the track 140 transversely thereto, and propelling mechanism for said base frame to effect rectilinear feed of said arm and chain-cutter in advance of the track and parallel thereto.

31. In a track-mounted mining apparatus 145 adapted to cut a horizontal kerf across its front from one side of the track to the other and along its sides parallel to the track, the combination with a rigid base frame, of supporting wheels therefor resting upon and braced by the 150

- track, a laterally movable cutter-arm carried by said base frame and extending horizontally therefrom, an endless chain cutter movable along said cutter-arm in a horizontal path, a chain driving motor connected to said cutter-arm to move bodily therewith, means for bodily adjusting said arm vertically in parallelism to move the chain-cutter from one set of relatively low cutting planes adjacent the floor of a mine chamber to another set of relatively high cutting planes adjacent the roof of the mine chamber, power-actuated means constructed and arranged to cause the arm and the chain-cutter to move laterally to cut a horizontal kerf at any one of several elevations and extending transversely from one side to the other of the track and along the track on either side thereof, and mechanism for effecting rectilinear feeding movement of said cutter-arm and such chain-cutter at any of its adjusted elevations at right angles to the track, parallel thereto and at any angle between such positions at right-angles to the track and parallel thereto.
32. In a system of coal mining, the combination with a wheeled-truck adapted to run upon and be laterally braced by a track extending longitudinally toward an upright coal face, of cutter mechanism supported upon and movable horizontally, while cutting, across the front end of the truck and along either side thereof, a motor movable bodily with the cutter mechanism, means for vertically adjusting the motor and the cutting mechanism in horizontal parallelism and adapted to hold either where it will form a kerf in relatively low horizontal planes or where it will form a kerf in other horizontal planes relatively higher than those aforesaid, power-actuated mechanism on the truck for causing the transverse movement of the cutting mechanism across the front end of the truck and along both sides of said truck, and means for effecting rectilinear feed of said cutting mechanism relatively to said truck through a range of 180 degrees or more relative to the position of said truck on the track.
33. In a system of coal mining, the combination with a wheeled-truck, of a cutter frame extending forward from the truck and adapted to swing across the front end thereof and along both sides thereof through an angle of 180 degrees or more, a cutter driving motor supported on the swinging cutter-frame, means for adjusting the motor and the cutter frame vertically for the forming of horizontal kerfs in either of several different horizontal planes, means for effecting rectilinear feed of said cutter in any of its arcuate positions within the range of its swinging path of travel, such rectilinear feeding movement being relatively to said truck, a power-driven reel movable horizontally with the cutter frame, and a cable connected to said reel and adapted to have its free end anchored in the mine chamber to propel said truck bodily with said cutting apparatus.
34. In a mining machine, the combination with a supporting frame, of a plane elongated kerf-cutter, means for operating said kerf-cutter including feed thereof in its own plane on an axis substantially at right angles thereto and near one end thereof, means for adjustably supporting said kerf-cutter on said supporting frame in position to cut kerfs in relatively low horizontal planes and in position to cut kerfs in relatively high planes while said supporting frame remains stationary and said kerf-cutter remains projecting forwardly from said frame, and additional supporting mechanism, and mechanism associated with said additional supporting member for effecting adjustments of said kerf-cutter in arcs transverse to its plane while still projecting forwardly from said frame from the low position of said kerf-cutter upwardly toward the position nearly parallel to the mine wall and also in an arc transverse to the plane of said kerf-cutter downwardly from its upper position toward a position substantially parallel to the mine wall.
35. In a mining machine, the combination with a main frame, of a second frame mounted on said main frame for arcuate movement on a forwardly extending axis, a third frame mounted on said second frame for arcuate movement on an axis extending transversely of the first-named axis and spaced therefrom, a kerf-cutting mechanism mounted on said third frame for feeding movement in its own plane on an axis perpendicular thereto and transversely of said second-named axis, means for rotating the second frame on the first-named axis to adjust the elevation of said second-named axis and the elevation of said third frame together with the kerf-cutting mechanism carried thereby to adjust the kerf-cutting mechanism from positions in relatively low cutting planes to positions in relatively high cutting planes while said kerf-cutting mechanism remains extending forwardly from all of said frames, and means for adjusting the third frame and said kerf-cutting mechanism on said second-named axis to adjust the inclination of said kerf-cutting mechanism from said relatively low cutting planes toward cutting planes approaching parallelism to the mine wall and also to adjust said kerf-cutting mechanism from relatively high cutting planes in an arc downwardly toward positions approaching parallelism with the mine wall.
36. In a mining machine, the combination with a portable frame, of a supplemental frame mounted thereon to move in an arc relatively thereto on an upright axis, a third frame mounted on said supplemental frame to move rectilinearly relatively to said supplemental frame, a fourth frame carried by said third frame and mounted thereon to move in an arc on a substantially horizontal axis extending forwardly, a fifth frame carried by said fourth frame and mounted thereon to move in an arc on an axis extending transversely of said forwardly projecting axis and spaced therefrom, an elongated kerf-cutter mounted on said fifth frame for feeding movement on an axis near the rear end thereof substantially at right angles to the plane of said kerf-cutter and transversely of said second-named axis, means for rotating said fourth frame on said third frame to adjust the position of said kerf-cutter for presenting the same to the mine wall in planes at the floor, at the roof, and at the spaced-apart side walls, means for effecting rectilinear feed of said kerf-cutter in opposite directions into and out of the mine wall by effecting rectilinear feed of said third frame on said supplemental frame to cut kerfs at the floor, at the roof and at the spaced-apart side walls, means for operating said kerf-cutter including arcuate feed thereon on said axis at the rear portion thereof to widen the kerfs effected by the reciprocation of said third frame, means for rotating said fifth frame on said second-named axis to adjust the cutter along arcs transversely thereof away from the kerfs cut substantially perpendicular to the mine wall, and turntable mechanism between said portable frame and said supplemental frame to effect arcuate feed of said kerf-cutter on a

- long radius while said third frame remains in its forwardly extending position and while said kerf-cutter remains in a position with its lateral edges in upright planes and extending alternately on 5 an incline forwardly and upwardly and on an incline forwardly and downwardly to effect complete cutting out of blocks of material from a mine wall at the head of a narrow entry.
37. In a mining machine, the combination with 10 a main frame, of a supplemental frame mounted on said main frame to move in an arc relatively to said frame, a third frame mounted in substantially horizontal position on said supplemental frame for rectilinear feeding movement relatively to said supplemental frame, an elongated plane kerf-cutter carried by said third frame, means for moving said third frame to effect reciprocatory rectilinear feeding movements of said kerf-cutter into and out of the mine wall 15 20 in a plane substantially parallel to the line of movement of said third frame, means for moving said supplemental frame in an arc relatively to said main frame to secure arcuate movement of said kerf-cutter on a comparatively long radius between the rectilinear feeding movements of 25 said kerf-cutter, and means for actuating said kerf-cutter during such rectilinear reciprocatory feeding movements and during such arcuate feeding movement.
38. In a mining machine, the combination with 30 a main frame, of a supplemental frame rotatably mounted on said main frame, a third frame mounted on said supplemental frame for rectilinear reciprocatory movements relatively to said supplemental frame, a plane elongated kerf-cutter carried by said third frame in a plane substantially parallel to the path of movement thereof and substantially perpendicular to the face of an upright mine wall, means for adjusting said kerf-cutter for presentation to the mine wall at 35 any inclination consistent with its remaining substantially in a plane perpendicular to the face of the mine wall, means for moving said third frame to secure reciprocatory feeding movements of said kerf-cutter in any of its adjusted positions, means for moving said supplemental frame in an arc on said main frame to secure arcuate feeding movement of said kerf-cutter on a long radius when said kerf-cutter is in a relatively high plane 40 or in a relatively low plane, and means for actuating said kerf-cutter during such reciprocatory feeding movements thereof and during such arcuate feeding movements thereof.
39. In a mining machine, the combination with 45 a main frame, of a supplemental frame rotatably mounted on said main frame, a third frame mounted for rectilinear reciprocatory movements on said supplemental frame, a fourth frame mounted on said third frame for rotary movement on a horizontal axis relatively to said third frame, a fifth frame mounted on said fourth frame for arcuate movement on an axis spaced from said horizontal axis and extending transversely thereof, an elongated kerf-cutter mounted on said 50 fifth frame for bodily movement therewith on said transverse axis, means for adjusting the position of said fifth frame on said transverse axis relatively to said fourth frame to adjust the position of said kerf-cutter from a position substantially perpendicular to the mine wall to a 55 position substantially parallel thereto or to any intermediate position, means for rotating said fourth frame relatively to said third frame on said horizontal axis to vary the elevation of said transverse axis and the position of said kerf- 60 cutter, means for moving said third frame to secure rectilinear feeding movements of said kerf-cutter when the latter is adjusted to a position in a plane parallel to the path of reciprocatory movement of said third frame, and means for moving said supplemental frame in an arc on said main frame to secure arcuate feeding movement of said kerf-cutter between reciprocatory rectilinear feeding movements when said kerf-cutter is in horizontal planes, and to secure arcuate feeding movements when said kerf-cutter is adjusted to positions extending into the mine wall on an upward incline and when extending into the mine wall on a downward incline. 65
40. In a mining machine, the combination with a main frame, of a supplemental frame rotatably mounted thereon for movement in an arc on an upright axis, a reciprocatory frame mounted on said supplemental frame for rectilinear movement relatively thereto, an elongated kerf-cutter, means for adjustably supporting said elongated kerf-cutter on said reciprocatory frame, means for adjusting said supporting means to support said kerf-cutter in a substantially horizontal relatively high cutting plane and to support said kerf-cutter in a substantially horizontal and relatively low cutting plane, means for operating said reciprocatory frame to effect reciprocating feeding movements of said kerf-cutter at such relatively high cutting plane and at such 70 relatively low cutting plane, and means for moving said supplemental frame in an arc on said main frame to secure arcuate feeding movement of said kerf-cutter between the reciprocatory feeding movements thereof. 75
41. In a mining machine, the combination with a main frame, of a supplemental frame mounted thereon for movement in an arc relatively thereto on an upright axis, a reciprocatory frame mounted on said supplemental frame for rectilinear movements relatively thereto, an elongated kerf-cutter, adjustable supporting mechanism for supporting said kerf-cutter for operation in a relatively high plane and in a relatively low cutting plane, each of said cutting planes 80 being substantially horizontal and parallel to the path of movement of said reciprocatory frame, mechanism for adjusting said supporting means to position said kerf-cutter in either of said planes, further adjusting mechanism for locating 85 the kerf-cutter to extend into the mine wall upwardly to the upper plane and also downwardly into the mine wall to the horizontal plane in accordance with the adjustments, and means for effecting feeding movement of said kerf-cutter 90 when in either of its horizontal planes or in either of its inclined positions to effect the cutting out from the mine wall of sections of material. 95
42. In a mining machine, the combination with a truck adapted to run on a track spaced from a mine wall and parallel thereto, of a reciprocatory supplemental frame mounted on said main frame for movement relatively thereto transversely of the track, an elongated flat chain kerf-cutter, means for adjustably supporting said kerf-cutter 100 on said reciprocatory frame for adjustment on spaced-apart axes, one of which occupies a position parallel to the path of reciprocatory movement of said frame and the other of which is transverse to such parallel axis and spaced therefrom, means for adjusting the kerf-cutter on said parallel axis to vary the position of the kerf-cutter from an upright kerf on one side of said axis to an upright kerf on the other side thereof, means for moving said frame to feed 105

5 said cutter when in position for cutting upright spaced-apart kerfs, means for feeding the kerf-cutter in an arc on an axis perpendicular thereto within the boundary thereof and near the rear end thereof between the forward and retracting movements of said reciprocatory frame, means for adjusting the inclination of the kerf-cutter along arcs transversely of its plane when said transverse axis is parallel to the mine wall, 10 and means for propelling the truck along the track to secure rectilinear feed of said kerf-cutter along its plane and along the mine wall.

15 43. In a mining machine, the combination with an elongated kerf-cutter, of means for supporting said kerf cutter for adjustment on an axis spaced therefrom and parallel to the plane thereof, means for adjusting said kerf-cutter by adjusting said axis to an upright position, a reciprocatory frame, a main frame for carrying said 20 reciprocatory frame, means for effecting reciprocation of said first named frame while said axis is in an upright position to secure feeding movement of said kerf-cutter transversely of the mine wall to effect the cutting of an upright kerf, 25 means for adjusting the inclination of said kerf-cutter in an arc transversely thereof on the axis parallel to the plane thereof, and propelling mechanism for said main frame to effect the feeding movement of said kerf-cutter in a plane extending through said kerf-cutter while said axis 30 extends along the mine wall.

35 44. In a mining machine, the combination with a truck adapted to run on a track parallel to the mine wall and spaced therefrom, of a reciprocatory frame mounted on said truck transversely of said track, an elongated kerf-cutter, a third frame carried by said reciprocatory frame for movement relatively thereto on an axis parallel to the path of movement thereof, a fourth frame 40 pivotally mounted on said third frame on an axis extending transversely of said third frame axis and spaced therefrom, an elongated kerf-cutter mounted on said fourth frame for arcuate movement on an axis perpendicular to the plane of 45 said kerf-cutter and extending transversely of the fourth frame axis, means for adjusting the position of said kerf-cutter arcuately transversely of the plane thereof, means for adjusting the position of said third frame together with the parts 50 carried thereby including said kerf-cutter, means for operating said reciprocatory frame to feed said kerf-cutter rectilinearly perpendicularly of the mine wall, and means for propelling said truck to effect rectilinear feeding movement of said 55 kerf-cutter along the mine wall.

60 45. In a mining machine of the class described, the combination of the main frame, the cutter bar mounted at one end of the frame and adapted to swing from a working position where it projects laterally in one direction from the frame to another position where it projects oppositely from the other side of the frame, the cutting device carried by the said bar, the driver for the cutter device, a motor shaft positioned in the transverse 65 planes of the central part of the frame with its longitudinal axis parallel to the longitudinal lines of the frame, an extensible power transmitting shaft having a horizontal axis parallel to that of said motor shaft and operatively connected to said motor shaft and to said cutter driver, and means for supporting said cutter bar at various distances from said motor.

70 46. In a machine of the nature described, the combination of a tool support rotatable on a horizontal axis, mechanism for effecting rotation of

80 said support, a cutting tool, members supporting said tool on said rotary support for swinging the tool in a plane parallel to the axial line of said rotatable support, and a motor carried by said rotatable support for effecting said swinging of the cutting tool, and means for actuating the cutting tool, substantially as described.

85 47. In a mining machine, a wheeled truck movable over a trackway, a horizontal turntable mounted thereon, cutting mechanism carried by said turntable and including a cutter bar having circulating cutting elements and pivoted to swing about an axis offset from, but parallel, to the axis of rotation of said turntable, means for holding said cutter bar in different horizontal angular positions relative to a straight horizontal line intersecting the pivotal axes of the bar and of the turntable, actuating means for said cutter bar operative to effect circulation of said cutting elements including a motor mounted on said turntable and driving connections between the same and said cutting elements, and means for adjusting said bar vertically rectilinearly from positions wherein the bottom of the horizontal kerf cut thereby will constitute a continuation of the surface upon which the trackway is mounted.

90 48. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving 105 connections between the same and said bar, and means for adjusting said bar vertically rectilinearly from positions wherein the bottom of the horizontal kerf cut thereby will constitute a continuation of the surface upon which the trackway is mounted, and motor driven driving means for effecting movement of the truck along the trackway.

100 49. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding 110 said cutter bar in different angular positions relative to a straight horizontal line intersecting the pivotal axis of the bar and of the turntable, actuating means for said cutter bar operative to effect circulation of said cutting elements including a motor mounted on said turntable and driving 115 connections between the same and said bar, and means for adjusting said bar vertically rectilinearly from positions wherein the bottom of the horizontal kerf cut thereby will constitute a continuation of the surface upon which the trackway 120 along which the truck runs is mounted, and motor driven driving means for effecting movement of the truck along the trackway.

115 50. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding 130 said cutter bar in different angular positions relative to a straight horizontal line intersecting the pivotal axis of the bar and of the turntable, actuating means for said cutter bar operative to effect circulation of said cutting elements including a motor mounted on said turntable and driving 135 connections between the same and said bar, and means for adjusting said bar vertically rectilinearly from positions wherein the bottom of the horizontal kerf cut thereby will constitute a continuation of the surface upon which the trackway 140 along which the truck runs is mounted, and motor driven driving mechanism for effecting movement of the truck along the trackway.

145 51. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis 150

- of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections between the same and said bar, and means for moving said turntable vertically rectilinearly to bring said bar into positions wherein the bottom of the horizontal kerf cut thereby will constitute a continuation of the surface upon which the track along which the truck runs is mounted.

5. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections between the same and said bar, means for adjusting said bar vertically rectilinearly from positions wherein the bottom of the horizontal kerf cut thereby will constitute a continuation of the surface upon which a track along which the truck runs is mounted, and means operated by said first-mentioned motor for changing the angle of said bar to a working face.

52. In a mining machine, a wheeled truck movable along a trackway, a horizontal turntable mounted thereon, cutting mechanism carried by said turntable and including a cutter bar having circulating cutting elements and pivoted to swing about an axis offset from but parallel to the axis of rotation of said turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections between the same and said bar, means for adjusting said bar vertically rectilinearly from positions wherein the bottom of the horizontal kerf cut thereby will constitute a continuation of the surface upon which the track along which the truck runs is mounted, and said bar being disposable on the bottom wholly outside the track and making a less angle with the track than the angle between said horizontal straight line and the line of the track.

53. In a mining machine, the combination of a wheeled track guided truck providing a base arranged in fixed relation to the axes of the wheels, a vertically pivoted frame member mounted above said base, supporting means for the latter permitting bodily vertical adjustment thereof relative to said base, an arm projecting from said vertically pivoted frame member, and cutting mechanism including a pivoted cutter bar pivoting in a depending bracket formed on said arm, driving means for said cutter bar including a vertical shaft, a motor on said frame, and driving connections between said shaft and motor, said parts being constructed and arranged to permit said bar to be lowered to the bottom upon which a track guiding the truck wheels is positioned and separate from said motor.

54. In a mining machine, the combination with a wheeled track guided truck providing a base, a turntable mounted thereon and including a member adjustable vertically relative to said base but held against rotary movement with respect thereto, a rotatable turntable element supported and guided by said member and rotatable on a vertical axis passing through the center of said member, a cutter bar supported by and pivotally mounted relative to said rotatable turntable element to swing about an axis parallel to but offset from the axis of the turntable, said axis of bar swing falling outside said member, means for locking said bar in a plurality of angular positions relative to said turntable and said turntable in a plurality of angular positions relative to said base, and means operative to vertically adjust the member.

55. In a system of coal mining apparatus comprising a ground-supported track and a portable mechanism adapted to be transported over and remain permanently upon and be braced by said track, and also adapted to cut a horizontal kerf in a coal face while supported on a section of track extending longitudinally toward said face, the combination with a rigid base frame, of wheels secured to said base frame and resting upon and braced by said track section, a supplemental frame mounted on said base frame for vertical adjustment relatively thereto, mechanism comprising telescoping guides for permanently confining said supplemental frame against tilting movement up or down relatively to said base frame, screw lifting mechanism for effecting said vertical adjustment, a narrow elongated cutter arm carried by said supplemental frame and movable therewith horizontally and laterally across the front of said base frame, the forward end of said arm extending horizontally to points outside and remote from the vertical bounding lines of the base frame, a cutter chain mounted to move in a horizontal path around the periphery of said arm, power transmission mechanism carried by said supplemental frame and connected to said cutter chain, a motor connected to said power transmission mechanism, and means operated by said motor for feeding said cutter chain while being actuated to effect the cutting of an elongated horizontal kerf in an upright mine wall adjacent said supplemental frame.

56. In a coal mining machine, the combination with a wheel-supported rigid base frame, of a supporting frame vertically adjustably mounted on said base frame, a cutter frame on the supporting frame and held rigidly connected thereto during operation, an endless chain cutter mounted on said cutter arm in a plane above the other parts of the machine, a motor on said supporting frame, gearing for transmitting the power of the motor to drive said chain cutter, means for adjusting the supporting frame together with the cutter frame vertically with respect to the base frame, telescoping guides between said base frame and said supporting frame for permanently confining said supporting frame against tilting movement up or down relatively to said base frame, and means for effecting the feed of said chain cutter during the actuation thereof.

57. In a mining machine, the combination with a main frame, of a supplemental frame movable horizontally rectilinearly relatively to said main frame, a cutting element, means for pivotally supporting said cutting element on an upright axis on said supplemental frame with the space in front of said supplemental frame free and

- unobstructed except for said upright pivotal support and said cutting element, means for adjusting the position of said upright pivotal support, a motor for swinging said cutting element about 5 its upright pivotal support relatively to said supplemental frame, and worm gearing connecting said motor with said cutting element to hold the latter in its various adjusted positions.
58. In a mining machine, the combination with 10 a kerf-cutter, of a frame for carrying said kerf-cutter, an additional frame, a two-armed fork for supporting said kerf-cutter carrying frame on said additional frame for arcuate adjustment of said kerf-cutter carrying frame on a horizontal 15 transverse axis to vary the inclination of the kerf-cutter up or down, and means for supporting said kerf-cutter on said kerf-cutter carrying frame for swinging feeding movement on an upright axis.
59. In a mining machine, the combination with 20 a supporting frame having a portion extending forwardly toward the upright working face of a mine vein, of a second frame suspended from said forwardly extending portion of said supporting frame for tilting movements on a horizontal trans- 25 verse axis in fixed relation to said supporting frame and substantially parallel to such working face, a third frame pivoted to said second frame for swinging movement relatively to said supporting frame on an upright axis at right angles 30 to said horizontal transverse axis, a plane kerf-cutter carried by said third frame and confined to a plane at right angles to the said upright axis, and means for operating said kerf-cutter includ- 35 ing swinging feeding movement thereof across the said working face in advance of said supporting frame while said transverse axis remains in substantial parallelism with said upright working face.
60. In a mining machine, the combination with 40 a portable supporting frame, of an elongated flat chain kerf-cutter, means for mounting said kerf-cutter to swing relatively to said supporting frame on an upright axis through an angle of 180 degrees or more from a position at one side of said frame approximately forwardly and laterally in 45 advance of said supporting frame to the other side of the latter, means for adjusting the inclination of said kerf-cutter on a horizontal axis extending transversely of the longitudinal length 50 of the machine while maintaining said upright axis of swinging movement at right angles to the plane of said kerf-cutter to compel the latter to cut a kerf in a plane at right angles to such axis, and self-contained power-operated mechanism connected to said kerf-cutter near the axis 55 of feeding movement thereof to drive the kerf-cutter and effect feeding movement thereof to cut a kerf in a plane at right angles to such feeding axis while said supporting frame remains stationary.
61. In a mining machine, the combination with 60 a forked supporting frame, of a supplemental frame pivotally mounted on said supporting frame for swinging movement relatively thereto and for support thereby in elevated position, a chain kerf-cutter, a cutter frame mounted on said supplemental frame for pivotal swinging feeding movement relatively thereto, means for tilting said supplemental frame together with said cutter frame and said kerf-cutter relatively to said supporting frame, and self-contained power-operated mechanism between said cutter frame and said supplemental frame for driving the kerf-cutter 65 and for feeding the same by movement of said cutter frame relatively to said supplemental frame to cut a plane kerf for all adjustments of said supplemental frame relatively to said supporting frame.
62. In a mining machine, the combination with 70 a frame, of an elongated kerf-cutter mounted thereon to extend outwardly from one end thereof for insertion into an upright mine wall, a circular extension from the upper side of the other end of said frame, an annular bearing for receiving said extension from below, and means for swinging said frame on said annular bearing to feed said cutter to cut a kerf in a plane at right angles to the axis of swinging movement of said frame.
63. In combination, a mining machine truck, a support non-rotatably carried thereon but movable longitudinally therealong, a co-operating support pivoted on said support on a longitudinal axis, means for adjusting said co-operating support about its axis in either direction from the horizontal, and kerf-cutting mechanism on said co-operating support.
64. In a mining machine, a support, cutting mechanism carried by said support and includ- 80 ing a swinging cutter bar, means for moving said bar to different planes respectively at angles to each other including a plurality of means for changing the plane of cut of said cutter bar, means for actuating the same, each operative independently of the other and respectively moving the bar in different paths, power actuated means for swinging said cutter bar, power actuated means for feeding said cutter bar, and a common source of power for said power actuated means.
65. In a mining machine, a frame movable on a trackway and including a horizontally dis- 85 posed guiding way, a motor reciprocable along a path parallel to said guiding way, and cutting mechanism operatively connected to said motor and including a pivotally mounted cutter chain carrying cutter bar swinging in a plane below and parallel to the plane of said way and adapted to be swung across the front end thereof.
66. In a mining machine, a wheeled frame including laterally spaced guiding members disposed in substantially the same horizontal planes, a motor reciprocable along a path parallel to said members, a swivel head operatively connected to 90 said motor, cutting mechanism operatively connected to said head and to said motor and including a pivotally mounted cutter bar horizontally disposed below the plane of said guiding members, and means for swinging said bar relative to said swivel head.
67. In a mining apparatus, in combination, a track, a wheeled truck movable thereon, a support swiveled on a fixed vertical axis on said truck, motor driven cutting mechanism carried 95 on said support and including a cutter bar movable to and swingable in horizontal and vertical planes, and means operative in different positions of said cutting mechanism whereby movement of said truck and of said bar bodily recti- 100 linearly relative to said truck may be had, said means including a common actuating element.
68. In a mining machine, the combination with 105 an elongated plane kerf-cutter, of a motor connected directly to said kerf-cutter, said kerf-cutter being carried directly by said motor to move bodily therewith, means for swinging said kerf-cutter on an axis at right angles to the plane thereof to cut a kerf at right angles to said axis, and a universally adjustable support for said 110

- motor and said kerf-cutter while said axis remains at right angles to the plane of said kerf-cutter.
69. In a mining machine, the combination with 5 a base frame, of a supplemental frame slidable rectilinearly and horizontally along said base frame, an elongated plane chain kerf-cutter, means for supporting said kerf-cutter on said supplemental frame for adjustment on a horizontal axis between horizontal and vertical cutting positions, a motor, mechanism driven by said motor for driving said kerf-cutter, and mechanism driven by said motor for sliding said supplemental frame rectilinearly and horizontally 10 along said base frame to effect rectilinear and horizontal feeding movement of said kerf-cutter in its adjusted position. 15
70. In a mining machine, the combination with a truck adapted to travel on a track, of a supporting frame mounted on said truck for movement relatively thereto on an upright axis, means for swinging said supporting frame relatively to said truck and locking such supporting frame in adjusted position, a supplemental frame 20 mounted on said supporting frame for rectilinear movement relatively thereto, a plane chain kerf-cutter pivoted to said supplemental frame, means for swinging said plane chain kerf-cutter relatively to said supplemental frame and locking 25 the same in adjusted position, and means for advancing and retracting said supporting frame rectilinearly relatively to said supplemental frame to present said plane chain kerf-cutter edgewise to the upright face of a vein and effect the cutting 30 of a plane kerf at right angles to such face while the kerf-cutter is locked against swinging movement and while said truck is stationary with the supporting frame and the supplemental frame 35 extending transversely of the track.
71. In a mining apparatus, the combination with a truck adapted to travel on a mine track, of a supporting frame pivoted to said truck to swing relatively thereto on an upright axis, means locking said supporting frame in an adjusted angular position relative to said truck, an elongated chain kerf-cutter pivoted to said supplemental frame on a vertical axis spaced horizontally, from the vertical axis of said supporting 40 frame, means affording adjustment of the space between said vertical axes, means locking said elongated kerf-cutter in adjusted position relative to said supporting frame, and means for moving the whole machine along the mine track at a feeding speed to present the chain kerf-cutter 45 edgewise to the upright face of the mine vein and cut a rectilinear kerf therein.
72. In mining apparatus, the combination with a truck adapted to travel along a mine track, of a supplemental frame pivoted thereto on an upright axis, an elongated kerf-cutter pivoted to said supplemental frame on an axis spaced horizontally from said upright axis, means for adjusting the distance between the axes, means for holding said supplemental frame from moving 50 relatively to said truck during rectilinear feeding of said kerf-cutter, means for holding said kerf-cutter against swinging relatively to said supplemental frame, and power operated means for moving the truck along the mine track to effect 55 feeding movement of said kerf-cutter rectilinearly parallel to the mine track.
73. In mining apparatus, the combination with a supporting frame, of a platform pivoted thereto on a vertical axis, an elongated cutter arm pivoted to said platform on another vertical axis, 60 means for swinging said platform and cutter on said first-named pivot, means for swinging said cutter arm on its pivot relatively to said platform, the two pivot points being horizontally and variably spaced, and means affording adjustment of the distance between said pivots. 65
74. In a mining machine, the combination with a wheel supported frame, of means for moving the frame along a trackway, a turntable rotatably mounted upon said frame and vertically adjustable relative thereto, an overhanging bracket carried by said turntable, a horizontally projecting elongated kerf cutter mounted upon said bracket and rotatable thereon in horizontal planes, means to lock said kerf cutter in either of several positions of angular adjustment relative to said bracket, means for rotating the turntable, and means mounted upon the turntable to actuate the kerf cutter. 70
75. In mining apparatus, the combination with a supporting frame, of a self-contained mining machine having an elongated cutter arm vertically pivoted adjacent one end to the machine, and motor driven means for swinging said arm about its pivot point, means for mounting said machine on said frame for sliding movement relatively thereto, means for effecting such sliding movement to feed the cutter, vertically pivoted platform for supporting said machine, and means for swinging said platform about its pivot point, the two pivot points being horizontally spaced. 75
76. In mining apparatus, the combination with a mining machine having an elongated cutter arm vertically pivoted adjacent one end to the machine, and motor driven means for swinging said arm about its pivot point, of a vertically pivoted platform for supporting said machine, means for swinging said platform about its pivot point, the two pivot points being horizontally and variably spaced, and means affording adjustment of the distance between said pivots. 80
77. In a mining machine, the combination with a wheel supported truck, of means for moving the truck along a trackway, a turntable rotatably mounted upon said truck and vertically adjustable relative thereto, an overhanging downwardly projecting bracket carried by said turntable, a horizontally projecting elongated kerf-cutter mounted upon the lower end of said bracket and rotatable thereon in horizontal planes, means to lock said kerf-cutter in either of several positions of angular adjustment relative to said turntable, means to rotate said turntable, and means mounted on said turntable to actuate said kerf-cutter. 85
78. In a mining machine, the combination with a wheel supported truck, of a supporting member rotatably mounted upon said truck and turnable in horizontal planes and bodily vertically adjustable relative to the truck wheels, a radially and downwardly extending bracket carried by said supporting member, a horizontally projecting elongated kerf-cutter mounted upon the lower and outer end of said bracket and pivotable thereon and relative thereto in horizontal planes, means to lock said kerf-cutter in either of several positions of angular adjustment relative to said bracket, and motor-operated means to actuate the kerf-cutter and to feed the truck during cutting. 90
79. In a mining machine, the combination of a wheeled track guided truck providing a base arranged in fixed relation to the axes of the wheels, a vertically pivoted frame member 95

- mounted above said base, supporting means for the latter permitting bodily vertical adjustment thereof relative to said base, an arm projecting from said vertically pivoted frame member and 5 provided with a depending bracket, and cutting mechanism including a pivoted cutter bar pivoting on said depending bracket on said arm, driving means for said cutter bar including a vertical shaft disposed in said bracket, a motor on 10 said frame, driving connections between said shaft and motor, said parts being constructed and arranged to permit said bar to be lowered to the bottom upon which the track guiding the truck wheels is positioned, and power-operated 15 mechanism for effecting rectilinear feed of said cutting mechanism when in such bottom position. 80
80. In a system of coal mining devices of the class described, the combination with a wheel truck adapted to run upon and be laterally braced 20 by a track extending longitudinally toward a vertical coal face, of cutter mechanism supported upon and movable across the front end of the truck while cutting, a motor movable with the cutting mechanism, means for inverting the cutting mechanism from a position where it will form a kerf in a low horizontal plane relative to the truck to a position where it will form a kerf in a high horizontal plane relative to the truck, and mechanism on the truck for causing trans- 25 verse movement of the cutter mechanism across the front end of the truck. 90
81. In mining apparatus, the combination with a wheeled truck adapted to travel along a mine trackway, of motor-operated mechanism for pro- 30 pelling the truck, a frame rotatably mounted on said truck for movement relatively thereto about a vertical axis, and having a projecting portion adapted to project outwardly beyond the side of the trackway, means for rotating said frame about 35 its axis, kerf-cutting mechanism including a cutter bar mounted on the outer extremity of said frame and disposable in a position to cut a horizontal kerf at the level of the mine bottom outside and below the level of the mine trackway, 40 means for holding said cutter bar in its different angular positions relative to said rotatable frame, motor operated mechanism for driving said kerf-cutting mechanism, and mechanism for adjusting said frame vertically relative to the truck 45 95
- 50 wheels to vary the plane of operation of the cutter bar. 100
82. In a mining machine, the combination with a base frame, of a supporting frame mounted thereon, a kerf-cutter, means for mounting said 55 kerf-cutter on said supporting frame for adjustment on a horizontal axis and to occupy a position at the floor of the mine chamber and to occupy an overhead position at the roof of the mine chamber, means for moving said kerf-cutter to 60 adjust the same from its floor position to its roof position, means for varying the inclination of the kerf-cutter transversely of itself to slanting planes between the floor and the roof, and means for operating the kerf-cutter including feeding there- 65 of along lines parallel to the coal face to effect the cutting of horizontal kerfs at the floor and at the roof and slanting kerfs intermediate the floor and the roof to effect dislodgment of the mineral from the mine vein without blasting. 110
- 70 83. In a mining machine, the combination with supporting framework, of a supplemental frame mounted thereon for adjustment relatively thereto on a horizontal axis, an elongated plane kerf-cutter, means for pivotally mounting said kerf- 75 cutter on said supplemental frame for adjustment 115
- to position the kerf-cutter to cut in horizontal planes parallel to said horizontal axis and distant therefrom or parallel to said axis and adjacent the same, means for effecting such positioning of the kerf-cutter, and means for adjusting the position of said supplemental frame on said horizontal axis to vary the elevation of said kerf-cutter. 120
84. In a mining machine, the combination with supporting framework, of a supplemental frame mounted thereon for adjustment relatively thereto on a horizontal axis, a tertiary frame pivoted to said supplemental frame on an axis spaced from said horizontal axis and extending transversely thereof, a kerf-cutter mounted on said tertiary frame, means for adjusting said supplemental frame on said horizontal axis to vary the elevation of said kerf-cutter from relatively low cutting planes to relatively high cutting planes, and means for adjusting said tertiary frame on said transverse axis to vary the elevation of said kerf-cutter between said low and high planes. 125
85. In a mining machine, the combination with a truck adapted to travel on a mine track, of a supporting frame mounted thereon, a supplemental frame adjustably mounted on said supporting frame for rotation relatively thereto on a longitudinal horizontal axis, a flat elongated chain kerf-cutter pivotally connected at its rear end to said supplemental frame for swinging feeding movement relatively thereto, means for rotating 130 said supplemental frame on said horizontal axis to adjust said kerf-cutter into shearing positions or undercutting and overcutting horizontal positions, means for supporting said kerf-cutter for adjustment relative to said supplemental frame to positions parallel to said horizontal axis but less distant therefrom, means for effecting adjustment of the kerf-cutter from positions distant from said horizontal axis to positions adjacent thereto, and means for operating said kerf-cutter 135 including feed thereof by swinging the same in its own plane on its pivot while occupying positions parallel to said horizontal axis. 140
86. In a mining machine, the combination with a main frame, of a supplemental frame mounted thereon for lateral rectilinear movement relatively thereto, means for holding the supplemental frame in adjusted position, an elongated kerf-cutter pivotally connected to said supplemental frame for swinging relatively thereto on an up- 145 right axis, means for holding said elongated kerf-cutter in adjusted angular relation to said supplemental frame in accordance with the position of the latter on one side or the other of said main frame, means for effecting reciprocation of said elongated kerf-cutter to secure rectilinear feed of the latter for sumping and withdrawal, means for moving said supplemental frame laterally to secure rectilinear transverse feed of said kerf-cutter, and means for driving said kerf-cutter. 150
87. A mining machine comprising a substantially horizontal main frame, a supplemental frame guided to move along rectilinear lines relatively to said main frame, an elongated kerf-cutter mounted on said supplemental frame to move bodily therewith, self-contained power-operated mechanism for moving said supplemental frame along said main frame to sump the kerf-cutter rectilinearly into the mine vein, and means comprising a flexible element having its free end connected to an anchorage extraneous to the machine for moving both frames rectilinearly transversely of themselves to feed said kerf-cutter for a straight cut in the mine vein. 155
88. In a mining machine, the combination with 160

- a supporting frame, of a supplemental frame mounted thereon for advancing and retracting movements relatively thereto, of an elongated chain kerf-cutting mechanism pivotally mounted on said supplemental frame, self-contained power-operated means for operating said kerf-cutting mechanism including arcuate feed thereof on its pivot, and self-contained power-operated mechanism under the control of the operator for advancing and retracting said kerf-cutting mechanism during its arcuate feeding movement to secure an approximately straight line of travel of the outer end of said kerf-cutting mechanism at the bottom of the kerf produced thereby.
- 15 89. In a mining machine, the combination with a base frame, of a supporting frame pivoted thereto for adjustment on a horizontal axis, a supplemental frame pivoted to said supporting frame on an axis spaced from said horizontal axis 80
- 20 and extending transversely thereof, a plane chain kerf-cutter pivoted to said supplemental frame for swinging movement on an axis at right angles to the plane cut by said kerf-cutter, means for adjusting said supporting and supplemental 85
- 25 frames and said kerf-cutter on said horizontal axis, means for swinging said supplemental frame end for end on said transverse axis, and means for swinging said kerf-cutter end for end on said right angle axis, whereby said kerf-cutter may be 90
- 30 positioned to cut a kerf parallel to said horizontal axis and outside of said transverse axis or parallel to said horizontal axis and inside of said transverse axis.
90. In a mining machine, the combination with 35 a base frame, of a supporting frame pivotally mounted thereon for rotation relatively thereto on a horizontal axis and having an offset extension, a supplemental frame pivoted to said offset extension on an axis spaced from said horizontal 95
- 40 axis and extending transversely thereof, a kerf-cutter pivotally connected to said supplemental frame to swing relatively thereto on an axis extending at right angles to the plane of the kerf cut by said kerf-cutter, and means for adjusting 100
- 45 the positions of said supplemental frame and said kerf-cutter to enable said kerf-cutter to cut kerfs in planes parallel to said horizontal axis and at a plurality of distances therefrom.
91. In a mining machine, the combination with 50 a supporting frame, of a supplemental frame pivoted thereto for adjustment through an arc of 180°, an electric motor connected to said supplemental frame and movable bodily therewith, an elongated chain kerf-cutter pivotally connected to 105
- 55 said supplemental frame to swing relatively thereto on an axis at right angles to the plane of the kerf cut by said kerf-cutter, means operated by said motor for swinging said kerf-cutter through 180°, and means for tilting said supplemental 110
- 60 frame together with said motor relatively to said supporting frame to position the kerf-cutter for the cutting of kerfs in parallel spaced-apart 115
- planes.
92. In a coal mining apparatus comprising under-cutting mechanism supported on and guided by a mine track extending approximately at right angles to the face of the coal to be undercut while performing its cutting operation, the combination with a main frame mounted on track wheels 120
- 65 adapted to run on the mine track, of an overhanging arm pivotally mounted on said main frame to swing horizontally with its outer end moving from one side of the track to the other in a path 125
- 70 forwardly of the main frame toward the coal face, an elongated cutter bar pivotally mounted on 130
- 75 the outer end of said overhanging arm to swing horizontally adjacent the plane of the floor on which the mine track is laid, said bar being provided with circulating cutting elements traversing an orbit during cutting, power operated means for moving the machine bodily forwardly and rearwardly on the mine track to effect feeding of the cutter bar during a portion of its operation, said power-operated means being adapted to operate to effect movement of the machine in opposite directions during cutting while the direction of orbital movement of said cutting elements remains the same, means for adjusting the inclination of said cutter bar on a horizontal axis at the lower end of said overhanging arm, and means for swinging said arm together with said cutter bar laterally to cut an additional kerf in the plane of the floor to connect said side kerfs.
93. In a mining machine, the combination with a wheeled truck movable along a trackway, of a horizontal turntable mounted thereon, cutting mechanism carried by said turntable and including a cutter bar having circulating cutting elements and pivoted to swing about an axis offset from but parallel to the axis of rotation of said 135
- turntable, means for holding said cutter bar in different angular positions relative to a straight horizontal line intersecting the pivotal axes of the bar and of the turntable, actuating means for said cutter bar operative to effect circulation of said cutting elements including a motor mounted on said turntable and driving connections between the same and said cutting elements, means for adjusting said bar vertically rectilinearly between positions wherein the bottom of the horizontal kerf cut thereby will constitute a continuation of the surface upon which the track along which the truck runs is mounted, and wherein the bottommost points of the bar and cutting elements will be above a horizontal plane above the 140
- top of the track, and motor driven means for moving the truck along said trackway.
94. In a mining machine, the combination with a portable truck adapted to travel on a mine track parallel to and spaced from the upright working 145
- face of a mine wall, of a supplemental frame carried by said truck and extending laterally therefrom toward said mine wall, a chain kerf-cutter mounted on said supplemental frame to swing relatively thereto on an axis at right angles to the plane of said kerf-cutter, means for driving said chain kerf-cutter, means for adjusting the elevation of said kerf-cutter to cut a kerf in any one of a plurality of horizontal planes, means for propelling said truck along said track 150
- 150 to feed the kerf-cutter rectilinearly parallel to the track, means for adjusting the kerf-cutter to cut a kerf in an upright plane parallel to the track and spaced back from the longwall face, and means for operating said kerf-cutter including arcuate swinging movement on said axis to cut such upright kerf.
95. In a mining machine, the combination with a truck adapted to travel on a mine track parallel to and spaced from a longwall working face, 155
- 160 of a supplemental frame mounted on said truck to move bodily therewith and extending laterally toward such working face, an elongated chain kerf-cutter mounted on said supplemental frame, means for adjusting said kerf-cutter to present the same edgewise to said working face at various elevations and cut kerfs at such elevations, means for propelling the truck to secure rectilinear feeding movement of said kerf-cutter, means for adjusting said chain kerf-cutter into 165
- 170

- an upright plane and into position to present the same edgewise to a right angle coal face to cut a kerf in an upright plane parallel to the mine track and spaced back from such long-
5 wall working face, and means dependent upon said propelling mechanism for feeding said chain kerf-cutter when in upright position. 80
96. In a mining machine, the combination with a main frame, of a supplemental frame having a rectilinear reciprocatory movement relatively to the main frame, and transversely of the path of travel thereof, an elongated chain kerf-cutter pivotally carried by said reciprocatory frame to swing on an axis at right angles to the plane of said kerf-cutter, means for adjusting the kerf-cutter transversely of its plane to vary the inclination thereof, means for swinging the kerf-cutter to adjust the same into a longwall working position, and means for propelling the machine along the mine wall to effect rectilinear feed of the kerf-cutter to cut a kerf in a plane at an adjusted inclination. 85
97. In a mining machine, the combination with a truck adapted to travel on a mine track parallel to a longwall working face, of a supporting frame mounted for reciprocatory movement transversely of the truck, an elongated chain kerf-cutter pivotally mounted on said frame to swing on an axis at right angles to the plane of said kerf-cutter, means for moving the said frame transversely of the truck to adjust the kerf-cutter to a position adjacent the working face, mechanism for swinging the kerf-cutter on said right angle axis to feed the kerf-cutter into the working face, and means for propelling the machine along the mine track to secure rectilinear feed of the kerf-cutter along the working face. 90
98. In a mining machine, the combination with a truck adapted to travel on a mine track, of a supporting frame movable transversely thereof, an elongated chain kerf-cutter pivoted to said frame for adjustment transversely of itself to vary the inclination thereof, means for moving said supporting frame relatively to the truck to adjust the position of the kerf-cutter relative to the working face, means for moving the kerf-cutter transversely of itself and relatively to said frame to adjust the inclination of said kerf-cutter, and means for moving the truck along the track to effect rectilinear feed of the kerf-cutter at its adjusted inclination. 100
99. In a mining machine, the combination with a main frame adapted to travel along a mine wall, of a supplemental frame mounted on said main frame and extending therefrom toward a longwall working face, an elongated chain kerf-cutter pivotally mounted on said supplemental frame to swing in its own plane on an axis at right angles to said plane, means for operating said kerf-cutter including rectilinear feeding movement thereof relatively to said main frame, means for adjusting said kerf-cutter to extend either in upwardly inclined planes or downwardly inclined planes parallel to the path of the machine, and means for propelling said main frame along said face to secure rectilinear feed of said kerf-cutter parallel to said path and while in either of said inclined positions. 110
100. In a mining machine, the combination with a truck adapted to travel on a mine track parallel to the working face of a mine wall and spaced therefrom, of a supplemental frame mounted for reciprocatory movement transversely of the track, an elongated chain kerf-cutter, adjustable supporting mechanism between said
- elongated chain kerf-cutter and said reciprocatory frame comprising one axis of adjustment for said kerf-cutter and extending perpendicular to the mine wall and another axis of adjustment for said kerf-cutter and extending parallel to the mine wall, means for adjusting the kerf-cutter on said perpendicular axis from undercutting to shearing position, means for adjusting said kerf-cutter on said parallel axis to vary its plane of inclination relative to the said working face, means for operating said kerf-cutter including arcuate feed thereof on an axis perpendicular to the plane thereof and within the boundary of the same at its rear end, and means for propelling the truck along said track to secure rectilinear feed of said kerf-cutter along the mine wall. 120
101. In a mining machine, the combination with a truck adapted to travel on a mine track, of an elongated chain kerf-cutter, a supporting frame comprising a turntable mounted on said truck, means for adjustably carrying said kerf-cutter on an axis in a plane extending adjacent to the top of the truck, and mechanism for operating said kerf-cutter to cut a kerf extending downwardly into the surface on which the track is laid. 125
102. In a mining machine, the combination with a truck adapted to travel on a mine track, of an elongated chain kerf-cutter, a supporting frame, mechanism for carrying said kerf-cutter on said frame for adjustment relative thereto on an axis in a plane extending adjacent to the top of said truck, means for adjusting said kerf-cutter on an axis parallel to the mine track, and means for operating said kerf-cutter including feed thereof to cut a kerf in the floor on which the mine track is laid and parallel to the latter. 130
103. In a mining machine, the combination with a truck adapted to travel on a track, of a supporting frame mounted thereon, an elongated chain kerf-cutter adjustably mounted on said frame on an axis in a plane adjacent to the top of said truck, means for holding the kerf-cutter in adjusted position relative to said frame to predetermined the depth of cut, and means for operating the kerf-cutter to cut an upright kerf in the floor on which the track is laid and at the said predetermined depth. 135
104. In a reversible kerf-cutting machine, the combination with a truck movable over a floor, of a platform thereon, a standard on said platform, an elongated kerf-cutter carried by said standard for adjustment relative thereto on a relatively low axis extending through said platform, means for reversing said platform to permit complete reversal of said kerf-cutter to cut on either side of said truck in the floor, and means for operating said kerf-cutter to cut upright kerfs in the floor at either side of the path of the truck. 140
105. In a mining machine, the combination with a wheel mounted truck, of a supporting frame mounted thereon, an elongated kerf-cutter carried by said frame for adjustment relative thereto on two axes one extending transversely of the truck adjacent the top of the machine and the other extending longitudinally of the truck and spaced laterally from the center line thereof, and means for operating said kerf-cutter to cut an upright kerf in the roof of a mine chamber by rectilinear feed. 145
106. In a mining machine, the combination with a wheel mounted truck, of a supporting frame thereon, an elongated kerf-cutter carried

- by said frame for adjustment on a horizontal axis offset from the center line of the machine in a plane extending through the bottom portion of said frame, means for shifting said axis to a position where it lies in a plane extending through the top portion of said frame, and means for operating said kerf-cutter to cut an upright kerf by rectilinear feed either in the floor of the mine chamber or to cut an upright kerf in the roof of the mine chamber in accordance with the position of said horizontal axis.
107. In a track mounted coal cutting machine, the combination with a truck adapted to travel on a mine track and be braced thereby, of a turntable mounted thereon for movement relatively thereto on a vertical axis, a supporting arm pivoted to said turntable for adjustment relative thereto on a horizontal axis and extending outwardly from said turntable a substantial distance, an elongated kerf-cutter comprising an elongated cutter bar, means for pivotally connecting said cutter bar to said supporting arm for adjustment relative thereto on rectangularly related axes, one of which is at right angles to said cutter bar and the other of which is in a plane parallel to said cutter bar and adjacent to said right angle axis, means for locking said cutter bar in adjusted position on its right angle axis, and means for operating said kerf-cutter including the feed thereof.
108. In a track mounted coal mining machine, the combination with a truck adapted to travel on a mine track and be braced thereby, of a turntable mounted thereon to move arcuately relatively thereto on a vertical axis, means for moving said turntable on said vertical axis relatively to said truck and holding the same in adjusted position, a supporting arm mounted on said turntable for adjustment relative thereto on a horizontal axis and projecting a substantial distance outwardly from said turntable, mechanism for moving said arm on said horizontal axis to adjust the elevation of the outer end thereof and holding the same at adjusted elevation, an elongated chain kerf-cutter comprising an elongated cutter bar, means for pivotally connecting said cutter bar to the outer end of said arm for adjustments relative thereto on rectangularly related axes, one of which is at right angles to the plane of said cutter bar, and the other of which is adjacent to said right angle axis and in a plane parallel to said cutter bar, means for adjusting said cutter bar arcuately transversely of its plane on said other axis and holding the cutter bar in adjusted position relative to said arm, means for holding said cutter bar in its adjusted position on its right angle axis relative to said arm, motor operated mechanism for driving said kerf-cutter while being held in its adjusted position, and motor operated mechanism for moving the whole machine along the mine track to effect rectilinear feed of said kerf-cutter.
109. In a mining machine, the combination with a wheel supported frame adapted to move along a trackway, of motor driven kerf-cutting mechanism including a swinging pivotal cutter bar, a support for said kerf-cutting mechanism swiveled to said frame on a horizontal axis, and adjusting means for said kerf-cutting mechanism operative to adjust the cutter bar relatively to said support to cause said cutter bar to occupy a series of positions one at the level of the floor on which the track is laid and others above such floor level.
110. In a mining machine, the combination with a wheel supported frame adapted to move along a trackway, of motor driven kerf-cutting mechanism including a cutter bar, a support for said kerf-cutting mechanism swiveled to said frame on a horizontal axis, and means for adjusting said cutter to parallel horizontal positions one near the level of said trackway and another adjacent said horizontal axis.
111. In a machine of the nature described, the combination of a cutting mechanism supporting means having a neck rotatably supported on a bearing, an elongated cutting mechanism hinged to said neck to permit movement of said mechanism toward and from the axial line of said neck, and a neck shaft extending through said neck and arranged in operative relation with the cutting mechanism for actuating said cutting mechanism, substantially as described.
112. In a machine of the nature described, the combination of a rotary neck resting on a bearing, a rotary neck shaft located in said neck on the axis of the latter, cutting mechanism plurally articulated to said neck and arranged in operative relation with said neck shaft, and means for rotating said neck shaft, substantially as described.
113. In a machine of the nature described, a rotary neck resting on a horizontal bearing, a rotary neck shaft in said neck on the axis of the latter, cutting mechanism articulated to said neck on a plurality of pivots for movement in a plurality of directions and in operative relation with a source of power, a motor-driven transmission shaft connected to said cutting mechanism, and reversible gearing whereby the operator may at will cause the neck to receive motion in either direction to adjust the position of said cutting mechanism.
114. In a machine of the nature described, a rotary neck resting on a horizontal bearing which is fixed relative to the machine body, cutting mechanism articulated to said neck on a plurality of pivots for movement in a plurality of directions and in operative relation with means controlled by the operator for actuating the cutting mechanism, a power transmission shaft connected to said cutting mechanism, a gear wheel on said neck, and means in operative relation with said wheel whereby the operator may, at will cause the neck to receive rotary motion to adjust the position of said cutting mechanism.
115. In a machine of the nature described, the combination of a rotatable neck mounted on a bearing which is horizontal and parallel to the machine path, means for rotating said neck, a cutting tool, members articulated on said neck on a plurality of pivots for carrying said cutting tool in an orbital path which is concentric to the axial line of the neck and supporting said tool in a line varying in angularity relative to said axial line, a neck shaft in said neck, and means operatively connecting said neck shaft and said cutting tool for actuating the latter for cutting.
116. In a mining machine, the combination with cutting means including a chain carrying cutter bar pivotally mounted for swinging movement in its own plane, of means for adjusting said cutting means to any one of a plurality of intersecting planes, a motor whose axis of rotation is parallel to the plane of the bar, mechanism driven by said motor for operating said cutting means, mechanism for adjusting the elevation of said cutting means, and means for ad-

- justing the cutter bar on a transverse horizontal axis.
117. In a mining machine, the combination with a truck adapted to travel on a mine track, of cutting mechanism comprising a chain carrying cutter bar pivotally mounted for swinging movement in its own plane, means for adjusting said cutting mechanism on a longitudinal axis to any one of a plurality of intersecting planes 10 perpendicular to a coal face, mechanism for vertically rectilinearly adjusting the cutting mechanism, means for tilting the cutting mechanism on a transverse horizontal axis, a motor, and means operated by said motor for operating said cutting mechanism including rectilinear sumping and withdrawal and intermediate swinging of the cutting mechanism. 80
118. In a mining machine, the combination with a truck adapted to travel on a mine track, 20 of an elongated chain kerf-cutter comprising a cutter bar pivotally mounted to swing in its own plane, a motor connected to said kerf-cutter to operate the same and move bodily therewith, means for adjusting the motor and the kerf-cutter 25 bodily on a longitudinal axis to cut in any one of intersecting planes at right angles to an upright coal face, mechanism for moving the said motor and kerf-cutter relatively to said truck to secure the feeding of the kerf-cutter rectilinearly 30 in a plane at right angles to the coal face and parallel to the mine track, and means for driving the kerf-cutter during such feed thereof. 90
119. In a mining machine, the combination with a truck adapted to travel on a mine track, 35 of guiding means extending longitudinally of the truck, a self-contained mining machine unit, a carrier slideable along said guiding means and adapted to support said mining machine unit for bodily movement therewith, and means comprising 40 a flexible connection to an anchorage for moving said carrier along said guiding means to secure feed of said mining machine unit. 95
120. In mining apparatus, the combination with a truck adapted to travel on a trackway, of 45 a mining machine, guiding means extending transversely of the truck, means for reversing the position of the guiding means, and means for moving the mining machine bodily parallel to said guiding means while the kerf-cutter is in 50 position to cut a kerf in either of the ribs of the coal vein parallel to the trackway. 100
121. In mining apparatus, the combination with a truck movable along a trackway, of guiding means extending transversely thereof, means 55 for reversing said guiding means, mining mechanism movable bodily along said guiding means and comprising a chain kerf-cutter adapted to occupy an upright plane, and mechanism comprising a flexible connection to an anchorage to 60 move said mining mechanism along said guiding means to produce a shearing cut in a rib wall on one side of the trackway and to produce a shearing cut in the opposite rib wall after said guiding means has been reversed. 105
122. In mining apparatus, the combination with a truck adapted to travel along a trackway, of guiding means extending transversely thereof, mining mechanism comprising an elongated kerf-cutter movable bodily along said guiding means, and mechanism for feeding said mining mechanism along said guiding means toward one rib wall to cut a kerf therein and for feeding said mining mechanism along said guiding means toward the opposite rib wall to cut a kerf therein. 110
123. In mining apparatus, the combination of approximately horizontally disposed guiding means, and cutting mechanism movable longitudinally of said guiding means and comprising an elongated kerf-cutter, said kerf-cutter being suspended beneath a horizontal plane extending through said guiding means and including a support rotatable about an axis extending longitudinally of said guiding means and also including means for connecting said kerf-cutter to said support to swing in planes spaced from said axis and on either side thereof, and means for operating said kerf-cutter. 115
124. In a mining machine, the combination with cutting means including a chain carrying cutter bar pivotally mounted for swinging movement into intersecting planes, of means for operating said cutting means, said operating means comprising a motor whose axis of rotation is parallel to the planes of said cutter bar, means for supporting said cutting means, means for moving vertically and rectilinearly said supporting means, and means for adjusting said cutter bar on a transverse horizontal axis into parallelism with said motor axis. 120
125. In a mining machine, the combination with 100 guiding means, of cutting mechanism movable parallel to said guiding means during cutting comprising a pivoted cutter bar located below a horizontal plane extending through said guiding means, means for moving the guiding means vertically, and means for tilting the cutting mechanism on a transverse horizontal axis. 105
126. In a mining machine, the combination with a truck-mounted guide, of kerf-cutting mechanism movable bodily rectilinearly in opposite directions along said guide, means for adjusting said guide vertically, said kerf-cutting mechanism comprising a swinging kerf-cutter mounted for bodily angular adjustment about a horizontal 110 longitudinally extending axis into a substantially horizontal or vertical plane, said kerf-cutter being mounted to swing on an axis transverse to said horizontal longitudinally extending axis, and having associated therewith a driving motor, and means for operating said kerf-cutting mechanism 115 to effect the cutting of sumping and arcuate and withdrawal kerfs in a horizontal plane or a vertical plane in the face of the mine vein. 120
127. In a machine of the nature described, the combination of a rotatable neck mounted on a bearing which is fixed relative to the machine body and is horizontal and parallel to the machine path, an elongated chain kerf-cutter, articulated members supporting said tool on said neck on a plurality of pivots for movement on the neck 125 toward and from the axial line of the neck, mechanism for effecting said movement of the kerf-cutter toward and from the axial line, and motor-operated means for actuating said cutting tool. 130
128. In a machine of the nature described, the combination of a rotatable neck which is on a bearing which is fixed relative to the machine body and is horizontal and parallel to the machine path, a cutting tool, articulated members supporting said tool on said neck for movement 135 toward and from the axial line of the neck, mechanism for effecting said movement, and means extending along the axial line of the neck extending through said neck for actuating said cutting tool, substantially as described. 140
129. In a machine of the nature described, the combination of a cutting mechanism supporting means having a neck rotatable on a bearing, an elongated cutting mechanism hinged to said support on an axis offset from said cutting mecha- 145

- nism to permit bodily movement of said mechanism toward and from the axial line of said neck, means for rotating said neck, and motor-operated means for actuating said cutting mechanism, substantially as described.
130. In a mining machine, the combination with a supporting frame, of a turret mounted thereon for adjustment on a horizontal axis, a second turret mounted on said first-named turret for adjustment relative thereto on an axis spaced from said horizontal axis, means for holding said turrets in adjusted positions, and a kerf-cutter mounted to swing on an axis at right angles to the kerf cut thereby, said right angle axis extending transversely of both of the turret axes.
131. In a mining machine, the combination with a supporting frame, of an elongated kerf-cutter, means for supporting said kerf-cutter on said frame for adjustment on parallel spaced-apart horizontal axes and swinging in its own plane, and means for operating the kerf-cutter in its adjusted plane.
132. In a mining machine, the combination with an angularly adjustable support, of a turret mounted thereon for angular movement about an axis transverse to the axis of movement of said support, a second turret mounted on said first-named turret for angular movement about an axis eccentrically spaced from the axis of the first named turret, a third turret mounted on said second turret for angular movement about an axis transverse to the axes of said first and second turrets, and a cutter carried by said third turret.
133. In a mining machine, the combination with a truck, of guiding means extending longitudinally thereof, a guiding frame extending transversely of the truck and shiftable bodily transversely of itself along said guiding means, cutting mechanism movable longitudinally of said guiding frame, said cutting mechanism comprising a swingable cutter bar, and means for moving said cutting mechanism longitudinally of said guiding frame to effect feed of said cutter bar in different positions thereof.
134. In a mining machine, the combination with a truck adapted to travel along a mine track, of transversely disposed guiding means thereon and adjusted into parallelism with an oblique face of the mine vein, kerf-cutting mechanism disposed transversely of said guiding means and movable under its own power laterally along said guiding means during horizontal kerf-cutting while the truck remains parallel to the ribs of the entry.
135. In a mining machine, the combination with a truck adapted to travel on a mine track, of guiding means extending longitudinally of the truck parallel to the mine track, of a guide frame extending transversely of the truck and movable bodily transversely of itself along said guiding means, kerf-cutting mechanism movable along said guide frame transversely of the truck and track, and power-operated means for operating said kerf-cutting mechanism including a rectilinear sumping and withdrawal cuts parallel to said guide frame.
136. In a mining machine, the combination with a truck adapted to travel on a mine track, of a guide frame extending transversely of the truck, kerf-cutting mechanism movable longitudinally of said guide frame and transversely of the truck and comprising a pivoted kerf-cutter and self-contained power-operated means for operating said kerf-cutting mechanism by effecting rectilinear sumping and withdrawal cuts of said kerf-cutter and an intermediate swinging feed movement thereof to cut a wide kerf in a rib wall parallel to the mine track.
137. In a mining machine, the combination with a truck movable on a trackway, of guiding means extending transversely thereof, kerf-cutting mechanism movable bodily transversely of itself along said guiding means, and means for operating said kerf-cutting mechanism including feed thereof transversely of itself along said guiding means transversely of the truck, said operating means including a flexible connection to an anchorage extraneous to the kerf-cutting mechanism.
138. In a mining machine, the combination with a truck, of longitudinally disposed guiding means swiveled thereon about a vertical axis, cutting mechanism movable longitudinally of said guiding means and including a motor and a pivoted cutter bar, means operated by said motor for swinging said cutter bar on its pivot, and means for bodily rotating the pivot of said cutter bar.
139. In a mining machine, the combination with a wheeled support, of longitudinally extending guiding means thereon, a motor reciprocable relative to said guiding means, elongated chain kerf-cutting mechanism operatively connected to said motor including a forwardly extending vertically disposed horizontally pivoted elongated flat cutter bar, and self contained power-operated means comprising a rack and pinion drive associated with said guiding means for effecting reciprocation of said cutting mechanism for the cutting of a vertical kerf.
140. In a mining machine, the combination with a support, of guiding means therefor, a motor reciprocable relative to said guiding means, cutting mechanism operatively connected to said motor and including a pivoted cutter bar extending parallel to said guiding means, means for rotating the pivot of said bar about an axis disposed parallel to the direction of said guiding means, means operated by said motor for driving said cutting mechanism, and motor-operated mechanism for effecting reciprocation of said cutter bar in different positions thereof.
141. In a mining machine, the combination with a wheeled truck, of guiding means pivotally mounted thereon and movable angularly relative thereto, a motor reciprocable relative to said guiding means, cutting mechanism operatively connected to said motor and including a forwardly extending pivoted cutter bar, means for adjusting said bar into either a horizontal or a vertical position, means driven by said motor for swinging said bar about its pivot when in either position, and motor-operated mechanism for effecting reciprocation of said cutting mechanism to secure rectilinear sumping and withdrawal feeding movements thereof.
142. In a mining machine, the combination with a truck, of longitudinally disposed guiding means thereon, cutting mechanism movable longitudinally of said guiding means and including a pivoted cutter bar, and means whereby said cutter bar may be swung into a plane disposed beneath said guiding means or in a plane at right angles to the aforesaid plane.
143. In mining apparatus, the combination with a truck, of guiding means thereon, cutting apparatus movable relative to said guiding means during cutting comprising a pivoted cutter bar lying in a plane below the bottom of said guiding means.

means, and means for disposing said bar in a plane above said guiding means.

144. In mining apparatus, the combination with a truck, of longitudinally extending guiding means thereon non-rotatable on a horizontal axis, cutting mechanism movable relative to said guiding means comprising a cutter bar, means for supporting the cutting mechanism in advance of said guiding means for operation outside of the boundaries thereof, means for disposing said bar in a plane below the plane extending through said guiding means, and means for varying the position of said bar when so disposed.

145. In mining apparatus, the combination with a truck, of guiding means thereon, cutting mechanism movable relative to said guiding means longitudinally of the latter including a motor driven cutter bar, means for disposing said bar in a plane below said guiding means, and means for varying the angle of the plane in which said bar lies when so disposed relative to said truck.

146. In a mining machine, the combination with a support, of cutting mechanism thereon including a swiveled cutter bar carrying a cutter chain, said bar being adjustable bodily into positions to cut in different ones of a plurality of intersecting planes all of which are parallel to a single line, a motor for operating said cutter chain, means to effect bodily movement of said bar into the desired plane, means operable by said motor to swing said bar in any plane to which it is moved, and means operable by said motor to effect bodily rectilinear movement parallel to said line in opposite directions of said bar while said cutter chain is operated in the same direction by said motor.

147. In a mining machine, the combination with a support, of cutting mechanism thereon including a swivelled cutter bar carrying a cutter chain, said bar being adjustable bodily into positions to cut in different ones of a plurality of intersecting planes all of which are parallel to a single line, a motor for operating said cutter chain, means to effect said bodily movement of said bar to the desired plane, and means operable by said motor to move the bar bodily rectilinearly in such plane, to swing the same therein, and to retract the same to effect the formation in such plane of a parallel ribbed kerf with the ribs parallel to said line.

148. In a mining machine, the combination with a wheeled truck, of kerf-cutting mechanism thereon including a pivoted cutter bar rotatable about a longitudinal axis and movable longitudinally relatively to said truck, a motor movable longitudinally with said bar, means operable by said motor for moving the kerf-cutting mechanism in a plane about its pivot, and motor-operated means for moving said bar longitudinally of the truck.

149. In a mining machine, the combination with a wheeled truck, of power-operated truck propulsion mechanism, a guideway carried by said truck, cutting mechanism reciprocable along said guideway including a cutter bar swinging in a vertical plane and a cutter chain on said bar, self-contained power-operated mechanism for effecting circulation of said cutter chain and swinging of said cutter bar, and self-contained power-operated mechanism for effecting reciprocation of said cutting mechanism.

150. In mining apparatus, the combination with a wheel-mounted support adapted to run along a trackway, of a frame on said support,

cutting mechanism including a cutter carrying head mounted on said frame for rotation about a longitudinal axis, said cutting mechanism including an elongated plane cutter bar carrying an orbitally movable cutter chain and suitably mounted on said head for swinging movement relatively thereto, a motor on said support, means for rotating said head about its axis, means driven by said motor for swinging said cutter bar about its pivot at a cutting speed, mechanism driven by said motor for actuating the cutter chain, and mechanism for tilting said cutter bar relative to said support about an axis closely adjacent to said pivot to change the angle of said bar relative to the horizontal.

151. In a mining machine, the combination with a wheeled truck, of a motor carried thereby, cutting mechanism on said truck including a cutter carrying head rotatable between horizontal and vertical cutting positions about a horizontal longitudinally extending axis, and an elongated plane cutter bar carrying an orbitally movable cutter chain pivotally mounted on said head for swinging movement relatively thereto, mechanism driven by said motor for actuating the cutter chain, mechanism for rotating said head bodily about said horizontal axis to change the plane of operation of said bar, mechanism driven by said motor for swinging said cutter bar about its pivot at a cutting speed in any position of said head about its axis, and mechanism for tilting said cutting mechanism about a transverse axis closely adjacent to said pivot to change the angle of the cutter bar relative to the horizontal.

152. In a mining machine, the combination with a wheeled truck, of a swivel member mounted thereon rotatable about a vertical axis, a motor carried by said swivel member, cutting mechanism on said swivel member including a cutter carrying head rotatable about a horizontal longitudinally extending axis and an elongated plane cutter bar carrying an orbitally movable cutter chain pivotally mounted on said head for swinging movement relatively thereto, mechanism driven by said motor for actuating said cutter chain, mechanism for rotating said head about said horizontal axis to move said bar bodily to change the plane of operation thereof, and mechanism driven by said motor for swinging said cutter bar about its pivot at a cutting speed in any position of said head about its axis.

153. In a mining machine, the combination with a wheeled truck, of a frame thereon rotatable about a vertical axis, a horizontal guideway wholly supported by said truck and mounted on said frame for horizontal adjustment about the said vertical axis to positions respectively parallel to or at right angles to the central longitudinal line of the truck, mining mechanism mounted on said guideway for movement therewith and including a motor and kerf-cutting mechanism driven by said motor including an elongated horizontal plane cutter bar carrying an orbitally movable cutter chain, mechanism driven by said motor for actuating said cutter chain, and mechanism driven by said motor for moving said mining mechanism bodily relative to said guideway at a cutting speed to cut a horizontal kerf.

154. In mining apparatus, the combination with a truck, of pivoted kerf-cutting mechanism thereon including a cutter bar and a cutter chain thereon, a support pivoted on a horizontal axis, means for adjusting said support to effect ad-

- justment of said kerf-cutting mechanism to angularly related plane for the cutting of plane kerfs therein, and self-contained means for moving said kerf-cutting and adjusting means longitudinally along said truck.
155. In mining apparatus, the combination with a truck, of a supporting structure pivotally mounted on said truck on a horizontal axis, an elongated kerf-cutter comprising a cutter bar 10 and a chain cutter thereon, means pivotally supporting said kerf-cutter on said supporting structure on an axis at right angles to the plane of said cutter bar, motor-operated means for driving the chain cutter and for swinging said cutter bar on its pivotal axis, means for adjusting said supporting structure on said horizontal axis to permit the cutting of plane kerfs in angularly related planes, and self-contained means for moving said kerf-cutter and said adjusting means 20 longitudinally of the truck.
156. In a mining machine, the combination with a support, of cutting mechanism carried by said support and including a swinging cutter bar, means for moving said bar to different planes 25 respectively at angles to each other including a plurality of means for changing the plane of cut of said bar, means for actuating the same each operative independently of the other and respectively moving the bar in different paths, power-30 actuated means for swinging the cutter bar, power-actuated means for feeding the cutter bar and a common source of power for said power-actuated means.
157. In mining apparatus, the combination 35 with a truck movable on a trackway, of horizontal guiding means on said truck, vertical kerf-cutting mechanism pivotally mounted on said truck and including a cutter bar having a cutter chain adapted to cut a vertical kerf for 40 said bar in a face when said bar is presented edgewise thereto, a motor, mechanism driven by said motor for actuating said cutter chain, and self-contained power-operated mechanism driven by said motor for moving said cutter mechanism 45 relatively to said guiding means to effect movement of said cutter bar bodily rectilinearly thereof, about its pivot vertically in the same plane, and reversely rectilinearly relatively to said guiding means to insert a vertical kerf in a face 50 in front of the end of the trackway.
158. In mining apparatus, the combination with a wheel mounted support adapted to run along a trackway, of a motor on said support, kerf-cutting mechanism on said support including 55 a cutter carrying head rotatable on a longitudinal axis, an elongated plane cutter bar pivotally mounted on said head and carrying an arbitrally movable cutter chain, mechanism driven by said motor for effecting bar swing at a cutting 60 speed, means for adjusting said cutter bar into different horizontal planes above and below the axis of head rotation, means for tilting said cutter bar about a transverse axis to change the angle of said cutter relative to the horizontal, and 65 mechanism driven by said motor for effecting forward and rearward rectilinear movements of said cutter bar at a cutting speed to make sumping and withdrawal cuts.
159. In a mining machine, the combination 70 with a frame movable on a trackway including a horizontal guiding way, of a motor reciprocable relatively thereto, and cutting mechanism operatively connected to said motor and including a pivotally mounted cutter chain carrying cutter 75 bar supported beyond the end of said trackway for swinging in a plane below the plane of said way and parallel thereto.
160. In a mining machine, the combination with a frame movable on a trackway and including laterally spaced guiding members of like elevation, a supplemental frame, a motor on said supplemental frame, said supplemental frame and said motor being reciprocable along said guiding members, and cutting mechanism operatively connected to said motor and including a pivotally mounted cutter chain carrying cutter bar occupying a position beyond the end of said trackway for horizontally swinging below the plane of said guiding members. 80
161. In a mining machine, the combination with a frame movable on a trackway and including a horizontally disposed guiding way, a supplemental frame reciprocable along said guiding way, a motor on said supplemental frame and movable bodily therewith, and cutting mechanism operatively connected to said motor and including a pivotally mounted cutter chain carrying cutter bar supported beyond one end of said trackway and swingable in a plane below and parallel to the plane of said way. 85
162. In mining apparatus, the combination with a frame movable on a trackway, of guiding means thereon, cutting mechanism rectilinearly reciprocable relatively thereto and comprising a pivotally mounted cutter chain carrying cutter bar normally 90 swinging in a plane parallel to and below the plane of said guiding means and a driving motor having a horizontal axis of rotation, a supplemental frame for supporting said cutting mechanism for reciprocation along said guiding means and in positions beyond the forward end of said trackway, and means for supporting said cutter bar in different planes. 95
163. In a mining machine, the combination with a frame movable on a trackway, and having horizontally disposed guiding means, cutting mechanism movable bodily longitudinally of said means and comprising an independently pivoted cutter chain carrying cutter bar disposable in a plane parallel to and above the plane of said guiding means and in an intersecting plane, a supplemental frame movable along said guiding means and supporting said cutting mechanism, and a driving motor for said cutter chain and mounted on said supplemental frame to move 100 bodily therewith with its axis of rotation always parallel to the path of movement of said supplemental frame relatively to said first-named frame. 110
164. In a mining machine, the combination with a wheeled frame including laterally spaced guiding members disposed in substantially the same horizontal plane, of a supplemental frame reciprocable along said members, a motor supported by said supplemental frame and movable 115 bodily therewith, a swivel head on said supplemental frame, cutting mechanism on said head and operatively connected to said motor, said cutting mechanism comprising a pivotally mounted cutter bar horizontally disposed below the plane of said guiding members, and means operated by said motor for swinging said cutter bar relatively to said swivel head. 120
165. In a mining machine, the combination with a wheeled frame including laterally spaced 125 guiding members, of a supplemental frame reciprocable on said guiding members, a motor on said supplemental frame and reciprocable therewith, cutting mechanism operatively connected to said motor and including a pivotally 130 supported

- mounted cutter bar horizontally disposed below the plane of said guiding members, and means for at will inverting said cutter bar without change of location of said motor.
- 5 .166. In a mining machine, the combination with a wheeled frame including laterally spaced guiding members of like elevation, of a supplemental frame reciprocable on said guiding members, a motor on said supplemental frame and movable 80 10 bodily therewith, cutting mechanism operatively connected to said motor and including a pivotally mounted cutter bar horizontally disposed below the plane of said guiding members and means for at will disposing said bar in horizontal or 15 vertical position without alteration in position of said motor.
167. In a mining machine, the combination with a wheeled frame including laterally spaced guiding members, of a supplemental frame reciprocable thereon, a motor on said supplemental frame to move bodily therewith, cutting mechanism operatively connected to said motor and including a pivotally mounted cutter bar horizontally disposed below the plane of said guiding 25 members, and means for at will disposing said bar in vertical position on opposite sides of the axis of said motor without alteration in position of said motor.
168. In a mining machine, the combination with a transport frame including laterally spaced guiding members lying respectively at opposite sides of a vertical plane, of a supplemental frame reciprocable on said guiding members, a motor on said supplemental frame and movable bodily 30 35 therewith, cutting mechanism operatively connected to said motor and including a pivotally mounted cutter bar horizontally disposed below the plane of said guiding members, means for swinging said bar about its pivot, and means for rotating said bar bodily about a longitudinally disposed axis without change of position of said motor.
169. In a mining machine, the combination with a transport frame including laterally spaced 40 45 guiding members of similar elevation, of a supplemental frame reciprocable thereon, a motor on said supplemental frame and movable bodily therewith, cutting mechanism operatively connected to said motor and including a pivotally mounted plane cutter bar horizontally disposed below the plane of said guiding members, means operatively connected to said motor and said bar for swinging said bar about its pivot, and means for angularly adjusting the pivot of said bar.
170. In a mining machine, the combination with a truck adapted to travel on a mine track, of a main frame thereon having laterally spaced guiding members respectively lying at opposite sides of a vertical plane, a supplemental frame reciprocable along said guiding members, a motor on said supplemental frame to move bodily therewith between said guiding members, means for effecting reciprocation of said supplemental frame and said motor, and cutting mechanism operatively connected to said motor and including a cutter bar horizontally disposed in a plane below the plane of said guiding members in cutting positions beyond the forward end of said track.
171. In a mining machine, the combination with a supporting frame movable along a track-way, of a motor thereon having its axis horizontal and parallel to the length of said frame, cutting mechanism operatively connected to the motor and including a plane cutter bar pivoted on an axis at right angles to the plane of the cutter bar, means for supporting said cutter bar for rotation bodily whereby the intersection of said right angle axis with said bar may trace a circle to whose plane the motor axis is perpendicular, and means for feeding said bar longitudinally into the working face when said bar pivot is in any of its positions in said last-named plane including a flexible feeding member operatively connected to the motor and to a fixed anchorage.
172. In a mining machine, the combination with an electric motor having an armature shaft, of a supporting frame for said motor, cutting mechanism carried by said frame including a cutter bar disposable in different planes respectively to effect horizontal and vertical cuts, means for changing the plane of cut of said cutter bar, means for driving said cutting mechanism from one end of said armature shaft, and means driven from the same end of the armature shaft to move 85 90 95 said motor, frame and cutting mechanism bodily to effect feeding of said cutting mechanism.
173. In a mining machine, the combination with an electric motor having an armature shaft, of cutting mechanism including a swinging cutter bar disposable in different planes respectively to effect horizontal and vertical cuts, means for changing the plane of cut of said cutter bar, means actuated from one end of said armature shaft for moving said motor and cutting mechanism bodily to effect feeding of the latter, and means for swinging said cutter bar also actuated from the same end of said armature shaft.
174. In a mining machine, the combination with an electric motor having an armature shaft, of cutting mechanism including a swinging cutter bar disposable in different planes respectively to effect horizontal and vertical cuts, means for changing the plane of cut of said cutter bar, means operated from one end of said armature 100 105 110 115 shaft for driving said cutting mechanism and swinging said cutter bar, and means operated from the same end of said armature shaft for moving said motor and cutting mechanism bodily to effect feeding of the latter.
175. In a machine of the nature described, the combination with a tool support rotatable on a horizontal axis, of mechanism for effecting rotation of said support, a cutting tool, members supporting said tool on said support for movement 120 125 130 135 toward and from the axial line of said support and for swinging on an axis at right angles to the plane of the kerf cut by said cutting tool, means for moving the said tool toward and from the axial line of the rotary support and for swinging said tool on said right angle axis, and means comprising a motor on said support for actuating said cutting tool and feeding the same.
176. In a mining machine, the combination with a kerf-cutter and a driving motor therefor, of means for supporting said kerf-cutter for angular adjustment, said kerf-cutter being adapted to cut in planes substantially parallel to the axis of said adjustment and also in planes intersecting said axis, means for moving said kerf-cutter bodily and arcuately toward and from said axis to adjust such kerf-cutter, and means for feeding said kerf-cutter while in its adjusted position.
177. In a mining machine, the combination with a support, of a motor casing rotatably mounted thereon for adjustment about a horizontal axis, and cutting mechanism carried by said motor casing and adjustable by rotation of said casing to cut in horizontal or vertical planes,

said cutting mechanism being adjustable with respect to said casing.

178. In a mining machine, the combination with a support, of a motor casing rotatably mounted thereon, cutting means comprising a kerf-cutter carried by said motor casing, a gear carried by said motor casing, a pinion co-operating with said gear to rotate said casing, a motor in said casing to drive said cutting means, and means operated by said motor for swinging said kerf-cutter.

179. In a machine of the nature described, the combination with a tool support rotatable on a horizontal axis, of mechanism for effecting rotation of said support, a cutting tool, a plurality of articulated members supporting said tool on said support for movement toward and from the axial line of said support and for swinging the tool on an axis at right angles to the plane of the kerf cut by said cutting tool, and operator-controlled power-actuated transmission mechanism for swinging the cutting tool in a plane at right angles to said last named axis.

180. In a mining machine, the combination with a pair of parallel ways, of cutting mechanism including a motor movable along said ways, said cutting mechanism comprising a cutter-chain carrying cutter-bar movable relatively to said ways and operative to cut a kerf partially above and partially below the plane of said ways, said cutter-chain being arranged to cut a kerf to admit the bar and said motor having at one end thereof power transmitting means to effect longitudinal movement of said cutter bar and actuation of said cutter-chain.

181. In a mining machine, the combination with a support, of a turntable thereon, parallel ways on said turntable, cutting mechanism including a pivoted cutter bar movable in a vertical plane intersecting the horizontal plane extending through said ways, said cutting mechanism including a cutter chain on said cutter bar to cut a kerf to admit the bar and including also a motor movable along said ways and power-transmission mechanism operated thereby to drive the cutter chain and swing the cutter bar in a vertical plane and feed the cutter bar rectilinearly above and below the plane through said ways.

182. In a mining machine, the combination with a support, of a turret mounted thereon for rotation on a vertical axis, cutting mechanism reciprocable bodily upon said turret and including a motor and an elongated chain kerf-cutter pivoted to swing in a vertical plane and operative to cut a kerf when it is moved edgewise into the mine vein, said motor having connected to one end thereof power transmission mechanism to effect reciprocation of said kerf-cutter and to swing said kerf-cutter, and means for angularly positioning said turret and locking the same.

183. In a mining machine, the combination with a truck, of a support non-rotatably carried thereby but movable longitudinally therealong, a co-operating support pivoted on said first-named support on a longitudinal axis, means for adjusting said co-operating support about its axis in either direction from a vertical plane through said axis, and kerf-cutting mechanism on said co-operating support including a cutting element and a driving motor therefor.

184. In a mining machine, the combination with a mining machine truck, of a support non-rotatably carried thereon, a co-operating sup-

port pivoted on a horizontal longitudinal axis substantially midway between the sides of the truck, means for adjusting said co-operating support about its axis, and kerf-cutting mechanism pivoted on said co-operating support for adjustment at will as a whole relatively thereto and including a cutting element and a driving motor therefor.

185. In a mining machine, the combination with a truck, of a support non-rotatably carried thereon, of a co-operating support pivoted on said first-named support on a horizontal longitudinal axis substantially midway between the sides of the truck, means for adjusting said co-operating support about its axis, kerf-cutting mechanism pivoted on said co-operating support for adjustment as a whole relatively thereto and a driving motor therefor, and means for holding said kerf-cutting mechanism in different angular relations to said co-operating support.

186. In a mining machine, the combination with a wheeled truck movable along a trackway, of kerf-cutting mechanism comprising a pivoted elongated kerf-cutter disposable in fixed relation at acute angles to the trackway, means for supporting said kerf-cutter approximately in the plane of said trackway, means for adjusting the elevation and inclination of said kerf-cutter when adjacent the mine bottom, and self-contained power-operated means supported on said truck for moving said kerf-cutter when disposed and adjusted as aforesaid rectilinearly relatively to the trackway, relatively transversely in the same plane and reversely rectilinearly to form a parallel ribbed kerf of a depth substantially equal to the length of the kerf-cutter.

187. In a mining machine, the combination with a wheeled frame, of kerf-cutting mechanism comprising an elongated pivoted kerf-cutter, means for supporting said kerf-cutter adjacent the mine bottom, means for adjusting the elevation of the kerf-cutting mechanism rectilinearly, means for adjusting the inclination of said elongated kerf-cutter relative to the mine bottom on an axis adjacent to the pivot of said kerf-cutter, and self-contained power-operated means for swinging said kerf-cutter in the plane to which it has been adjusted, while said truck remains stationary.

188. In a mining machine, the combination with a wheeled guiding means movable on a trackway, of cutter mechanism thereon comprising a motor and a pivotally mounted horizontally disposed cutter bar, means for moving said cutter bar longitudinally or angularly relative to said guiding means to start a kerf in a face parallel to the trackway or to cut a kerf across a face in front of the end of the truck, and means for varying the angle of the plane of operation of the cutter bar relative to the horizontal.

189. In a mining machine, the combination with a wheeled truck movable on a trackway, of cutter mechanism including a pivoted cutter-chain carrying cutter bar disposable in fixed relation at acute angles to the trackway, self-contained power-operated means supported on said truck for moving the bar when so disposed rectilinearly relative to the trackway, relatively transversely in the same plane, and reversely rectilinearly to form a parallel ribbed kerf of a depth substantially equal to the length of the cutter-bar, and means for varying the angle of the plane of the cutter bar relative to the horizontal.

190. In a mining machine, the combination with a wheeled truck movable on a trackway, of

- cutter mechanism including a cutter-chain carrying cutter-bar disposable in fixed relation at acute angles to the trackway by being pivotal relative to the truck, self-contained power-operated means supported on said truck for swinging the bar and for moving the bar rectilinearly relative to the trackway when positioned at an angle to the direction of the trackway at the opposite sides of the center of the latter, to form a parallel ribbed horizontal kerf of a depth substantially equal to the length of the bar in a face in front of the trackway, said power-operated means comprising a motor disposed horizontally and having its power shaft parallel to the direction of rectilinear feed, and means for inserting said cutter bar to permit cutting in substantially horizontal planes below the axis of the power shaft of said motor and above said axis.
191. In a mining machine, the combination with supporting means, of kerf-cutting mechanism thereon hinged to swing about an axis offset from the longitudinal center line of the machine, said kerf-cutting mechanism comprising an elongated plane chain kerf-cutter, means for swinging said kerf-cutting mechanism about its hinge, and means for effecting tilting of said kerf-cutter on a transverse axis.
192. In a mining machine, the combination with wheeled supporting means, of kerf-cutting mechanism thereon hinged to swing about an axis parallel with and offset from the longitudinal center line of the machine, said kerf-cutting mechanism comprising an elongated kerf-cutter, means for swinging said kerf-cutting mechanism about its hinge, and means to vary the elevation of said kerf-cutter and to tilt the same on a transverse axis.
193. In mining apparatus, the combination with a portable frame, of a coal cutting machine mounted thereon and hinged to said portable frame to swing about an axis extending longitudinally of the apparatus and offset from the longitudinal center line of said portable frame, said coal cutting machine comprising a pivoted elongated kerf-cutter adapted to cut a plain kerf, mechanism for tilting the coal cutting machine about its hinge relative to said portable frame to vary the plane of operation of said elongated kerf-cutter, and motor operated means for swinging said kerf-cutter in its plane in any tilted position of said coal cutting machine about its hinge.
194. In a mining machine, the combination with main supporting means, of supplemental supporting means thereon hinged to swing about an axis offset from the longitudinal center line of the machine, kerf-cutting mechanism carried by said supplemental supporting means including a pivoted cutter-carrying cutter-bar, means for swinging said supplemental supporting means about its hinge to change the plane of cut of said cutter bar, means for swinging said cutter bar about its pivot in any position of said supplemental supporting means on its hinge to cut kerfs in a plurality of intersecting planes, and means for moving said cutter-bar forwardly and rearwardly to effect rectilinear sumping and withdrawal movements of said cutter bar to form a parallel ribbed kerf.
195. In a mining machine, the combination with supporting means, of a cutter carrying head rotatably mounted thereon, a motor carried by said head for rotation therewith, a cutter actuated by said motor, means for rotating said head relatively to said supporting means comprising a worm gear encircling the head axis and secured to said head, a worm meshing with said worm gear, and means for rotating said worm in opposite directions.
196. In a mining machine, the combination with supporting means, of cutting mechanism thereon including a rotatable cutter carrying head and a driving motor for said cutting mechanism and including a motor casing rotatable with said head, and means for effecting rotation of said head and motor casing relatively to said supporting means including a gear encircling the head axis and a driving gear meshing with said gear.
197. In a mining machine, the combination with supporting means, of an elongated chain kerf-cutter comprising a cutter bar and head secured thereto, a motor having a casing, a worm gear on the casing encircling the axis of said head, means for supporting said head on said casing to swing on said axis, a worm carried by said head in position to mesh with said worm gear, means for operating said worm in either direction to effect swing of said kerf-cutter on said axis, and means for driving the kerf-cutter from said motor.
198. In a mining machine, the combination with a wheel supported truck, of means for moving said truck along a trackway at a feeding speed, a turntable rotatably mounted on said truck and vertically adjustable relative thereto, an overhanging downwardly projecting bracket carried by said turntable, a horizontally projecting elongated kerf-cutter mounted upon the lower end of said bracket and rotatable thereon in horizontal planes, means to lock said kerf-cutter in either of several positions of angular adjustment, means to rotate the turntable and lock the same, and means mounted upon said turntable to actuate said kerf-cutter.
199. In a mining machine, the combination with a wheel supported truck, of a supporting member rotatably mounted upon said truck and turnable in horizontal planes and bodily vertically adjustable relative to the truck wheels, a radially and downwardly extending bracket carried by said supporting member, a horizontally projecting elongated kerf-cutter mounted upon the lower and outer end of said bracket and pivotable thereon and relative thereto in horizontal planes, means to lock said kerf-cutter in either of several positions of angular adjustment relative to said bracket, means to rotate the rotatably mounted supporting member, and motor operated means to actuate the kerf-cutter and feed the truck during cutting.
200. In a mining machine, the combination with a truck adapted to travel on a mine track, of a turntable mounted thereon for rotation relatively thereto on an upright axis, means for adjusting the elevation of said turntable relative to said truck, a radially and downwardly extending overhanging bracket, mounted on said turntable, a horizontally projecting elongated kerf-cutter mounted upon the lower end of said bracket, and pivotal thereon and relative thereto in horizontal planes, means for locking said kerf-cutter in any one of several positions of angular adjustment relative to said bracket, means to rotate the turntable and lock the same relative to said truck, means comprising a motor on the turntable for driving the kerf-cutter, and motor-operated means for moving the truck along the track at a feeding speed to feed the kerf-cutter

- rectilinearly while locked against swinging on either of its vertical pivotal axes.
201. In mining apparatus, the combination with a wheeled truck adapted to run on a mine trackway, of a support on said truck having a portion overhanging the front end of the truck and adjustable into different positions, a frame mounted on said overhanging support portion for swinging movement relatively thereto and having a portion adapted to project laterally outside the mine trackway, kerf-cutting mechanism including a cutter bar pivotally mounted at the outer extremity of said projecting frame portion for swinging movement relatively thereto about a vertical axis, a motor, and means driven by said motor for actuating said cutting mechanism and for propelling the apparatus along the mine trackway. 80
202. In mining apparatus, the combination with a support, of a frame guided along said support, cutting mechanism carried by said frame and including a cutter bar, means for moving said frame and cutting mechanism along said support in opposite directions at the same speed, a motor for operating said cutting mechanism, and reversing mechanism for effecting reversal of the movement of said cutting mechanism while said motor runs continuously in the same direction. 85
203. In mining apparatus, the combination with a portable frame, of a guiding frame thereon, cutting mechanism including an elongated chain kerf-cutter movable relatively to said guiding frame while said kerf-cutter occupies a vertical plane, means comprising a motor for moving said kerf-cutter rectilinearly forwardly and rearwardly at a feeding speed to cut a vertical plane kerf into the face of the mine vein, and reversing mechanism for withdrawing the kerf-cutter while the motor continues to run in the same direction to continue to operate said kerf-cutter at a feeding speed. 90
204. In a mining machine, the combination with a truck adapted to travel along a mine track, of a turntable mounted thereon, a horizontal elongated chain kerf-cutter mounted on said turntable to move bodily therewith, means comprising an electric motor supported on said turntable for driving said kerf-cutter, means for adjusting said kerf-cutter in elevation and inclination relative to the horizontal, and self-contained power-operated mechanism for feeding said kerf-cutter rectilinearly relatively to the mine track, arcuately across the face of the mine vein in advance of the mine track, and reversely rectilinearly relatively to the mine track to insert a parallel ribbed kerf in said face. 95
205. In mining apparatus, the combination with a truck adapted to travel along a mine track, of a carrier pivoted to said truck on an upright axis, a unitary mining machine comprising a motor and mounted on said carrier to rotate bodily therewith, means for rotating said carrier to effect arcuate swinging movement of said mining machine including said motor, while said truck is stationary and for locking of said carrier in adjusted angular position, and self-contained power-operated mechanism to effect feeding movement of said mining machine along rectilinear lines parallel to the mine track. 100
206. In mining apparatus, the combination with a truck adapted to travel along a mine track, of a carrier pivotally mounted thereon, a unitary mining machine mounted on said carrier and comprising a pivoted elongated kerf-cutter and self-contained power-operated means for imparting a swinging feeding movement thereto on its pivot while said truck remains stationary on the mine track, means for locking the carrier in an adjusted angular position relative to the truck, and operator-controlled power-operated feeding mechanism to effect rectilinear feed of said kerf-cutter while said carrier is locked in such angular position. 105
207. In mining apparatus, the combination with a truck adapted to travel along a mine track, of a carrier pivotally mounted thereon, a unitary mining machine mounted on said carrier and comprising a motor and a frame with an elongated kerf-cutter pivoted thereto and means operated by said motor for effecting arcuate feeding movement of said kerf-cutter relatively to said frame while said truck remains stationary on the mine track, and motor operated truck propelling mechanism mounted on the truck for operation independently of said mining machine. 110
208. In mining apparatus, the combination with a truck adapted to travel along a mine track, of a carrier pivoted to said truck on an upright axis, a unitary mining machine comprising a motor and mounted on said carrier to rotate bodily therewith, means for rotating said carrier to effect arcuate swinging movement of said mining machine while said truck is stationary and for holding said carrier in adjusted angular position, and self-contained power-operated mechanism for effecting feeding movement of said mining machine along rectilinear lines parallel to the mine track. 115
209. In mining apparatus, the combination with a truck adapted to travel on a mine track, of a carrier pivoted thereto to rotate on an upright axis, a unitary mining machine mounted on said carrier to move bodily therewith, said mining machine comprising a motor operatively connected to kerf-cutting mechanism, self-contained power-operated mechanism for effecting swinging feeding movement of said kerf-cutting mechanism, and self-contained power-operated mechanism for effecting rectilinear feeding movement of said kerf-cutting mechanism. 120
210. In a mining machine, the combination with a main frame, of a supplemental frame movable rectilinearly relatively to said main frame, a pivoted elongated chain kerf-cutter mounted on said supplemental frame to move bodily therewith in an upright plane, and self-contained power-operated mechanism for sumping said kerf-cutter into the upper portion of the face of the mine vein and moving the same downwardly in the same plane and withdrawing the kerf-cutter rectilinearly while said main frame remains stationary to insert a plane upright kerf having top and bottom surfaces respectively in continuation of the roof and floor of the mine entry being extended. 125
211. In a mining machine, the combination with a main frame, of a supplemental frame guided rectilinearly thereon, a pivoted elongated chain kerf-cutter mounted on said supplemental frame to move bodily therewith, means for adjusting said kerf-cutter on a horizontal axis to positions to cut in horizontal planes or to positions to cut in vertical planes, means comprising a flexible draft element having its free end connected to a fixed anchorage extraneous to the machine for moving both frames to feed said kerf-cutter when cutting in a horizontal plane, and self-contained power-operated mechanism for moving said supplemental frame relatively 130
- 75

- to said main frame while the latter is stationary to effect rectilinear feed of said kerf-cutter when in a vertical plane, then moving said kerf-cutter angularly in the same plane, and finally with-
5 drawing said kerf-cutter rectilinearly to complete a vertical kerf. 80
212. In mining apparatus, the combination with a wheeled truck, of cutting mechanism mounted thereon including a cutter bar movable 10 relatively to said truck in a vertical plane and having cutting elements movable therealong for cutting a kerf to admit said bar, a reversible motor, means driven by said motor and including gearing providing sufficient speed reduction for 15 moving said cutter bar relatively to said truck at a cutting speed, and means associated with said bar moving means and driven by said gearing for effecting rectilinear movements of said cutting mechanism in opposite directions without 20 reversal of said motor, for effecting sumping and withdrawal movements of said cutter bar during cutting. 85
213. In a mining machine, the combination with supporting means, of a machine frame there-
25 on rotatable about a substantially horizontal axis extending longitudinally of the machine, cutting mechanism carried by said frame including a pivoted cutter bar, a motor carried by said frame to move bodily therewith, and mechanism for ef-
30 fecting rotation of said frame about its axis to adjust bodily said cutter bar and said motor. 90
214. In mining apparatus, the combination with a portable support, of a coal cutting ma-
chine journaled thereon for rotation about a hor-
35 izontal axis extending longitudinally of said sup-
port and comprising a motor and cutting and feeding mechanism driven thereby, and means for effecting rotation of said machine relatively to said support. 100
215. In a mining machine, the combination with a portable main frame, of a supplemental frame slideable longitudinally along said portable main frame, a motor mounted on said supplemental frame, an elongated chain kerf-cutter comprising a pivoted cutter bar, a support mounted on said supplemental frame for rotation relatively there-
40 to on a horizontal axis, means for pivotally mounting said kerf-cutter on said support for rotation relatively thereto on an axis permanently at right angles to the plane of said cutter bar and extending transversely of said horizontal axis, means comprising worm gearing for swinging said kerf-cutter on its right angle axis to adjust the angular position of said kerf-cutter, means com-
45 105 prising a worm gear concentric with said horizontal axis for rotating said support on said horizontal axis to position said kerf-cutter in upright or horizontal planes parallel to said horizontal axis, means for effecting tilting of said kerf-cutter on a horizontal axis extending transversely of said first-named horizontal axis, and self-con-
50 tained power-operated mechanism including said motor for moving said supplemental frame along said main frame to feed said kerf-cutter recti-
55 110 linearly. 115
216. In a universal mining machine, the combi-
nation with a wheeled supporting frame adapted to travel along a mine track, of a turntable thereon, a main guide frame mounted on said turntable to move bodily therewith, a supplemental guide frame slideable transversely of itself along said main guide frame, a non-rotatable recipro-
60 115 cable frame mounted on said supplemental guide frame, a bracket swiveled to said reciproicable frame for rotary adjustment on a horizontal axis,
65 120
- a turret pivoted to said bracket for rotation on an axis transverse relative to said longitudinal axis and offset therefrom, an elongated chain kerf-cutter comprising a cutter bar, means for swiveling said cutter bar to said turret for swing-
70 ing movement on an axis at right angles to the plane of said bar, means for moving the whole machine along the mine track or said main guide frame along said supporting frame to secure feed-
75 ing movement of the kerf-cutter parallel to the mine track, self-contained power-operated means for effecting reciprocation of said non-
80 rotatable frame to secure rectilinear feed of said kerf-cutter outwardly from the supporting frame and back toward it, means for rotating said turn-
85 125 table and holding the same in adjusted position relative to said supporting frame, means for rotating said bracket to vary the plane and elevation of the said kerf-cutter, and locking said bracket in adjusted position, means for adjusting the elevation of the turntable relatively to said sup-
90 130 porting frame to vary the elevation of said kerf-
95 cutter, means for rotating said turret on said transverse axis to move the kerf-cutter toward or from the axial line of said bracket and locking said turret in adjusted position, and motor oper-
100 135 ated mechanism for driving said kerf-cutter and effecting self-locking swinging adjustment there-
105 140 of on the axis at right angles to the cutter bar, said kerf-cutter being adjustable to positions at the floor level with its pivot at either side of the mine track in a narrow entry and to positions at the floor level in advance of the mine track and to a plurality of horizontal positions at various elevations above the mine bottom including a horizontal plane above all other parts of the ma-
110 145 chine and to positions at various elevations inclined upwardly and downwardly from the horizontal and to upright positions in vertical planes to cut kerfs in the roof or the floor or either rib wall or the working face in advance of the mine track and to various planes parallel to said first-named horizontal axis and to and from the axial line of said bracket to planes intersecting said axial line. 150
217. In a mining machine, the combination with a truck, of a turntable mounted thereon to rotate on a vertical axis, a motor carried by said turntable, kerf-cutting mechanism operatively connected to said motor and comprising an elongated chain kerf-cutter adapted to occupy horizontal positions in relatively high planes, means for rectilinearly vertically adjusting the position of said kerf-cutter, and self-contained power-oper-
120 155 ated means for effecting rectilinear sumping and withdrawal and intermediate swinging feeding movements of said kerf-cutter to cut a parallel ribbed kerf in the upright face of a mine vein. 160
218. In a mining machine, the combination with a truck adapted to travel on a mine track, of a turntable mounted thereon, an elongated chain kerf-cutter supported by said turntable and movable bodily therewith, means for adjusting said kerf-cutter in elevation, means for adjusting said kerf cutter inclination relative to the horizontal on transverse axes, means for locking said turntable in an adjusted angular position relative to said truck, and self-contained power-operated mechanism for feeding said kerf-cutter rectilinearly parallel to the mine track while locked at an ad-
135 165 justed angle relative to the truck. 170
219. In a mining machine, the combination with a portable supporting frame, of a supplemental frame mounted thereon for movement relatively thereto, a motor on said supplemental frame and

movable bodily therewith, an elongated chain kerf-cutter, means for supporting said kerf-cutter on said supplemental frame for adjustments on three different axes relatively to said supplemental frame, one at right angles to the kerf-cutter and the other two extending transversely of each other and each parallel to and spaced from the plane extending through said kerf-cutter, means for effecting the adjustments of said kerf-cutter relatively to said supplemental frame on said three axes, and means for driving said kerf-cutter from said motor in any of its adjusted positions.

220. In a mining machine, the combination with a flat elongated chain kerf-cutter, of means for supporting said kerf-cutter for swinging feeding movement on an axis extending at right angles to the plane of said kerf-cutter, a plurality of serially arranged supports connected to said supporting means, each of said serially arranged supports being rotatable on an axis which is always transverse to the axis of the next adjacent support beginning with a horizontal axis of rotation of the first support permanently transverse to said right angle axis, and means for moving said supporting means and said supports each to its adjusted position individually and holding it there, the adjustment on the horizontal axis of rotation of said first support enabling the inclination of the kerf-cutter and of its right angle axis to be adjusted on said horizontal axis to a slanting kerf-cutting position relative to a horizontal plane with the ends of the kerf-cutter at different elevations and said right angle axis out of a vertical plane.

221. In a mining machine, the combination with a supporting frame, of a supplemental frame structure, an elongated chain kerf-cutter, means for supporting said supplemental frame structure for rectilinear sliding movement relatively to said supporting frame, means for supporting said kerf-cutter for adjustment to a plane above all other parts of the machine and to a plane at the mine floor level, means for adjusting the kerf-cutter to such positions, motor operated means for driving said kerf-cutter and for feeding the same rectilinearly into the mine vein to produce a sumping cut, and power-operated mechanism comprising a rope anchored extraneously to the machine to move both frames rectilinearly in a direction extending transversely of the kerf-cutter to cut a kerf extending the sumping cut in a long wall operation.

222. In mining apparatus, the combination with a supporting frame, of a supplemental frame pivoted thereto on an upright axis, an elongated cutter pivoted on said supplemental frame, means for swinging said supplemental frame and said elongated cutter on said first-named axis, means for swinging said elongated cutter about its pivot relatively to said supplemental frame, the two pivots being horizontally spaced, and self-contained power-operated mechanism for moving said supplemental frame relatively to said supporting frame to secure rectilinear feed of said elongated cutter while said supporting frame remains stationary.

223. In a mining machine, the combination with a main frame, of a supplemental frame, an elongated chain kerf-cutter pivotally supported by said supplemental frame to move bodily therewith, means for adjusting the kerf-cutter on its pivot relatively to said supplemental frame, power-operated means for feeding said kerf-cutter into the coal face longitudinally, and

power-operated means for feeding the kerf-cutter laterally along rectilinear lines.

224. A mining machine comprising a supporting frame, a supplemental frame slidably mounted on said supporting frame for advancing and retracting movements relatively thereto, a kerf-cutter pivotally connected to said supplemental frame, self-contained power-operated means for effecting a transverse feeding movement of said kerf-cutter, power-operated means for advancing and retracting said supplemental frame, and means for controlling said power-operated means to effect the cutting of a straight kerf.

225. In a mining machine, the combination with a truck adapted to travel on a mine track and be braced thereby, of elongated chain kerf-cutting mechanism, framework for pivotally supporting said kerf-cutting mechanism on said truck at all times on an axis at right angles to the plane thereof, mechanism for bodily and arcuately lowering the kerf-cutting mechanism relatively to said supporting framework on an axis adjacent to said right angle axis to a transverse horizontal plane beneath the plane extending through the top of the track with its pivot at one side of the track, said kerf-cutting mechanism being supported by said framework while thus lowered, and means for effecting vertical adjustment of said kerf-cutting mechanism while in said horizontal plane.

226. In a mining machine, the combination with a main frame, of a supplemental frame slidably mounted for reciprocating movement longitudinally of said main frame, an elongated chain kerf-cutter, means for pivotally supporting said kerf-cutter on said supplemental frame for adjustment relatively thereto on three different axes, one of which is horizontal and permanently longitudinal of said supplemental frame and another of which is permanently at right angles to the plane of the kerf-cutter and the third of which is permanently transverse relative to the other two axes, separate and independent means for adjusting the position of the kerf-cutter on each of said axes individually and holding the kerf-cutter locked in its adjusted positions, and self-contained power-operated mechanism under the control of the operator for effecting rectilinear movements of said supplemental frame and said kerf-cutter while the latter occupies a plane parallel to the path of travel of said supplemental frame.

227. In a mining machine, the combination with a main frame, of a supplemental frame mounted on said main frame for movement relatively thereto, an elongated chain kerf-cutter supported on said supplemental frame to move bodily therewith, means for adjusting said kerf-cutter on a horizontal axis relatively to said supplemental frame, means for adjusting said kerf-cutter on an axis permanently at right angles to the plane of said kerf-cutter, means for adjusting said kerf-cutter on an axis extending transversely of both said horizontal axis and said right angle axis, and means for moving said supplemental frame rectilinearly relatively to said main frame to secure rectilinear feeding movement of said kerf-cutter in its adjusted position.

228. In a mining machine, the combination with a main frame, of a supplemental frame movable rectilinearly relatively to said main frame, an elongated chain kerf-cutter mounted on said supplemental frame to move bodily therewith, means for adjusting said kerf-cutter on three different axes, one of which is permanently at

- right angles to the plane of the kerf-cutter and another of which extends at right angles to said permanent right angle axis, means for adjusting the kerf-cutter individually on the three different axes, and motor-operated mechanism for moving the supplemental frame rectilinearly relatively to said main frame to secure rectilinear feeding movement of said kerf-cutter in its adjusted position. 80
- 10 229. In a mining machine, the combination with a supporting frame, of an elongated chain kerf-cutter, a support mounted on said frame for rotation relatively thereto on a longitudinal axis, a supplemental support mounted on said first-named support for rotation relatively thereto on an axis extending at right angles to said first-named axis, means for rotating said first-named support on said longitudinal axis to adjust the position of said kerf-cutter to cut in relatively high or relatively low cutting planes, independent means for rotating said supplemental support on said right angle axis to move the kerf-cutter toward or from the axial line of said longitudinal axis, and motor-operated mechanism for operating said kerf-cutter including swinging feeding movement. 85
- 15 230. In a mining machine, the combination with a widely expanded base frame, of a cutting tool support mounted thereon for rotation relatively thereto on a horizontal axis, mechanism for effecting rotation of said support on said horizontal axis relatively to said frame, an elongated kerf-cutting tool, members supporting said elongated cutting tool on said support for movement toward and from the axial line of said support, means on said rotatable support for positively moving said elongated tool toward and from the axial line of said rotary support and holding the same in adjusted position relative to said support during kerf-cutting operation in any of its adjusted positions, and operator-controlled self-contained motor operated apparatus for operating said elongated cutting tool including the feed thereof, said motor operated apparatus comprising power transmission mechanism extending along said horizontal axis and said support to said cutting tool to drive the same. 90
- 20 231. In a mining machine, the combination with a truck adapted to run upon and be braced by a mine track, of a turntable mounted on said truck for adjustment relative thereto on a vertical axis, means associated with the periphery of said turntable to rotate the same, mechanism for adjusting the elevation of said turntable relative to said truck, an endless chain kerf-cutter comprising an elongated cutter bar, supporting framework mounted on said turntable to move bodily therewith, means for pivotally mounting the rear end of said cutter bar on said framework on an axis spaced horizontally from the vertical axis of said turntable so as to occupy a position outside of the boundaries of said truck to enable said kerf-cutter to occupy a position wholly at one side of the mine track, means independent of said elevating mechanism for adjusting said kerf-cutter relative to said turntable for disposition at the mine bottom wholly at one side of the mine track to cut a kerf in continuation of such mine bottom, and means for operating said kerf-cutter including rectilinear feed thereof along such mine bottom. 95
- 25 232. In a mining machine, the combination with a truck adapted to move along a mine track midway between the ribs of an entry, of a turntable mounted on said truck, mechanism for adjusting the elevation of said turntable relative to said truck, means associated with the periphery of said turntable to rotate the same, supporting framework mounted on said turntable to move bodily therewith, an elongated chain kerf-cutter comprising a cutter bar pivoted at its rear end to said framework for support thereby in a transportation position above the mine track and below a horizontal plane extending through the top of the machine, mechanism for adjusting the turntable relative to said truck to move the bar pivot wholly to one side of the mine track, means independent of said elevating mechanism and mounted on said framework for moving said kerf-cutter to a horizontal plane at the mine bottom wholly at one side of the mine track while said kerf-cutter remains at all times supported by said framework, and means for operating said kerf-cutter to produce a rectilinear sumping cut and an arcuate cut and a reversely rectilinear withdrawal cut to produce a kerf in advance of the mine track and the sides thereof in continuation of the mine bottom on which the track is laid. 100
- 30 233. In a mining machine, the combination with a wheeled truck adapted to travel on a mine track and be braced thereby, of a turntable mounted thereon for angular adjustment relatively thereto on a vertical axis, means for effecting such angular adjustment and holding the turntable in adjusted position, an elongated support mounted on said turntable and extending outwardly therefrom, means for rotating said elongated support on an axis extending outwardly from said turntable and holding the same in adjusted position relative to said turntable, an elongated chain kerf-cutter comprising an elongated cutter bar, mechanism for mounting said kerf-cutter on the outer end of said elongated support for adjustment relative thereto on rectangularly related axes one of which is at right angles to the plane of said cutter bar and the other of which extends at right angles to said outwardly extending axis, means for effecting adjustments of said kerf-cutter on said rectangularly related axes, and motor operated means comprising power transmission mechanism extending along said outwardly extending axis to said kerf-cutter to drive the same while supported in adjusted position. 105
- 35 234. In a coal mining machine, the combination with a truck having wheels adapted to run on a mine track, of an elongated chain kerf-cutter comprising an elongated cutter bar, means for pivotally supporting said cutter bar on two different horizontally spaced vertical axes one of which is intermediate the ends of said truck and the other of which is outside of the limits of said truck, means for locking said cutter bar in adjusted position on its pivotal axes, mechanism comprising self-locking worm gearing for adjusting said kerf-cutter along lines transversely of its plane from a position above the horizontal plane of the track down to a kerf-cutting plane at the level of the mine bottom on which the track is laid and at one side of the track while said supporting means continues to carry said kerf-cutter, and self-contained power-operated mechanism supported solely on said truck for operating said kerf-cutter including rectilinear sumping feed thereof to cut a kerf in substantial continuation of the mine bottom. 110
- 40 235. In a track mounted mining machine, the combination with a truck adapted to travel on a mine track and be braced thereby, of a turntable 115
- 45 120
- 50 125
- 55 130
- 60 135
- 65 140
- 70 145
- 75 150

- mounted thereon for movement relatively thereto in an upright axis, means for moving said turntable on said upright axis and holding the same in adjusted position relative to said truck, an 5 elongated supporting arm extending outwardly a substantial distance from said turntable, means mounting said arm on said turntable for rotary movement on an axis extending outwardly from said turntable and longitudinally thereof, means 10 for rotating said arm on said last named axis relatively to said turntable and holding said arm in adjusted position relative to said turntable, an elongated chain kerf-cutter comprising an elongated cutter bar, means for supporting the 15 cutter bar on the outer end of said arm for adjustment relative thereto on rectangularly related axes one of which is permanently at right angles to said cutter bar and the other of which extends transversely of said longitudinal axis and permanently 20 at right angles thereto, means for adjusting said kerf-cutter along arcuate lines transversely of the plane of said cutter bar on the axis which extends transversely of said longitudinal axis and is at right angles thereto and holding 25 said cutter bar in adjusted position relative to said arm, means for locking the cutter bar in adjusted position on its right angle axis relative to said arm, the aforesaid holding means serving to connect said cutter bar rigidly to said truck 30 in adjusted position, and motor operated mechanism for operating said kerf-cutter including rectilinear feed thereof by moving the whole machine along the mine track at a feeding speed.
236. In a track mounted coal mining machine, 35 the combination with a wheeled truck adapted to travel on a mine track and be braced thereby, of a turntable mounted thereon for movement relatively thereto on a vertical axis, means for moving said turntable on said vertical axis to adjust 40 the angular position thereof relative to said truck and hold said turntable in adjusted position rigidly connected to said truck, an outwardly extending supporting arm mounted on said turntable for adjustment relative thereto on a horizontal 45 axis, means for moving said arm on said horizontal axis relative to said turntable to adjust the elevation of the outer end of said arm and hold the same in adjusted position rigidly connected to said turntable, an elongated chain kerf- 50 cutter comprising an elongated kerf-cutter, mechanism for pivotally connecting said cutter bar to the outer end of said arm for adjustment relatively thereto on an axis extending transversely of the said arm, means for moving said 55 cutter bar on said transverse axis along arcuate lines extending transversely of the said cutter bar and holding said cutter bar in adjusted position rigidly connected to said arm, a motor on the turntable, power transmission mechanism 60 extending from said motor along said arm to said kerf-cutter to drive the same, and means operated by said motor for moving the whole machine along the mine track to effect rectilinear feed of said kerf-cutter parallel to the mine track.
- 65 237. In a mining machine, the combination with a supporting frame, of a supporting head rotatable on a horizontal axis relatively to said frame, said horizontal axis being in fixed relation to said frame by being confined against change 70 in elevation relative thereto but adapted to occupy a position in a vertical plane extending longitudinally through the horizontal center line of said frame, an elongated kerf-cutting tool, mechanism for supporting said kerf-cutting tool on said head for movement toward or from the hori-

zontal axial line of said head, mechanism for turning the head on said horizontal axis to adjust the elevation of said kerf-cutting tool, means for moving the kerf-cutting tool relatively to said head toward or from said horizontal axial line of said head, and operator-controlled self-contained motor operated mechanism for driving said kerf-cutting tool and swinging it on an axis at right angles to the plane of the kerf cut by said tool.

238. In a mining machine, the combination with a kerf-cutting unit, of a head, means for rotatably supporting said head on a horizontal axis, spaced apart trunnions for pivotally supporting said kerf-cutting unit on an axis spaced from said horizontal axis and extending transversely thereof, means for adjusting the angular position of said kerf-cutting unit relative to said trunnions, and motor operated mechanism for feeding said kerf cutting unit on an axis at right angles to the plane of the kerf cut thereby.

239. In a mining machine, the combination with a supporting frame, of a head mounted thereon for rotation relatively thereto on a horizontal axis confined against change in elevation relative to said frame, a flat elongated chain kerf-cutter comprising an elongated cutter bar, members supporting said kerf-cutter on said head for adjustment relative thereto on rectangularly related axes on one of which said kerf-cutter is movable toward or from said horizontal axis and on the other of which said kerf-cutter is movable in its own plane, mechanism for rotating said kerf-cutter on said rectangularly related axes, and motor operated mechanism for driving said kerf-cutter.

240. In a mining machine, the combination with a supporting frame, of wheeled means for carrying said frame for movement along a mine track, a rotary head mounted on said frame on a longitudinal axis, an elongated kerf-cutter comprising an elongated cutter bar, members supporting said kerf-cutter for adjustment thereof toward and from the longitudinal axis of said rotary head, means for rotating said head on said longitudinal axis, and means for adjusting the kerf-cutter bodily and arcuately transversely of its plane on an axis intersecting said longitudinal axis and at right angles thereto.

241. In a mining machine, the combination with a portable supporting frame, of a head mounted thereon for rotation relatively thereto on a horizontal axis, an elongated chain kerf-cutter mounted thereon for adjustment relatively thereto on another horizontal axis and on an axis at right angles to said kerf-cutter, means for rotating said head on said first-named horizontal axis, means comprising self-locking worm gearing for rotating said kerf-cutter on said right angle axis, a motor on said supporting frame, power transmission mechanism between said motor and said kerf-cutter to drive the same, means comprising self-locking worm gearing for swinging said kerf-cutter on said second named horizontal axis to adjust the kerf-cutter to a slanting position, and power operated mechanism for moving the whole machine rectilinearly to secure rectilinear feeding movement of the kerf-cutter when in either floor cutting position or roof cutting position or in any slanting position intermediate the floor and the roof.

242. In a mining machine, the combination with a truck adapted to travel on a mine track, of a widely expanded turntable having a width approximately equal to the width of said truck

- and mounted on said truck for movement relatively thereto on an upright axis, means associated with the periphery of said turntable for rotating the latter and locking the same in adjusted angular relation to said truck, means for adjusting the elevation of said turntable relative to said truck, an elongated chain kerf-cutter pivoted to said turntable for swinging movement relatively thereto on an upright axis outside of the boundaries of said truck and at either side thereof, means for holding said kerf-cutter in adjusted angular relation to said turntable during rectilinear feed of said kerf-cutter, and self-contained power-operated mechanism for operating said kerf-cutter including rectilinear feed thereof while being held in adjusted angular relation to said turntable with its pivot at one side of the truck.
243. In a mining machine, the combination with supporting framework, of a supplemental frame mounted thereon for adjustment relative thereto on a horizontal axis in a plane having a fixed relation to said framework, an elongated kerf-cutter, means for adjustably supporting said kerf-cutter on said supplemental frame to occupy a plurality of positions parallel to said horizontal axis and at a plurality of distances therefrom, means for adjusting said kerf-cutter to occupy a plurality of horizontal positions at a plurality of distances from said horizontal axis including horizontal positions adjacent to said horizontal axis, and mechanism for rotating said supplemental frame together with said kerf-cutter on said horizontal axis relatively to said supporting framework.
244. In a mining machine, the combination with a supporting frame, of means carrying said frame for travel along a mine track, a supplemental frame mounted on said supporting frame for adjustment relative thereto on a horizontal axis which is in fixed relation to said supporting frame by being confined against change in elevation relative thereto, an elongated kerf-cutter adjustably mounted on said supplemental frame to occupy positions at various distances from said horizontal axis including positions adjacent to and parallel with said horizontal axis, means for rotating said supplemental frame on said horizontal axis to vary the position of said kerf-cutter from relatively low cutting planes to relatively high cutting planes, and means operable while said kerf-cutter continues to be supported by said supplemental frame to adjust said kerf-cutter relative to said supplemental frame to locate the kerf-cutter at a plurality of distances from said horizontal axis and approximately parallel thereto.
245. In mining apparatus, the combination with a wheeled supporting frame movable along a mine track, of a widely expanded turntable having a diameter approximately equal to the width of said truck and pivoted thereto on a vertical axis, mechanism for locking said turntable in adjusted angular position, a motor carried by said turntable, a head mounted on said turntable to move bodily therewith and to turn over relatively thereto on a horizontal axis in a plane having a fixed relation to said turntable, an elongated chain kerf-cutter pivotally mounted on the outer end of said head, mechanism operated by said motor for driving said kerf-cutter, means for turning over said head together with said kerf-cutter while the latter is supported clear of the surface on which the track is laid, and mechanism carried by said head for adjusting said kerf-cutter to a plurality of positions parallel to said horizontal axis and at a plurality of distances therefrom including positions adjacent to said horizontal axis while said kerf-cutter is supported entirely above said surface.
246. In a mining machine, the combination with a truck adapted for travel on a mine track, of an elongated kerf-cutter comprising a flat cutter bar with an endless chain cutter thereon, means for supporting said kerf-cutter for swinging adjustment relative to said truck on parallel axes one of which is always at right angles to the plane of the cutter bar and within the path of travel of said endless chain cutter, means for swinging said kerf-cutter on either of said axes, means for supporting said kerf-cutter for adjustment bodily angularly on a longitudinal axis extending transversely of both of the aforesaid axes, means for effecting the last-named adjustment of said kerf-cutter, and mechanism co-acting with the means for swinging the kerf-cutter on its right angle axis for adjusting the kerf-cutter into a plurality of parallel positions parallel to said longitudinal axis and at a plurality of distances therefrom.
247. An entry cutting installation comprising, in combination, a truck adapted to travel along a mine track, a supporting frame pivoted to said truck for movement relatively thereto on an upright axis, an elongated chain kerf-cutter comprising an elongated cutter bar, an upright pivotal connection between said cutter bar and said supporting frame, said upright pivotal connection being horizontally and variably spaced from said first-named pivot, means for holding said frame in adjusted angular position relative to said truck, mechanism for holding said kerf-cutter in adjusted angular relation to said frame, means for adjusting the horizontal space between said vertical pivots, power-operated mechanism for effecting rectilinear feeding movements of said kerf-cutter, and self-contained power-operated mechanism for effecting arcuate feeding movements of said kerf-cutter.
248. In a mining machine, the combination with a supporting frame, of a supplemental frame mounted thereon for sliding movement relatively thereto along rectilinear lines the outer end of said supplemental frame being projected outwardly from said supporting frame, an elongated kerf-cutter carried on the outer end of said supplemental frame to move bodily therewith in position to project downwardly into the surface on which the first-named frame is supported, and means for operating said kerf-cutter including rectilinear feed thereof outside of the boundaries of said supporting frame by sliding said supplemental frame along said supporting frame to cut an upright kerf into said surface.
249. In mining apparatus, the combination with a wheeled frame movable on a trackway, of a bearing on said frame confined against movement up or down relative thereto but slideable transversely of itself relatively to said frame, a head supported by said bearing for rotation on a horizontal axis confined against movement up or down relative to said frame by said bearing, cutting mechanism comprising a pivotally mounted cutter bar having a chain adapted to cut a kerf for said bar in a coal face when said bar is presented edgewise thereto, means for rotating said head on said horizontal axis to adjust the position of said cutting mechanism for the cutting of either horizontal kerfs or upright kerfs, and self-contained power-operated means for moving said head on said horizontal axis.

said bar bodily rectilinearly of the trackway to present the cutting mechanism edgewise to the coal face and produce a sumping cut, for moving said bar about its pivot in the same plane, and 5 for moving the bar reversely rectilinearly of the trackway, either when the cutter bar is in a horizontal plane or in an upright plane, to insert a horizontal parallel ribbed kerf or an upright parallel ribbed kerf in the mine vein in accordance 10 with the adjusted position of said cutting mechanism, and power-operated means for feeding the kerf-cutter rectilinearly transversely of itself by sliding said bearing transversely of itself along said frame.

15 250. In a mining machine, the combination of a truck movable along a trackway, of a widely expanded turntable having a width greater than the width of said trackway, an elongated chain kerf-cutter mounted on said turntable to move 20 bodily therewith and occupying a top-cutting position in a plane above all other parts of the machine, mechanism for adjusting the elevation of said turntable relative to said truck to vary the elevation of said kerf-cutter, a motor on 25 said turntable, means operated by said motor for driving said chain kerf-cutter, means for rotating said turntable and for locking the same in adjusted angular position relative to said truck, and self-contained power-operated mechanism 30 for moving the kerf-cutter rectilinearly parallel to the mine track at a feeding speed.

251. In mining apparatus, the combination with a supporting frame, of a supplemental frame reciprocable along said supporting frame at a 35 fixed elevation, a head pivoted to said supplemental frame on a horizontal axis fixed as to elevation relative to said supplemental frame, an elongated chain kerf-cutter pivotally connected to said head to swing in its own plane, mechanism 40 for adjusting said kerf-cutter to positions for cutting kerfs in planes parallel to said horizontal axis and at a plurality of distances therefrom, said adjusting mechanism coacting with said head to support said kerf cutter at all times 45 above the surface on which the machine is supported, mechanism for adjusting said head on said horizontal axis through a complete circle, and holding the same in adjusted position, and self-contained power-operated mechanism for 50 swinging said kerf-cutter in its own plane in any of its adjusted positions and for feeding said kerf-cutter rectilinearly parallel to said horizontal axis when in any of said positions parallel to said axis.

55 252. In a mining machine, the combination with a truck movable on a trackway, of a turntable, means associated with the periphery of said turntable for rotating and locking the same, a rotatable head mounted on said turntable on 60 a horizontal axis extending longitudinally of the trackway and confined to a fixed elevation relative to said turntable, means for adjusting the elevation of said turntable relative to said truck, an elongated chain kerf-cutter comprising an 65 elongated cutter bar pivotally connected to said head to swing in its own plane, means for moving said kerf-cutter relatively to said head to adjust the position thereof relative to said horizontal axis, mechanism for rotating said head on said 70 horizontal axis, and self-contained power-operated means for moving said kerf-cutter bodily rectilinearly of the trackway to present the kerf-cutter edgewise to the coal face in advance of the trackway and effect a sumping cut therein, for 75 swinging the kerf-cutter in its own plane and for

withdrawing the kerf-cutter from the coal vein while completing the cutting of the plane kerf therein at right angles to the coal face.

253. In a mining machine, the combination with a truck movable along a mine track, of a turntable, means associated with the periphery of said turntable for rotating and locking the same, a head pivoted to said turntable for rotation relatively thereto on a horizontal axis confined to a fixed elevation relative to said turntable, means for adjusting the elevation of said turntable relative to the truck, an elongated kerf-cutter comprising an elongated cutter bar pivoted at its rear end to said head for swinging feeding movement on an axis permanently at 80 right angles to the plane of said cutter bar, means for rotating said head on said horizontal axis and holding the same in adjusted position, and self-contained power-operated mechanism for presenting said kerf-cutter edgewise to the coal face while occupying an acute angle relative to a line parallel to said horizontal axis and extending through the intersection of said right angle axis and said cutter bar and effecting a 85 sumping cut into the coal vein, for feeding the kerf-cutter about said right angle axis in its own plane, and for feeding the kerf-cutter reversely rectilinearly to insert parallel ribbed kerfs into the coal vein at right angles to the coal face in advance of the mine track, each of 90 said kerfs being in a plane parallel to said horizontal axis and each having a width less than twice the length of the cutter bar.

254. In a mining machine, the combination with a supporting frame, of a supplemental frame 110 guided for movement along said supporting frame rectilinearly and horizontally, a chain-carrying kerf-cutter comprising a cutter bar pivotally mounted on said supplemental frame in position to be presented edgewise to the upright face of a 115 mine vein, means for adjusting said kerf-cutter to cut a kerf in any one of a plurality of intersecting planes, and self-contained power-operated mechanism for operating said kerf-cutter in any one of said planes including rectilinear sumping 120 feed of said kerf-cutter by guiding said supplemental frame rectilinearly and horizontally along said supporting frame followed by transverse feed of said kerf-cutter in its own plane and finally withdrawing the kerf-cutter by a retroacting 125 horizontal rectilinear movement of said supplemental frame along said supporting frame thereby completing a plane parallel ribbed kerf.

255. In a mining machine, the combination with a supporting frame, of a supplemental frame, 130 means for guiding said supplemental frame rectilinearly along said supporting frame, an elongated chain kerf-cutter mounted on said supplemental frame to occupy any one of various intersecting planes each parallel to the path of travel 135 of said supplemental frame relative to said supporting frame, means for adjusting said kerf-cutter into any one of such planes and holding the same in adjusted position, means for pivotally supporting said kerf-cutter for swinging feeding movement in its own plane on an axis permanently at right angles to the plane of said kerf-cutter, and self-contained power-operated mechanism under the control of the operator for moving said supplemental frame horizontally and 140 rectilinearly along said guiding means in opposite directions and for swinging said kerf-cutter on its right angle axis between the end of the forward movement of said kerf-cutter and the 145 beginning of its return movement.

256. In a mining machine, the combination with a wheeled supporting frame movable on a trackway, of guiding means on said frame parallel to said trackway and disposed at right angles to the face of a mine vein, kerf-cutting mechanism moving longitudinally of said guiding means and comprising a pivotally mounted cutter bar having a cutter chain adapted to cut a path for said bar when the latter is presented edgewise to said bar when the latter is presented edgewise to said face, means for adjustably supporting said kerf-cutter in horizontal or upright planes, and self-contained power-operated mechanism for inserting a kerf in said face having provision for moving the cutter bar longitudinally of and angularly relative to said guiding means whether the kerf being cut in horizontal or upright. 80
257. In a mining machine, the combination with a wheeled frame movable along a trackway, of guiding means thereon parallel to said trackway, cutting mechanism connected to said guiding means for movement parallel to the trackway, said cutting mechanism comprising a pivotally mounted cutter bar adapted to cut a path for itself when presented edgewise to the face of a mine vein, mechanism for supporting said cutter bar in an upright plane in shear cutting position, and motor-operated mechanism for effecting movement of said cutter bar angularly and longitudinally parallel to said trackway to insert a plane kerf in said face having a depth substantially equal to the effective length of said cutter bar. 90
258. In a track mounted coal mining machine, the combination with a truck adapted to travel on a mine track and be braced thereby, of a turntable mounted on said truck for rotation relatively thereto on an upright axis, means for rotating said turntable on said upright axis relatively to said truck and holding said turntable in adjusted position relative thereto, a cutter supporting arm mounted on said turntable for adjustment relative thereto on a horizontal axis, means for moving said arm relatively to said turntable on said horizontal axis to adjust the elevation of the outer end of said arm, an elongated chain kerf-cutter comprising an elongated cutter bar, means for pivotally connecting said cutter bar to said arm on rectangularly related axes one of which is at right angles to the plane of said cutter bar and the other of which is parallel to the plane of said cutter bar, means for adjusting said cutter bar arcuately transversely of its plane on said parallel axis and holding the cutter bar in adjusted position, means for holding said cutter bar in adjusted position on its right angle axis, said cutter bar being held rigidly in adjusted position relative to said arm and said arm being held in rigid position relative to said turntable and said turntable being held in rigid position relative to said truck during cutting, motor-operated means comprising power transmission mechanism extending along said arm to said kerf-cutter to drive the same, and motor operated mechanism for moving the whole machine along the mine track to effect rectilinear feeding movement of said kerf-cutter in its adjusted plane at adjusted elevation to cut a kerf parallel to the mine track. 100
259. In a mining machine, the combination with a wheeled truck movable along a mine trackway, of cutter mechanism including a cutter bar, means for pivotally supporting said cutter bar on a vertical axis in a vertical plane extending through the longitudinal center line of the trackway, said cutter bar being supported in a horizontal plane above all other parts of the machine, means for swinging said cutter bar to acute angle positions relative to the trackway and locking the same in such positions, and self-contained power-operated means supported on said truck and including said swinging means for moving the cutter bar rectilinearly relative to the trackway, relatively transversely in the same plane, and reversely rectilinearly to form a parallel ribbed kerf of a depth substantially equal to the active length of the cutter bar. 105
260. A mining machine comprising a turntable rotatable horizontally on an upright axis, means associated with the periphery of said turntable for turning the same on such upright axis, means for adjusting the elevation of the turntable, a neck mounted on said turntable on an axis which is horizontal and confined to a fixed elevation relative to said turntable, an elongated cutting tool, mechanism for supporting said cutting tool at all times above the surface on which the machine is supported and for movement toward and from the axial line of said neck, mechanism for moving the cutting tool toward and from the axial line of the neck while supported as aforesaid above said surface, means for supporting the cutting tool for swinging movement on an axis permanently at right angles to the plane of the kerf cut by said cutting tool, operator controlled power-driven mechanism for effecting swinging feeding movement of said cutting tool on such right angle axis, and motor operated means for driving said cutting tool. 110
261. In a mining machine, the combination with a truck adapted for travel on a mine track, of a turntable having a diameter approximately equal to the width of said truck, means associated with the peripheral portion of said turntable to rotate the same, a head mounted on said turntable to rotate on a horizontal axis confined to a fixed elevation relative to said turntable, mechanism for rotating said head on said horizontal axis, an elongated cutting tool, means for supporting said cutting tool on said head for movement toward and from said horizontal axis, mechanism on said rotatable head for moving said tool toward and from said horizontal axis, means for adjusting the elevation of the turntable relative to the truck and motor operated mechanism for driving said cutting tool and for swinging the same on an axis permanently at right angles to the plane of the kerf cut by said cutting tool. 115
262. In a mining machine, the combination with a wheeled frame movable along a mine track, of a head mounted thereon to rotate on a horizontal axis confined to a fixed elevation relative to said frame and extending parallel to the mine track, means for rotating said head on said horizontal axis and holding the same in adjusted position, an elongated chain kerf-cutter comprising a cutter bar, means for pivotally connecting said cutter bar to said head for swinging in its own plane on an axis permanently at right angles to the plane of said cutter bar, means on said head for adjusting said kerf-cutter to positions at a plurality of distances from said horizontal axis including positions adjacent thereto 120 while supporting said kerf-cutter entirely above the surface on which the machine is supported, motor-operated mechanism for moving the machine along the mine track, and motor operated mechanism for driving the kerf-cutter and swinging the same in its own plane on said right angle axis. 130
263. In a mining machine, the combination with a wheeled frame movable along a mine track, of a rotary support mounted thereon for rota- 145

tion on a horizontal axis fixed permanently in elevation relative to said frame and extending longitudinally of the machine parallel to the mine track, means for rotating said support on 5 said horizontal axis and holding the same in adjusted position, an elongated chain kerf-cutter pivotally connected to said support to swing in its own plane on an axis permanently at right angles to the plane of said kerf-cutter, mechanism for 10 supporting said kerf-cutter for movement toward and from said horizontal axis and to positions in parallelism to said horizontal axis and adjacent thereto, means for effecting movement of said kerf-cutter toward and from said horizontal axis 15 and to a plurality of positions parallel to said horizontal axis and at a plurality of distances therefrom, motor-operated mechanism for moving the entire machine along the mine track, and motor operating mechanism for driving the kerf 20 cutter and for swinging the same on said right angle axis.

264. In a mining machine, the combination with a wheeled supporting frame movable along a mine track, of a turntable mounted thereon to 25 rotate on a vertical axis intermediate the ends of said truck, a depending neck mounted on said turntable to move bodily therewith, means connected directly to the turntable to rotate the same, an elongated kerf-cutter including a pivoted cutter bar provided with cutting elements movable in an orbit within whose limits the pivot of said bar is disposed, said cutter bar being pivotally supported on the outer lower end of said neck to swing relatively thereto on a vertical axis outside of the boundaries of said truck and spaced horizontally from the vertical axis of the turntable, means for holding the cutter bar in 30 adjusted angular relation to said neck, mechanism for adjusting the elevation of said turntable 35 relative to said truck to dispose the cutter bar in a transverse plane beneath the level of the top of the track with its pivot at one side of the mine track, and motor operated mechanism for driving and feeding said kerf-cutter while confined to 40 such plane.

265. In a mining machine, the combination with a wheeled supporting frame adapted to move along a mine track, of a turntable mounted thereon to rotate relatively thereto on an upright axis 45 intermediate the ends of said frame, cutting mechanism pivotally connected to said turntable to swing relatively thereto on an upright axis spaced horizontally from said turntable axis, said cutting mechanism comprising a cutter bar 50 provided with cutting elements moving in an orbit within whose limits the pivot of said cutting mechanism is disposed, means for adjusting the elevation of said cutting mechanism and for varying the inclination thereof along lines 55 transversely of itself on a horizontal axis extending transversely of the machine to position and hold the cutter bar in a transverse plane beneath the level of the top of the track and wholly at one side of the same and extending 60 in a direction making an acute angle with the said track, and self-contained power-operated mechanism for operating said cutting mechanism while being held in said plane.

266. In a mining machine, the combination 65 with a truck adapted to travel on a mine track, of a turntable thereon, a head pivoted to said turntable on an axis parallel to the plane of said turntable, cutting mechanism pivotally connected to said head for swinging movement relatively 70 to said turntable on an axis extending trans-

versely of said horizontal axis, said cutting mechanism comprising a cutter bar provided with cutting elements moving in an orbit within whose limits the transverse axis of said cutting mechanism is disposed, means for adjusting the elevation of said turntable relative to said truck and for varying the inclination of said cutter bar on an axis extending transversely of the machine, mechanism for turning said head on said horizontal axis, and self-contained power-operated mechanism for operating said cutting mechanism including the feed thereof.

267. In a mining machine, the combination with a truck adapted to travel along a mine track, of a turntable mounted thereon for rotation relatively thereto on an upright axis, means connected directly to the turntable for rotating and locking the same, elongated chain kerf-cutting mechanism comprising an elongated cutter bar, a support for said kerf-cutting mechanism swiveled to said turntable on a horizontal axis confined to a fixed elevation relative to said turntable, means for pivotally connecting said elongated cutter bar to said support for swinging movement relatively thereto on an axis permanently at right angles to the plane of said cutter bar, means for rotating said support on said horizontal axis and holding the same in adjusted position relative to said turntable, and means for adjusting the elevation of said turntable relative to said truck and for adjusting the inclination of said kerf-cutting mechanism on another horizontal axis relative to said track.

268. In a coal mining machine adapted to cut a kerf the bottom of which is approximately in 110 the plane of the floor in a narrow entry while the machine is supported and guided and braced by the mine track during its cutting operation, the combination with a main frame, of wheels for supporting said main frame on a mine track, 115 a widely expanded turntable having a diameter approximately equal to the width of said main frame and mounted on said main frame to rotate relatively thereto on an upright axis, means applied to the turntable itself for holding the 120 same in adjusted position relative to said main frame, an overhanging arm connected to said turntable to move bodily therewith in position to swing horizontally across the forward end of the mine track, an elongated cutting element 125 pivotally mounted on the outer end of said overhanging arm in position to swing horizontally, means for adjusting the elevation of said turntable relative to said main frame including lowering of said turntable to change the position of 130 said cutting element from a plane above the level of the mine track to a position adjacent to the plane of the floor, the range of the horizontal movement of said overhanging arm on the main frame and the range of pivotal movement of said 135 cutting element on the outer end of said overhanging arm being such as to permit the cutting element to be at one side of the mine track with its bottom below the level of the top of the track during its feeding in movement, and on the other 140 side of the track with its bottom below the level of the top of the track during its feeding out movement, and self-contained power-operated means for operating said cutting element including rectilinear sumping and withdrawal 145 feeding movements connected by a swinging feeding movement of said cutting element.

269. In a mining machine, the combination with a truck adapted to travel on a mine track, of a turntable mounted thereon, means connected 150

- to the peripheral portion of said turntable to rotate the same, supporting means extending radially outward and downward from said turntable, an elongated kerf-cutter comprising a 5 pivoted cutter bar provided with cutting elements moving in an orbit within whose limits the pivot of said bar is disposed, means comprising a screw below the turntable for varying the elevation of said turntable to dispose said kerf-cutter 10 for the cutting of a kerf at the level of the floor on which the track is laid with the pivot of said cutter bar at one side of the mine track, means for holding the turntable in adjusted position relative to said truck, and self-contained power-15 operated means for operating said kerf-cutter by moving the cutter bar rectilinearly, relatively transversely in the same plane, and reversely rectilinearly to form a parallel ribbed kerf.
270. In a bottom cutting machine, the combination with an elongated chain kerf-cutter, of a truck adapted to travel on a mine track, a turntable on said truck, means applied to the turntable itself for rotating the same, mechanism for supporting said kerf-cutter on said turntable 25 above the level of the mine track, means for effecting lowering of said turntable relatively to said truck to position said kerf-cutter to cut a kerf in the plane of the mine bottom, and self-contained power-operated mechanism for operating said kerf-cutter by summing in rectilinearly, feeding arcuately, and withdrawing rectilinearly, to cut a parallel ribbed kerf along the plane of the mine bottom.
271. In a bottom and top cutting machine, the combination with a truck movable on a mine track, of a turntable thereon, means applied to the turntable itself to rotate the same, an elongated chain kerf-cutter comprising an elongated cutter bar, mechanism for adjustably supporting 35 said kerf-cutter on said turntable in position to cut a kerf in a plane above all other parts of the machine or in position to cut a kerf in a plane below all other parts of the machine, means comprising a screw below said turntable for adjusting the elevation of said turntable relative to said truck when said kerf-cutter is in a top cutting position or when it is in a bottom cutting position, and self-contained power-operated mechanism for operating said kerf-cutter when 45 50 in either top cutting position or in bottom cutting position by summing in rectilinearly, feeding arcuately, and withdrawing rectilinearly to cut a parallel ribbed kerf in either of said planes.
272. In a mining machine, the combination with a supporting frame, of means comprising wheels for mounting said frame for travel on a mine track, a supplemental frame swiveled to said supporting frame on a horizontal axis confined to a fixed elevation relative to said supporting frame, self-locking worm gearing for swiveling said supplemental frame on said horizontal axis, means for adjusting the elevation of said supporting frame and of said horizontal axis relative to said wheels, an elongated chain kerf-cutter comprising an elongated cutter bar pivoted at its rear end portion to said supplemental frame to swing on an axis permanently at right angles to the plane of said cutter bar, and self-contained power-operated mechanism comprising a rack-bar extending along the top of the machine for operating said kerf-cutter by summing in rectilinearly, feeding arcuately on said right angle axis, and withdrawing rectilinearly to cut a parallel ribbed kerf either in a horizontal plane or in a vertical plane parallel to the mine track.
273. In a combined bottom cutting and shear cutting machine, the combination with a supporting frame, of means comprising wheels for mounting said frame for travel on a mine track, a supplemental frame swiveled to said supporting frame on a horizontal axis confined to a fixed elevation relative to said supporting frame and extending longitudinally thereof parallel to the mine track, self-locking worm gearing for swiveling said supplemental frame on said horizontal axis, an elongated chain kerf-cutter comprising an elongated cutter bar pivoted at its rear end portion to said supplemental frame on an axis permanently at right angles to the plane of said cutter bar and extending transversely of said longitudinal axis to occupy either bottom cutting or shear cutting positions, means for adjusting the elevation of said supporting frame relative to said wheels and for adjusting the inclination of said kerf-cutter on another horizontal axis intersecting said horizontal axis and said right angle axis when in bottom cutting position, and self-contained power-operated mechanism for operating said kerf-cutter by summing in rectilinearly, feeding arcuately, and withdrawing rectilinearly to cut a parallel ribbed kerf either in bottom cutting position or in shear cutting position.
274. In a mining machine, the combination with a supporting frame, of means comprising wheels for mounting the same on a mine track, a supplemental frame swiveled to said supporting frame on a horizontal axis confined to an elevation relative to said supporting frame and extending longitudinally thereof parallel to the mine track, an elongated chain kerf-cutter comprising an elongated cutter bar pivoted at its rear end portion to said supplemental frame on an axis permanently at right angles to the plane of said cutter bar and extending transversely of said horizontal axis, means for rotating said supplemental frame on said horizontal axis and holding the same in adjusted position to adjust said kerf-cutter to bottom cutting or top cutting or shear cutting positions, means for adjusting the elevation of said supporting frame relatively to said wheels and for adjusting the inclination of said kerf-cutter on another horizontal axis intersecting said right angle axis when in bottom cutting or top cutting position, and self-contained power-operated mechanism, for operating said kerf-cutter by summing in rectilinearly, feeding arcuately, and withdrawing rectilinearly to cut a parallel ribbed kerf in a bottom plane or a top plane or in a shearing plane.
275. In coal mining apparatus comprising undercutting mechanism supported on and guided by a mine track extending approximately at right angles to the face of the coal to be undercut while performing its cutting operation, the combination with a wheel mounted main frame adapted to run on the mine track, of a widely expanded turntable having a diameter approximately equal to the width of said main frame, means connected to the turntable itself for rotating the same, an overhanging arm connected to said turntable to move bodily therewith when said turntable is rotated on its upright axis, an elongated chain kerf-cutter comprising an elongated cutter bar pivotally mounted on the outer end of said overhanging arm to swing horizontally in a plane above or below the level of the mine track, mechanism for adjusting the elevation of said cutter bar relative to the plane of the mine track, and a self-contained power-operated mechanism for operating said cutter bar.

tion of said turntable together with said over-hanging arm and said kerf-cutter to vary the elevation of the latter from a transportation position above the level of the mine track to a bottom cutting position at the plane of the floor on which the track is laid, power-operated means for moving the machine bodily forwardly and rearwardly on the mine track to effect feeding of the kerf-cutter during a portion of its operation, said power-operated means being adapted to operate to effect movement of the machine in opposite directions during cutting while the direction of driving of the kerf-cutter remains the same, and self-contained power-operated means for swinging said kerf-cutter laterally to cut a connecting kerf in the plane of the floor.

276. In a mining machine, the combination with a truck adapted to travel on a mine track, of a support mounted thereon to rotate horizontally relatively thereto on a vertical axis, an arm pivotally connected to said support and extending outwardly therefrom, means between said support and said arm for moving said arm on its pivot relatively to said support to vary the elevation of the outer extremity of said arm, a cutting tool swivelly connected to the outer extremity of said arm on rectangularly related axes, means for holding said cutting tool in adjusted positions on said rectangularly related axes, means for holding said support in adjusted positions on said vertical axis, the adjustments on the aforesaid axes enabling said cutting tool to be positioned at a plurality of elevations at right angles to a coal face extending transversely of the space in advance of the mine track, and means for operating said cutting tool at its adjusted elevation including longitudinal feed thereof to produce in the said face an incision having a cross-sectional area approximately equal to the cross-section dimensions of said cutting tool.

277. In a mining machine, the combination with a truck adapted to travel on a mine track, of a turntable mounted thereon for rotation relatively thereto on a vertical axis, an arm pivotally connected to said turntable for swinging movement relatively thereto on a horizontal axis, an elongated kerf-cutter comprising an elongated cutter bar, means for supporting said cutter bar on the outer end of said arm on rectangularly related axes, one of which is permanently at right angles to the cutter bar and the other of which is permanently transverse of said horizontal axis, means for effecting adjustments on each of the aforesaid axes, and motor-operated mechanism for operating said kerf-cutter in its adjusted position.

278. In a mining machine, the combination with a truck adapted to travel on a mine track, of a support mounted thereon for horizontal movement relatively thereto on a vertical axis, an arm pivoted thereto, mechanism between said support and said arm for moving the latter on its pivot to vary the elevation of the outer end of said arm, an elongated incision cutting tool, means for supporting said cutting tool at the outer end of said arm on rectangularly related axes, means for adjusting said cutting tool on said rectangularly related axes to a position in parallelism to the mine track at the various elevations of the outer end of said arm, and motor operated mechanism for operating said cutting tool including feed thereof parallel to the mine track to cut an incision at right angles to the coal face extending transversely of the space

in advance of the mine track, the cross-sectional area of such incision being approximately equal to the cross-sectional dimensions of said cutting tool.

279. In a mining machine, the combination with a supporting frame, of a tool support rotatable on a horizontal axis relatively to said frame, said axis being fixed in elevation relative to said frame, mechanism for rotating said tool support on said horizontal axis, an elongated cutting tool, means for supporting said cutting tool on the outer end of said tool support on rectangularly related axes one of which is at right angles to the plane of the kerf cut by said cutting tool and the other of which is spaced from said horizontal axis and transverse thereof, means for adjusting the cutting tool on the last-named transverse axis to move the cutting tool toward and from the axial line of the rotary support, and self-contained power-operated mechanism for driving said cutting tool and swinging the same at a feeding speed on said right angle axis. 80 85 90 95

280. In a mining machine, the combination with a supporting frame, of mechanism comprising wheels for mounting said frame for movement along a trackway, cutting mechanism comprising a pivotally mounted cutter bar having a chain cutter adapted to cut a kerf for said bar in an upright face of a mine vein when said bar is presented edgewise thereto, mechanism for supporting said cutting mechanism for bodily adjustment about a horizontal axis extending longitudinally of the trackway, said axis being permanently confined to a fixed elevation relative to said frame, means for moving said supporting mechanism about said horizontal axis selectively into different intersecting planes each parallel to said horizontal axis, and self-contained power-operated means comprising a sliding rack bar for moving said bar bodily rectilinearly of the trackway, about its pivot in the same plane, and reversely rectilinearly of the trackway to insert a parallel ribbed kerf in a face in front of the end of the trackway in any one of said selected planes. 100 105 110 115

281. In a mining machine, the combination with a supporting frame, of means comprising wheels for mounting said frame for movement along a mine track, cutting mechanism comprising a pivotally mounted cutter bar having a chain cutter adapted to cut a kerf for said bar in an upright coal face, when said bar is presented edgewise thereto, means for supporting said cutting mechanism for bodily adjustment on an axis extending longitudinally of the trackway at a permanently fixed elevation relative to said frame, mechanism for moving said supporting means bodily about said horizontal axis to adjust said cutting mechanism into different intersecting planes each parallel to said horizontal axis and spaced therefrom, means for pivoting said cutter bar to the outer end of said cutting mechanism supporting means for swinging feeding movement in its own plane, and self-contained power-operated means comprising a slidable support at the top of the machine for moving said bar bodily rectilinearly in a path extending longitudinally of the trackway, about its pivot in the same plane, and reversely rectilinearly to insert a parallel ribbed kerf in a face in front of the end of the trackway. 120 125 130 135 140

282. In a mining machine, the combination with a truck adapted to travel on a mine track, of a horizontal support mounted thereon to rotate relatively thereto on a vertical axis, an arm mounted on the outer end of said support to swing 145 150

- relatively thereto on a horizontal axis, mechanism comprising worm gearing for swinging said arm on said horizontal axis, an elongated cutting tool, means supporting said cutting tool on the outer 5 end of said arm for adjustment on rectangularly related axes, means for holding said last named supporting means in adjusted position on said rectangularly related axes, and means for operating said cutting tool including feed thereof longitudinally of itself. 10
283. In a mining machine, the combination with a truck adapted to travel on a mine track, of a turntable having a diameter approximately equal to the width of said truck and mounted on 15 the latter to rotate relatively thereto on an upright axis, means connected to the peripheral portion of said turntable to rotate the same, kerf-cutting mechanism mounted on said turntable to rotate bodily therewith including a cutter carrying head 20 rotatable on a horizontal axis and an elongated plane cutter bar pivotally mounted on said head and carrying an orbitally movable cutter chain, means for rotating said head on said horizontal axis to adjust said cutter bar into different planes, 25 and mechanism for adjusting the elevation of said turntable relative to said truck and for tilting said cutting mechanism about a horizontal transverse axis to change the elevation of the cutter bar and the angle thereof relative to the horizontal. 30
284. In a mining machine, the combination with a truck adapted to travel on a mine track, of a turntable mounted on said truck and rotatable relatively thereto on an upright axis, said 35 turntable having a diameter approximately equal to the width of said truck, of kerf-cutting mechanism carried by said turntable and including a head rotatable on a horizontal axis permanently fixed as to elevation relative to said turntable, an 40 elongated plane kerf-cutter pivotally connected to said head to swing on an axis permanently at right angles to the plane of said kerf-cutter, said kerf-cutter comprising an orbitally movable chain cutter, means for rotating said head on said horizontal axis to adjust the kerf-cutter into relative 45 high horizontal planes or relatively low horizontal planes, and holding the kerf-cutter at adjusted elevation relative to the turntable, a motor on said turntable, power-transmission mechanism extending from said motor along said horizontal axis and said right angle axis to said kerf-cutter to drive said chain cutter and swing said 50 kerf-cutter on said right angle axis, and means for adjusting the elevation of said turntable relative to said truck and for tilting said kerf-cutter on a horizontal axis extending transversely of the mine track to adjust the elevation of the kerf-cutter and the angle of its plane relative to the horizontal. 55
285. In a mining machine, the combination with a portable base, of a support swingable horizontally relatively to said base about a vertical axis, an arm swiveled to the outer end of said support to swing relatively thereto on a horizontal axis, the outer end of said arm being offset from said horizontal axis, a cutting tool swivelly mounted on the outer end of said arm to swing about rectangularly related axes, means for rotating said arm on said horizontal axis to change 60 the elevation of the outer end of said arm, means for holding said cutting tool in adjusted position on said rectangularly related axes, and means for operating said cutting tool including feed thereof. 70
286. In a mining machine, the combination 75 with a portable base, of a support swivelly mounted on said base to swing horizontally relatively thereto to position the outer end of said support at either side of said base, an arm swiveled to said support on a horizontal axis, the outer end of said arm being offset from said horizontal axis, mechanism for rotating said arm on said horizontal axis while the outer end of said arm describes a circle in a vertical plane, a cutting tool mounted on the outer end of said arm on rectangularly related axes to swing into positions in a horizontal plane spaced from said horizontal axis and either parallel to said horizontal axis or extending transversely thereof, means for holding the cutting tool in its different adjusted positions, and means for operating said cutting tool including feed thereof. 80
287. In mining apparatus, the combination with a portable base, of a horizontal support mounted on said base to swing horizontally relatively thereto, an arm pivotally mounted on the outer end of said horizontal support to swing into angularly related positions above and below the pivotal connection between said arm and said support, a cutting tool mounted on said arm for adjustment relative thereto on rectangularly related axes, means connected to said support and arm for swinging the latter about its pivot relatively to said support and for holding said arm in its different angular positions, and means for operating said cutting tool including the feed thereof. 90
288. In a mining machine, the combination with a portable base, of a horizontal support swivelly mounted on said base and overlying said base and swingable horizontally relatively to said base wherein the outer extremity thereof overhangs one side of said base, means for locking said support in adjusted position relative to said base, an arm pivotally mounted on the outer extremity of said horizontal support and extending downwardly along one side of said base at the rear of the forward end of said base, means for moving the outer end of said arm on a horizontal axis to a position above or below a horizontal plane extending through said support and holding said arm in adjusted position, a cutting tool carried at the outer end of said arm, means for adjusting the position of said cutting tool on rectangularly related axes additional to said horizontal axis, relative to said arm and holding the same in adjusted position, and means for operating said cutting tool including the feed thereof. 100
289. In a mining machine, the combination with a portable base, of a horizontal support swivelly mounted on said base and overlying said base and swingable horizontally relatively to said base into positions wherein the outer extremity thereof overlies one side of said base, means for locking said horizontal support in adjusted position relative to said base, an arm pivotally connected on a horizontal axis to the outer extremity of said horizontal support and branching outwardly and either upwardly or downwardly from a horizontal plane through said horizontal axis, means for moving said outwardly branching arm on said horizontal axis to position the outer end of said arm either above or below such horizontal plane, a cutting tool, means for mounting said cutting tool on said arm for adjustment relative to said horizontal support on rectangularly related axes additional to said horizontal axis, means for holding said cutting tool in adjusted position on such rectangularly related axes, said cutting 110

- 150

tool after adjustment on the horizontal axis and on the rectangularly related axes being held rigidly connected to said horizontal support, and means for operating said cutting tool including feed thereof.

290. In a mining machine, the combination with a supporting frame movable along a track-way, of a neck rotatable on a horizontal axis, means for rotating said neck and holding the same in adjusted position, an elongated cutting tool, mechanism for supporting said tool on the outer extremity of said neck for rotation on rectangularly related axes one of which is permanently at right angles to the plane of the kerf cut by said cutting tool, mechanism for moving said cutting tool on the other of said rectangularly related axes to move the cutting tool toward and from the axial line of said rotatable neck, and self-contained power-operated mechanism for driving said cutting tool and swinging the same on said right angle axis.

291. In a mining machine, the combination with a wheel-mounted frame adapted to travel on a mine track, of a neck mounted on said frame to rotate on a horizontal axis relatively thereto and branching outwardly and away from said horizontal axis, an elongated kerf-cutter, means for mounting said kerf-cutter on the outer extremity of said neck for movement relatively thereto on rectangularly related axes one of which is permanently at right angles to the plane of the kerf cut by said kerf-cutter, mechanism for moving said kerf-cutter on the other of said rectangularly related axes toward and from the axial line of the neck, and self-contained power-operated mechanism extending through said neck to said kerf-cutter to drive the same and swing the kerf-cutter on its right angle axis.

292. In a mining machine, the combination with a portable base, of a horizontal support mounted on said base and overlying said base and swingable horizontally relatively to said base into positions wherein the outer extremity thereof overhangs the sides of said base, an arm pivotally mounted on a horizontal axis, on the outer extremity of said support and branching downwardly and outwardly from said support, a cutting tool swivelly mounted on the outer extremity of said arm to swing relatively to said support about rectangularly related axes additional to said horizontal axis, and mechanism for operating said cutting tool including the feed thereof.

293. In a mining machine, the combination with a portable base, of a horizontal support swivelly mounted on said base and overlying said base and swingable horizontally relatively to said base into positions wherein the outer extremity thereof overhangs the sides of said base, an arm pivotally mounted on a horizontal axis, on the outer extremity of said support and branching outwardly and downwardly from said support along either side of said base at the rear of the forward end of said base, an elongated cutting tool swivelled on the outer extremity of said arm to swing about rectangularly related axes additional to said horizontal axis, and means for operating said cutting tool including feed thereof.

294. In a mining machine, the combination with a supporting frame, of a tool support rotatable relatively to said frame on a horizontal axis, means for rotating said support on said horizontal axis and holding the same in adjusted position, an elongated chain kerf-cutter comprising an elongated cutter bar, members sup-

porting said cutter bar on said support for movement transversely of its plane toward and from the axial line of said support and for swinging movement in its own plane on an axis permanently at right angles to the plane of said cutter bar, means for moving the cutter bar transversely of its plane toward and from said axial line on a pivot intersecting said right angle axis and holding the same in adjusted position during cutting, motor operated mechanism for driving said kerf-cutter and for swinging the same on its right angle axis, and operator controlled mechanism for effecting reversal of the swing of said cutter bar on its right angle axis.

295. In a mining machine, the combination with a supporting frame, of a tool support rotatable on a horizontal axis relatively to said frame, means for rotating said support on said horizontal axis and holding the same in adjusted position relative to said frame, an elongated chain kerf-cutter comprising an elongated cutter bar, members supporting said cutter bar for movement toward and from the axial line of said support and for swinging on an axis permanently at right angles to the plane of said cutter bar, means comprising self-locking gearing for moving said kerf-cutter toward and from said axial line on an axis extending transversely of both of the aforesaid axes and holding the same in adjusted position, motor operated mechanism for swinging said cutter bar on its right angle axis, and operator controlled mechanism adjacent to said kerf-cutter for reversing the direction of swinging movement of said cutter bar on said right angle axis.

296. In a mining machine, the combination with a portable base, of a horizontal supporting structure overlying said base and swingable horizontally relatively to said base into positions wherein the outer extremity thereof overhangs the sides of said base, the outer extremity of said supporting structure being swingable relatively to said base to various elevations, an elongated cutting tool mounted on the outer extremity of said supporting structure, for adjustment on rectangularly related axes located on the outer end of such structure, said supporting structure being adjustable to position said cutting tool in relatively low planes along either side of the base and below the top of the base and in relatively high planes above the top of the base to cut kerfs in relatively low planes and in relatively high planes, and motor operated mechanism for operating said kerf-cutter including feed thereof in any of its adjusted positions.

297. In a mining machine, the combination with a portable support, of a rotatable neck mounted on said support for rotation relatively thereto on a horizontal axis, a plane kerf-cutter, means for supporting said kerf-cutter solely on said neck at all times for pivotal movement in its own plane on an axis permanently at right angles to said kerf-cutter and for bodily movement with said right angle axis toward and from the axis of said neck while the neck axis remains stationary, means for rotating said neck on the neck axis and holding said neck in adjusted position relative to said portable support, means for moving said kerf-cutter together with its right angle axis bodily toward and from the neck axis while supported above ground by said neck and for holding the kerf-cutter in the plane to which it has been adjusted, and motor operated power-transmission mechanism extending along said neck axis and along said neck to said kerf-cutter.

to drive the same and to feed the same in its own plane on said right angle axis.

298. In a mining machine, the combination with a truck adapted to travel along a trackway, of a turntable mounted on said truck to rotate relatively thereto on a vertical axis, a motor carried by said turntable, means for adjusting the elevation of the turntable relative to the truck, a horizontal support swiveled to said turntable on a horizontal axis, a cutter head pivoted to the outer end of said horizontal support on an axis intersecting the said horizontal axis, an elongated chain kerf-cutter comprising an elongated cutter bar pivoted to said head to swing relatively thereto on an axis at right angles to said second named axis and intersecting said horizontal axis, means for rotating said turntable and holding the same in adjusted position, means for rotating said horizontal support and holding the same in adjusted position, means for adjusting said head on said second named axis and hold the same in adjusted position, and power-transmission mechanism between said motor and said kerf-cutter to operate the latter including swinging feeding movement thereof on its right angle axis.

299. In mining apparatus, the combination with a portable base, of a support swivelly mounted on said base to swing horizontally relatively thereto about a vertical axis, an arm structure swivelly mounted on the outer end of said support to swing relatively thereto on a horizontal axis, an elongated cutting tool mounted on the outer end of said arm structure to swing on another horizontal axis, means for swinging said arm structure on said first-named horizontal axis and holding the same in adjusted position in either relatively high or relatively low planes, means for adjusting said cutting tool on said other horizontal axis and holding the same in adjusted position, said adjustments enabling said cutting tool to be located in any one of various parallel positions at various elevations, and means for operating said cutting tool including feed thereof rectilinearly and longitudinally of itself in any one of said parallel positions to insert parallel elongated incisions in the mine vein.

300. In a mining machine, the combination with a truck adapted to travel on a mine track, of a supporting frame mounted thereon to rotate relatively thereto on a vertical axis, an elongated kerf-cutter, means for mounting said kerf-cutter on said frame to swing in a vertical plane on a horizontal axis permanently at right angles to the plane of said kerf-cutter and for adjustment on a vertical axis spaced horizontally from the vertical axis of said supporting frame, means for rotating said supporting frame relatively to said truck on said first named vertical axis and holding said frame in adjusted position, means for adjusting the kerf-cutter on said second named vertical axis to adjust the kerf-cutter to a vertical plane parallel to the mine track and parallel to the ribs of the mine entry through a wide range of angular positions of said supporting frame relative to said truck, and motor operated mechanism for effecting rectilinear sumping feeding movement of said kerf-cutter in its adjusted position for effecting swinging feeding movement of the kerf-cutter in the same plane and for effecting rectilinear withdrawal feeding movement of the kerf-cutter to produce a vertical parallel ribbed kerf of adjusted height.

301. In a mining machine, the combination with a portable support, of a frame thereon, a head rotatable on a horizontal axis, relatively to said

frame, an elongated cutting tool mounted on the outer end of said head for adjustment relative thereto on rectangularly related axes one of which is always at right angles to plane of the kerf-cut of said cutting tool and the other is always at right angles to said horizontal axis, means for rotating the head on its horizontal axis and adjusting the cutting tool on the axis at right angles to said horizontal axis, and motor operated mechanism for operating said cutting tool including swinging feeding movement on its right angle axis.

302. In a mining machine, the combination with a wheeled frame adapted to travel on a mine track, of a support swiveled thereon for rotation on an axis extending longitudinally of the machine and confined against change in elevation relative to said frame, means comprising self-locking worm gearing for rotating said support on said axis and holding the latter locked in adjusted position, an elongated chain kerf-cutter pivoted to said support to swing relatively thereto on an axis at right angles to said longitudinal axis and at right angles to the plane of said kerf-cutter, means comprising self-locking worm gearing for swinging said kerf-cutter on its pivot and locking the same at an adjusted angle, and self-contained power operated mechanism comprising a slideable elongated bar for feeding said kerf-cutter rectilinearly relatively to the mine track while said kerf-cutter is locked at an adjusted angle and while said support is locked against turning on said longitudinal axis, for swinging said kerf-cutter on its right angle axis in the same plane and for reversely feeding said kerf-cutter rectilinearly in the same plane to cut a parallel ribbed kerf having a width in accordance with the angular adjustments of said kerf-cutter when fed rectilinearly.

303. In a mining machine, the combination with a portable base, of a frame mounted thereon to rotate relatively thereto on a vertical axis, a turnover head mounted on said frame to rotate on a horizontal axis, means for turning said head over on said horizontal axis to invert said head and hold the latter in its inverted position, an elongated chain kerf-cutter comprising an elongated cutter bar, means for supporting said kerf-cutter on said head to swing relatively thereto on an axis at right angles to said cutter bar, motor operated mechanism for operating said kerf-cutter including swinging feeding movement thereof on its right angle axis to cut a plane kerf in the face of the mine vein, and means for feeding said kerf-cutter longitudinally of itself relatively to said frame after said head has been turned over to insert a narrow kerf in the mine vein spaced from said plane kerf.

304. In a mining machine, the combination with a truck adapted to travel on a mining track, of a turntable thereon for rotation relatively thereto on a vertical axis, means for rotating said turntable and holding the same in adjusted position relative to said truck, a guide frame mounted on said turntable to rotate bodily therewith, a supplemental frame movable along said guideway radially of said turntable, an elongated chain kerf-cutter comprising an elongated cutter bar, means for pivotally mounting said kerf-cutter on said supplemental frame for movement relatively thereto on angularly related axes one of which is horizontal and radial of said turntable axis and the other of which is at right angles to the plane of said cutter bar, operator controlled power actuated transmission mecha-

- nism for swinging said kerf-cutter on its right angle axis and holding the same in adjusted position, means for turning said kerf-cutter over on said horizontal axis and holding the same in 5 adjusted position, and operator controlled power actuated mechanism for effecting rectilinear movement of said supplemental frame along said guide frame radially of said turntable axis while said kerf-cutter is locked in parallelism to the 10 path of said supplemental frame to insert a narrow kerf in the face of the mine vein spaced from the kerf cut by the swinging of the kerf-cutter before being turned over.
305. In a mining machine, the combination 15 with a guide frame, of a supporting frame movable rectilinearly along said guide frame, an elongated chain kerf-cutter comprising an elongated cutter bar, means for mounting said kerf-cutter on said frame to move on an axis at right 20 angles to said cutter bar, motor operated mechanism comprising interlocking gearing for swinging said kerf-cutter in its right angle axis, and alternatively operable clutches for controlling said motor operating mechanism to swing said 25 kerf-cutter in either direction.
306. In a mining machine, the combination 30 with a wheeled truck movable along a trackway, of a frame mounted thereon for adjustment angularly relative thereto on a vertical axis, means for rotating said frame on such upright axis and holding the same in adjusted position, an elongated chain kerf-cutter comprising an elongated cutter bar pivotally connected to said frame on a vertical axis spaced horizontally from 35 said first named vertical axis, operator controlled power operated mechanism for swinging said kerf-cutter on said second named vertical axis in either direction and locking the kerf-cutter in adjusted angular relation to said frame, means 40 for lowering the kerf-cutter from a plane above the level of the mine track to the mine bottom at one side of the mine track in a narrow space between the track and the adjacent rib while said kerf-cutter is supported solely by said frame and 45 independently of the mine bottom, and operator controlled motor operated mechanism for feeding the kerf-cutter rectilinearly relatively to said truck while the latter is stationary on the mine track.
307. In a mining machine, the combination 50 with a portable support, of a frame mounted thereon for adjustment relatively thereto on an upright axis, a head swiveled to said frame on a horizontal axis, means for adjusting said head on said horizontal axis and holding the same in adjusted position, an elongated kerf-cutter comprising an elongated cutter bar, means for mounting said kerf-cutter on the outer end of said head on rectangularly related axes one of 55 which is at right angles to said cutter bar and the other of which is offset from the axial line of said head and transverse thereto, means for adjusting the kerf-cutter on said transverse axis relative to said head and holding the same in adjusted position, and operator controlled power operated mechanism for driving said kerf-cutter and swinging the same on its right angle axis.
308. In a mining machine, the combination 60 with a truck adapted to travel on a mine track, of a turntable mounted thereon, means for adjusting said turntable on a vertical axis and holding the same in adjusted position relative to said truck, a supporting structure mounted on said turntable to move radially and rectilinearly relatively thereto, a head mounted on said supporting 65 structure for inversion on a horizontal axis, mechanism for inverting said head and holding the same in adjusted position, an elongated kerf-cutter comprising an elongated cutter bar pivoted to the outer end of said head on a vertical axis permanently at right angles to said cutter bar, and self-contained power operated mechanism for operating said kerf-cutter to produce a bottom kerf in a horizontal plane by summing said kerf-cutter rectilinearly, swinging the same arcuately and withdrawing the same rectilinearly when said kerf-cutter is in its lower horizontal position and for producing a plurality of horizontally spaced apart radial kerfs above the bottom kerf when the said head is inverted, by summing said kerf-cutter rectilinearly longitudinally of itself and withdrawing longitudinally in a plurality of positions in the mine vein.
309. In a mining machine, the combination 70 with a main frame, of a guide frame mounted on said main frame for adjustment relatively thereto along rectilinear lines, a carrier frame guided along said guide frame rectilinearly transversely of the path of adjustment of said guide frame on said main frame, an elongated chain kerf-cutter comprising an elongated cutter bar pivotally connected to said carrier frame to swing relatively thereto on a horizontal axis at right angles to the plane of said cutter bar, self-contained power operated mechanism for operating 75 said kerf-cutter to cut a vertical kerf by effecting reciprocation of said carrier frame rectilinearly along said guide frame and swinging of said kerf-cutter arcuately on its right angle axis while said frames are stationary, and means for adjusting said carrier frame along said main frame to enable said kerf-cutter to cut kerfs in many parallel vertical planes.
310. In a mining machine, the combination 80 with a truck adapted to travel on a mine track, of a main guide frame mounted thereon, an auxiliary guide frame adjustable rectilinearly along said main frame transversely of the mine track, a carrier frame movable along said auxiliary frame rectilinearly parallel to the mine track, an elongated chain kerf-cutter comprising an elongated cutter bar pivotally connected to said carrier frame to swing on a horizontal axis at right angles to said cutter bar, means for moving said auxiliary guide frame and said kerf-cutter along 85 said main frame transversely of the mine track to adjust said kerf-cutter to any one of several shear-cutting positions in vertical planes parallel to the mine track, and self-contained power operated mechanism for operating the kerf-cutter 90 in any one of its adjusted positions to cut a parallel ribbed kerf by moving said carrier frame outwardly to sum the kerf-cutter, swing the kerf-cutter on its right angle axis and return the carrier frame to effect the withdrawal cut.
311. In a mining machine, the combination 95 with a portable base, of a head swiveled thereto on a horizontal axis, an elongated kerf-cutter comprising an elongated cutter bar, means for mounting said kerf-cutter on said head for adjustment 100 relative thereto on rectangularly related axes one of which is offset from said horizontal axis and at right angles thereto and the other of which is at right angles to said cutter bar, means for adjusting said kerf-cutter on said three axes to 105 position the kerf-cutter in spaced apart vertical planes one of which is adjacent to said horizontal axis and the other of which is spaced therefrom, and means for adjusting said head into a plurality of positions in a horizontal plane to in- 110

- crease the latitude of adjustment of said kerf-cutter from any of the aforesaid vertical planes. 312. In a track mounted mining machine, the combination with a truck adapted to travel on a mine track, of a turntable pivotally mounted thereon to rotate on an upright axis, means for holding said turntable in adjusted angular position relative to said truck, a unitary mining machine comprising an elongated chain kerf-cutter pivoted to swing on an upright axis spaced horizontally from said first named upright axis, means for holding said kerf-cutter in adjusted position on said second named upright axis, and means for adjusting the elevation of said unitary mining machine relative to said truck, said unitary mining machine comprising means to drive said kerf-cutter and a flexible draft element connected to an anchorage extraneous to the unitary mining machine to effect rectilinear feeding of said kerf-cutter. 313. In a track mounted mining machine, the combination with a truck adapted to travel on a mine track, of a turntable mounted thereon for adjustment relative thereto on an upright axis, means for holding said turntable in adjusted position relative to said truck, a unitary mining machine mounted on said turntable to move bodily therewith, said mining machine comprising an elongated chain kerf-cutter including a pivoted elongated cutter bar and winding mechanism with a rope connected thereto and wound thereon and adapted to have its free end connected to an anchorage extraneous to said mining machine, and means for holding said kerf-cutter in adjusted position on the pivot of said cutter bar while said mining machine is operating to drive said kerf-cutter and feed the same. 314. In a mining machine, the combination with a truck adapted to move above a mine track, of a widely expanded turntable having a diameter approximately equal to the width of said truck, an elongated chain kerf-cutter mounted on said turntable and comprising an elongated cutter bar rigidly connected to said turntable to move bodily therewith and extending radially outwardly therefrom, an electric motor carried by said turntable, driving connections between said motor and said chain kerf-cutter, means for swinging the turntable together with said kerf-cutter on a vertical axis rearwardly of the front end of said truck and midway between the sides of said truck and locking said turntable in adjusted angular position with the cutter bar rigidly connected thereto and occupying an acute angle relative to the mine track, means for adjusting the elevation of said turntable relative to the truck and the inclination of said kerf-cutter on a horizontal axis along arcuate lines extending transversely of the plane of the cutter bar, mechanism for mounting said kerf-cutter including said cutter bar for rotation through 180° on a horizontal axis relatively to said turntable to invert the kerf-cutter and change the elevation thereof relative to the truck and holding the kerf-cutter in adjusted position, said horizontal axis being fixed relative to said turntable, and operator-controlled power-operated mechanism for moving the whole machine along the mine track at a feeding speed to effect rectilinear feed of said kerf-cutter while said turntable is locked to said truck and while said kerf-cutter is held rigidly connected to said turntable in adjusted position. 315. In a mining apparatus, the combination with a wheeled truck, of a machine frame mounted thereon and having a cutter bar thereon swingable relative thereto in a vertical plane, a driving motor carried by said machine frame, and means driven by said motor for swinging said bar about its pivot in opposite directions comprising selectively operable reversing clutches. 316. In mining apparatus, the combination with a wheeled truck, of a supporting frame therefor, kerf-cutting mechanism comprising a cutter bar pivoted to said frame to swing in a vertical plane, a driving motor carried by said frame, means driven by said motor for swinging said bar about its pivot in opposite directions comprising relatively rotating elements, and selectively operable mechanism for controlling rotation of said elements. 317. In mining apparatus, the combination with a wheeled truck having a horizontally extending guiding frame thereon, of cutting mechanism slidably mounted on said guiding frame and including an elongated cutter bar mounted for swinging movement in a vertical plane relatively to said guiding frame to cut a vertical kerf and a driving motor for said cutting mechanism, feeding mechanism driven by said motor for sliding said cutting mechanism bodily in a longitudinal direction relatively to said guiding frame during the cutting operation and including co-acting relatively rotatable mechanically engaged feeding elements, mechanism driven by said motor for swinging the cutter bar relatively to said guiding frame, and mechanism driven by said motor for propelling the truck. 318. In a mining machine, the combination with a truck adapted to travel on a mine track, of a supporting frame mounted thereon to rotate relatively thereto on a vertical axis, an elongated kerf-cutter, means for mounting said kerf-cutter on said frame to swing in a vertical plane on a horizontal axis permanently at right angles to the plane of said kerf-cutter and for adjustment on a vertical axis of said supporting frame, means for rotating said supporting frame relatively to said truck on said vertical axis and holding said frame in adjusted position, means for adjusting the kerf-cutter on said second-named vertical axis to adjust such kerf-cutter to a vertical plane parallel to the mine track and parallel to the ribs of the mine entry irrespective of the angular position of said supporting frame relative to said truck through a range of 90° from either side of the medial line of the machine, and motor operated mechanism for effecting rectilinear sumping feeding movement of the kerf-cutter in its adjusted position and for effecting swinging feeding movement of the kerf-cutter in the same plane and for effecting rectilinear withdrawal feeding movement of the kerf-cutter to produce vertical parallel ribbed kerfs of various heights in any vertical plane between the ribs of the mine entry in the face extending across the space in advance of the mine track. 319. In a mining machine, the combination with a truck adapted to travel on a mine track, of a supporting frame mounted thereon to rotate relatively thereto on a vertical axis, a head swiveled to said frame on a horizontal axis, an elongated chain-kerf-cutter, mechanism for supporting said kerf-cutter on said head on rectangularly related axes one of which is vertical and the other of which is horizontal and permanently at right angles to the vertical plane of said kerf-cutter, mechanism for swiveling said head on its horizontal axis to invert said kerf-cutter from one vertical position to another, means for rotating said frame relatively to said truck on said first- 140 145 150

- named vertical axis and holding said frame in adjusted position relative to said truck, means for rotating said kerf-cutter on said second named vertical axis to adjust said kerf-cutter into parallelism with the mine track and the ribs of the mine entry, and motor operated mechanism for sumping said kerf-cutter rectilinearly parallel to the mine track, feeding the same arcuately on said horizontal axis, and withdrawing the kerf-cutter rectilinearly to insert a parallel ribbed kerf in the face of the mine vein extending across the space in advance of the mine track, the aforesaid adjustments being such as to enable vertical kerfs of various heights to be cut in any plane at right angles to said face and at any place across the face between the ribs of the mine entry.
320. In a mining machine, the combination with a portable base frame, of a supporting frame mounted thereon for arcuate adjustment relatively thereto on a vertical axis, mechanism for effecting such arcuate adjustment and for holding said supporting frame in adjusted position relative to said base frame, a turnover head swiveled to said supporting frame on a horizontal axis, an elongated chain kerf-cutter comprising an elongated cutter bar, mechanism for mounting said kerf-cutter on the outer end of said head on rectangularly related axes one of which is horizontal and permanently at right angles to said cutter bar and the other of which is vertical in transverse relation to said first-named horizontal axis and spaced therefrom, said last-named vertical axis being parallel to said first-named vertical axis and horizontally spaced therefrom, means for swinging said kerf-cutter on the spaced vertical axis and hold the same in adjusted position in parallelism to the ribs of the mine entry, mechanism for turning the head over to invert said kerf-cutter and extend the reach from the opposite side of the mine track, and motor operated mechanism for operating said kerf-cutter by sumping in rectilinearly, swinging arcuately and withdrawing rectilinearly to insert a parallel ribbed kerf in the face extending across the space in advance of the mine track.
321. In a mining machine, the combination with a portable base frame, of a supporting frame mounted thereon for arcuate adjustment relative thereto on a vertical axis, of means for effecting such arcuate adjustment and the holding of said supporting frame in adjusted position relative to said base frame, a turnover head swiveled to said supporting frame on a horizontal axis, means for turning over said head to invert the same, an elongated chain kerf-cutter comprising an elongated cutter bar, mechanism for mounting said kerf-cutter on the outer end of said head to swing relatively thereto on rectangularly related axes one of which is horizontal and permanently at right angles to said cutter bar and the other of which is vertical and offset from the horizontal axis of said head and spaced horizontally from the vertical axis of said supporting frame, and motor operated mechanism for operating said kerf-cutter including rectilinear sumping feed thereof, swinging feed thereof on said right angle axis and rectilinear withdrawal feed to insert a parallel ribbed kerf in the mine vein.
322. In mining apparatus, the combination with a wheeled truck having a guiding frame, of a machine frame slidably mounted thereon and having a cutter bar thereon mounted for swinging movement relatively thereto in a vertical plane, a driving motor carried by said machine frame,

means driven by said motor for moving said machine frame relatively to said guiding frame to effect rectilinear movement of said cutter bar during cutting, and means driven by said motor for propelling the truck.

323. In mining apparatus, the combination with a wheeled truck, of a machine frame mounted thereon having a cutter bar thereon swingable relative thereto in a vertical plane, a driving motor carried by said machine frame, and means driven by said motor for swinging said bar in its plane and for propelling the truck comprising relatively rotatable truck driving and bar swinging shafts, and constantly operative positive operating connections between said bar swinging shaft and said cutter bar.

324. In mining apparatus, the combination with a wheeled truck adapted to move along a mine track, of a frame mounted on said truck to slide rectilinearly along the same, an elongated chain kerf-cutter comprising an elongated cutter bar and an endless chain cutter thereon, means for pivotally connecting said cutter bar to said frame to swing on an axis permanently at right angles to said cutter bar, means for swinging said cutter bar on said right angle axis and locking the same at an acute angle relative to the mine track, a motor, means operated by said motor for driving said endless chain cutter continuously in the same direction, and operator-controlled motor-operated mechanism for effecting sumping and withdrawal rectilinear feeding movements of said kerf-cutter without changing the direction of the driving of said chain cutter.

325. In mining apparatus, the combination with a wheeled truck, having a guiding frame thereon, of cutting mechanism slidably mounted on said guiding frame and including a cutter bar mounted for angular movement in a vertical plane relatively to said guiding frame to cut a vertical kerf, a driving motor for said cutting mechanism, means for sliding said cutting mechanism bodily in a longitudinal direction relatively to said guiding frame during cutting while said bar remains at a fixed angle relative to said guiding frame, and means driven by said motor for moving said cutter bar angularly in its plane and for propelling the truck, said bar swinging mechanism including mechanically interlocking elements having relative movement to effect swinging of the cutter bar.

326. In mining apparatus, the combination with a wheeled truck having a horizontally extending guiding frame thereon, of cutting mechanism slidably mounted on said guiding frame and including an elongated cutter bar mounted for swinging movement in a vertical plane relatively to said guiding frame to cut a vertical kerf, a driving motor for said cutting mechanism, feeding mechanism driven by said motor for sliding said cutting mechanism bodily in a longitudinal direction relatively to said guiding frame during the cutting operation and including co-acting relatively rotatable mechanically engaged feeding elements, and mechanism driven by said motor for propelling the truck.

327. In mining apparatus, the combination with a wheeled support adapted to run along a track-way, of a longitudinally extending guiding frame mounted on said support and swingable horizontally laterally relatively thereto, cutting mechanism mounted on said guiding frame and slidably longitudinally relatively thereto and including a cutter bar swingable in a vertical plane relatively to said guiding frame, a driving motor, feeding

- mechanism driven by said motor for sliding said cutting mechanism bodily in a longitudinal direction relatively to said guiding frame and including mechanically interlocking elements having relative movement to effect feed, and mechanism driven by said motor for swinging said cutter bar relatively to said guiding frame and for propelling said truck. 5
328. In mining apparatus, the combination with a portable support having a horizontally extending guideway thereon, of cutting mechanism slidably mounted on said guideway including an elongated cutter bit carrying cutter bar swingable in a vertical plane relatively to said guideway to cut a vertical kerf, mechanism for effecting sliding movement of said cutting mechanism along said guideway including a rotatable power driving winding element disposed on a vertical axis and carried by and movable with said support, and a co-operating flexible feeding element extending from said winding element to an anchorage to effect feed. 10
329. In a mining machine, the combination with a wheeled truck adapted to move along a mine track, of a frame guided along said truck, cutting mechanism mounted on said frame to move bodily therewith along said truck, said cutting mechanism comprising an elongated pivoted cutter bar with an endless chain cutter traveling thereon, a motor, and operator-controlled mechanism driven by said motor for moving said frame along said truck to sump the cutting mechanism rectilinearly, feed the cutter bar on its pivot in the same plane, and retract the frame along the truck rectilinearly to effect a withdrawal cut and complete a parallel ribbed kerf, said motor operated mechanism comprising reversing means to effect driving of the chain cutter in the same direction during such feeding movements. 15
330. In a mining machine, the combination with a truck adapted to travel on a mine track, of a guide frame mounted on said truck for angular adjustment relative thereto on an upright axis, an elongated chain kerf-cutter, means for supporting said kerf-cutter for swinging feeding movement in a vertical plane on a horizontal axis, and for rectilinear movement relatively to said guide frame horizontally and rectilinearly, a motor on said guide frame, power-transmission mechanism between said motor and said chain kerf-cutter for driving the latter, mechanism for effecting reciprocation of said kerf-cutter rectilinearly while said kerf-cutter continues to be driven in the same direction, and means for effecting reversal of swinging movement of said kerf-cutter in a vertical plane on said horizontal axis while said kerf-cutter continues to be driven in the same direction. 20
331. In a mining machine, the combination with a wheeled truck adapted to travel along a mine track, of a kerf-cutter, means for supporting said kerf-cutter on said truck for adjustment to a position wholly outside of the track and in horizontal planes below the top of the trackway to cut a horizontal kerf at the level of the mine bottom outside and below the level of the track or to cut a vertical kerf extending parallel to the trackway and midway between the sides of the machine, means for adjusting said kerf-cutter into the aforesaid positions, and mechanism for operating the kerf-cutter in its adjusted positions. 25
332. In a mining machine, the combination with a wheeled truck adapted to travel along a mine track, of a pivoted kerf-cutter, adjustable supporting means between the truck and said pivoted kerf-cutter for positioning the latter wholly outside the mine track and in horizontal planes below the top of the track to cut a horizontal kerf at the level of the mine bottom outside and below the level of the mine track, to cut a vertical kerf extending parallel to the track rails and midway between the track rails, or a horizontal kerf at the level of the mine roof, means for adjusting the kerf-cutter into the aforesaid positions, and motor actuated mechanism for operating the kerf-cutter in its adjusted positions. 30
333. In a mining machine, the combination with a wheeled truck adapted to travel along a mine trackway, of kerf-cutting mechanism supported by said truck including a pivoted kerf-cutter and adjustable supporting means for said kerf-cutter for positioning the latter wholly outside the trackway and in horizontal planes below the top of the trackway to make a horizontal cut at the level of the mine bottom outside and below the level of the mine trackway, or to make a vertical cut extending in the direction of the trackway and midway between the sides of the machine, means for adjusting said kerf-cutter into the aforesaid positions, motor operated mechanism for swinging said kerf-cutter about its pivot, and motor operated mechanism for propelling the machine along the trackway to effect sumping and withdrawal movements of said kerf-cutter. 35
334. In a mining machine, the combination with a wheeled truck adapted to run along a mine trackway, of a support mounted on said truck for adjustment horizontally relative thereto about a vertical axis and including supporting means, an elongated kerf-cutter hinged to said supporting means to permit movement of said kerf-cutter bodily along lines transversely of itself, means for effecting adjustment of said kerf-cutter in parallelism between planes extending through the boundaries of said truck, and motor operated mechanism arranged in operative relation to said kerf-cutter to drive the latter. 40
335. In a mining machine, the combination with a wheeled truck adapted to move along a mine trackway, of a horizontal turntable on said truck, a neck seated on said turntable for rotation relatively thereto on a horizontal axis, a kerf-cutter, a motor, power-transmission mechanism between said motor and said kerf-cutter, adjustable supporting means for plurally articulating said kerf-cutter to said neck, and motor operated mechanism for effecting rectilinear feed of said kerf-cutter. 45
336. In a mining machine, the combination with a wheeled truck adapted to move along a mine trackway, of an elongated chain kerf-cutter comprising an elongated cutter bar, mechanism for adjustably supporting said kerf-cutter on said truck for moving said kerf-cutter to position the same wholly outside the trackway to cut a kerf at the level of the mine floor outside and below the level of the mine trackway and to position said kerf-cutter into different horizontal planes relative to the truck including horizontal planes extending through the body of the machine and horizontal planes above the body of the machine and to position the kerf-cutter to vertical parallel shearing planes extending along both sides of the truck outside of the boundaries thereof and also through the body of the machine including a vertical plane extending longitudinally and 50

- midway between the sides of the truck, and motor operated mechanism for operating said kerf-cutter in the aforesaid positions including rectilinear and arcuate feeding thereof.
- 5 337. In a mining machine, the combination with a wheeled support adapted to move along a mine trackway, of kerf-cutting mechanism on said support including a pivoted kerf-cutter and adjustable supporting means for said kerf-cutter
- 10 for positioning the latter into different parallel horizontal planes between the mine bottom and the mine roof including horizontal planes below the machine body and above the machine body and through the body of the machine and includ-
- 15 ing a support rotatable about a horizontal axis to adjust said kerf-cutter into parallel vertical cutting positions anywhere between the ribs of the mine entry including a vertical cutting position midway between the track rails and extend-
- 20 ing parallel to the latter, said adjustable supporting means also including means for positioning the kerf-cutter wholly outside the trackway to cut a horizontal kerf at the level of the mine bottom outside and below the level of the mine
- 25 trackway, and motor operated mechanism for operating said kerf-cutter including feed thereof in adjusted position. 80
338. In mining apparatus, the combination with supporting means movable along a track- 85
- 30 way, of an elongated kerf-cutter mounted on said supporting means and comprising a pivotally mounted elongated cutter bar having an endless chain cutter thereon adapted to cut an up- 90
- 35 right kerf for said bar in a mine face when said bar is presented edgewise thereto, and operator- 95
- 40 controlled self-contained power-operated means comprising an elongated bar guided for sliding movement through said supporting means for feeding said kerf-cutter bodily rectilinearly relative to the trackway, about its pivot in the same 100
- 45 plane, and reversely rectilinearly, to insert such an upright kerf in said mine face, said kerf-cutter being adjustable to various positions inclined upwardly or downwardly relative to the horizontal 105
- 50 and automatically locked in such adjusted positions while being fed rectilinearly to extend the kerf from the roof to the floor of the mine chamber. 110
339. In a mining machine, the combination with a wheeled truck movable along a trackway, 115
- 55 of elongated chain kerf-cutting mechanism includ- 120
- 60 ing a pivotally mounted elongated cutter-bar disposable in fixed relation at acute angles to the trackway with the upper outer edge of said kerf- 125
- 65 cutter at various heights to reach the roof of the mine chamber spaced above all other parts of the machine, and operator-controlled self- 130
- 70 contained power-operated means comprising an elongated bar guided through the upper part of the machine and supported solely on said truck for moving the elongated cutter bar when so disposed in an upright plane rectilinearly relative to the trackway, relatively transversely in the same upright plane, and reversely rectilinearly 135
- 75 to form a shearing kerf of a depth substantially equal to the effective length of said bar and of a height equal to the height of the roof from the floor of the mine chamber. 140
340. In a mining machine, the combination with supporting means movable along a track- 145
- 80 way, of cutting mechanism thereon comprising an elongated cutter bar with an endless chain cutter thereon adapted to cut an upright kerf for said bar when said chain cutter is presented edgewise to a mine face, means for adjusting the
- cutting mechanism on a horizontal axis for the cutting of either horizontal underkerfs or horizontal overkerfs or upright shearing kerfs on either side of the machine, means for adjusting the cutter bar to various distances from such horizontal axis and to upright and horizontal planes parallel to said horizontal axis when the cutter bar is at such varying distances from the horizontal axis, and operator-controlled self-contained power-operated means for feeding said chain cutter rectilinearly of the trackway, about its pivot in the same plane, and reversely rectilinearly of the trackway when the chain cutter is in either under-cutting or over-cutting or shear cutting position to insert parallel ribbed kerfs in said mine face in accordance with the adjusted position of the cutter mechanism. 150
341. In mining apparatus, the combination with a wheeled truck movable along a trackway, of cutting means mounted on said truck and comprising a motor connected to and carrying a pivoted elongated cutter bar with an endless chain cutter thereon, means for bodily adjusting the cutter bar and motor about a horizontal axis extending longitudinally of the trackway and intermediate the sides thereof to enable said chain cutter to cut in either horizontal or upright planes, and operator-controlled self-contained power-operated mechanism supported solely by said truck for feeding the chain cutter rectilinearly relative to the trackway with its outer extremity in a plane parallel to the trackway and outside of the boundaries of the machine whether the cutter bar is horizontal or upright, for feeding the chain cutter angularly relative to the trackway to a 110 position where the outer extremity of said cutter bar is in a parallel plane also outside of the boundaries of the machine whether the cutter bar is horizontal or upright, and for feeding the chain cutter reversely rectilinearly relative to the track- 115
- 120 way to effect the cutting of a parallel ribbed kerf the ribs of which extend in parallel planes parallel to the trackway and both entirely outside of the boundaries of the machine whether the cutter bar is horizontal or upright. 120
342. In a track-mounted mining machine, the combination with a wheeled truck adapted to travel along a trackway, of a turntable mounted on said truck to rotate relatively thereto on a vertical axis and having a projecting portion adapted to project outwardly beyond the sides of the trackway, means connected directly to the turntable itself for rotating the same on said vertical axis and holding the same in adjusted position relative to said truck, a neck mounted on said projecting portion to move bodily therewith and to rotate relatively thereto on a horizontal axis, an elongated chain kerf-cutter comprising an elongated cutter-bar, a pivotal connection between the rear end of said cutter-bar and the 130 outer end of said neck, mechanism co-operating with said pivotal connection to move said kerf-cutter transversely of its own plane toward and from the axial line of said neck while supporting said kerf-cutter at all times on the outer end of 140 said neck with the outer end radially more remote from the turntable axis than said pivotal connection, motor-operated means comprising power transmission mechanism extending along the horizontal axis of said neck for driving said 145 kerf-cutter, motor-operated mechanism for effecting rectilinear feeding movement of said kerf-cutter, and mechanism for rotating said neck on said horizontal axis while said kerf-cutter remains supported at all times on the outer end of 150

- said neck and for holding said neck in adjusted position.
343. In a track mounted mining machine, the combination with a wheeled frame, of a turntable mounted thereon, a rotatable neck having a horizontal axis in a horizontal plane confined to a permanently fixed elevation relative to said turntable, an elongated cutting tool, means for supporting and at the will of the operator moving said cutting tool on said neck toward and from the axial line of the neck and for moving the tool on an axis which is forward of the neck and permanently perpendicular to the plane of the kerf cut by said cutting tool, the latter being carried entirely by said supporting and moving means during all adjustments of said cutting tool, means for rotating said turntable to adjust the angular position of said cutting tool relative to said wheel supported frame and holding said turntable in adjusted position, a motor on said turntable, power-transmission mechanism between said motor and said cutting tool to drive the latter and swing the same on said perpendicular axis, and means to adjust the elevation of the turntable relative to said frame to vary the elevation of the aforesaid horizontal axis relative to said wheeled frame while such horizontal axis remains permanently at fixed elevation relative to said turntable.
344. In a mining machine, the combination with a wheel supported frame, of a turntable mounted thereon, mechanism connected directly to the turntable itself to rotate the same, means for adjusting the elevation of said turntable rectilinearly relative to said frame, a rotatable neck, a bearing for said neck and mounted on said turntable to confine said neck to rotation on a horizontal axis at a permanently fixed elevation relative to said turntable, an elongated chain kerf-cutter comprising an elongated cutter bar, means for supporting said kerf-cutter on said neck for movement toward and from the axial line of said neck and for swinging movement on an axis permanently at right angles to the plane of said kerf-cutter, means for rotating said neck on said horizontal axis and holding the same in adjusted position, said horizontal axis remaining at all times at fixed elevation relative to said turntable, means for moving the kerf-cutter toward and from the axial line of the neck, and holding the same in adjusted position, and motor-operated mechanism extending along said neck axis to said kerf-cutter to drive the latter and at the will of the operator swing said kerf-cutter on its perpendicular axis.
345. In a mining machine, the combination with a frame having a width approximately equal to the gauge of a mine track, of means comprising wheels at the sides of said frame for supporting the same for movement along a mine track, mechanism for adjusting the elevation of said frame relative to said wheels, a neck, a bearing for rotatably supporting said neck on a horizontal axis, means mounting said bearing in said frame by confining said horizontal axis permanently to a fixed elevation relative to said frame, an elongated chain kerf-cutter comprising an elongated cutter bar pivotally connected to said neck to swing on an axis permanently at right angles to the plane of said kerf-cutter, a motor on said frame, and power-transmission mechanism extending from said motor along the neck axis to said kerf-cutter to drive the latter and to swing the kerf-cutter on its right angle axis in any position of adjustment of said neck relative to said frame while said neck axis remains at the aforesaid fixed elevation relative to said frame.
346. In a mining machine, the combination with a wheeled support, of a frame mounted thereon to rotate relatively thereto on a horizontal axis, a motor carried by said frame, mechanism for rotating said frame on said horizontal axis relatively to said support, cutting mechanism operatively connected to said motor and including a cutter bar pivotally connected to said frame, mechanism driven by said motor for swinging said cutter bar on its pivot, and mechanism for varying the elevation of said frame bodily to change the plane of swing of the cutter bar.
347. In a track mounted mining machine, the combination with a wheeled truck adapted to travel along a mine trackway, of a turntable having a diameter approximately equal to the track gauge and mounted on said truck for adjustment vertically relatively thereto and for rotative movement about a vertical axis, kerf-cutting mechanism on said turntable including a pivoted cutter bar swingable about a vertical axis parallel to the first named axis and located outside of the boundaries of said truck and said turntable, said kerf-cutting mechanism being provided with cutting elements movable in an orbit within whose limits the pivot of said bar is disposed, means for adjusting said turntable in elevation relative to said truck and for rotating said turntable relatively to said truck to dispose said cutter bar in a transverse plane beneath the level of the top of the trackway with its pivot at one side of the trackway and to position said cutter bar in a horizontal plane substantially above the trackway, said rotating means being associated with the peripheral portion of said turntable, means for holding said cutter bar in adjusted angular relation on its pivot relative to said turntable, and self-contained power-operated mechanism for operating said kerf-cutting mechanism in its adjusted position including rectilinear feed thereof in planes beneath the level of the top of the trackway.
348. In a mining machine, the combination with a supporting frame, of a rotatable neck, a bearing for said neck, means for mounting said bearing on said frame to permanently confine the horizontal axis of said neck relative to said bearing to a fixed elevation relative to said frame, an elongated cutting tool, plurally articulated members supporting said tool on said neck for movement bodily toward and from the axial line of the neck, mechanism for effecting such movement while the kerf-cutter continues to be supported by said neck clear of the mine bottom, mechanism for rotating said neck on said horizontal axis while supported by said bearing, and motor operated means extending along said horizontal axis and through said neck for driving said cutting tool.
349. In a mining machine, the combination with an elongated chain kerf-cutter comprising an elongated cutter bar with an endless chain cutter thereon, of means for supporting said kerf-cutter for swinging feeding movement at right angles to the plane of said cutter bar through a complete circle, power-transmission mechanism for driving said chain cutter, a worm gear concentric with the axis of swinging feeding movement of said kerf-cutter, a worm meshing with said worm gear, power-transmission mechanism connected to the opposite ends of said worm, and mechanism only alternately operable to con-

trol the direction of swinging movement of said kerf-cutter.

350. In a mining machine, the combination with a kerf-cutter, of means for supporting the same for pivotal movement on an axis at right angles to the kerf cut by said kerf-cutter, a motor, a driving shaft connected to said motor to be driven thereby and mounted on said axis, power transmission mechanism between said shaft and 10 said kerf-cutter to drive the latter and swing it on said axis, and means for effecting reversal of swinging movement of said kerf-cutter while the motor continues to rotate in the same direction.

351. In a mining machine, the combination 15 with an elongated chain kerf-cutter comprising an elongated cutter bar with an endless chain cutter traveling about the same, of means for pivotally supporting the cutter bar on an axis at right angles to said cutter bar and within the 20 path of travel of the chain cutter, a motor, a worm gear concentric with said axis, a worm meshing with said worm gear, power-transmission mechanism between said motor and kerf-cutter to drive said chain cutter, and means connected to opposite ends of said worm for effecting reversal of swinging movement of said kerf-cutter on said axis while the motor continues to drive the chain cutter always in the same direction.

352. In a mining machine, the combination 30 with an elongated chain kerf-cutter, of means for pivotally supporting the same for swinging feeding movement on an axis at right angles to the plane of said kerf-cutter, a worm gear concentric 35 with said axis, a worm meshing with said worm gear, means extending radially from said axis to the opposite ends of said worm, and clutch-controlled mechanism associated with said radial means for controlling the direction of swinging 40 movement of said kerf-cutter.

353. In a mining machine, the combination 45 with an elongated chain kerf-cutter comprising an elongated cutter bar and an endless chain cutter traveling thereon, means for supporting said kerf-cutter for pivotal swinging movement on an axis at right angles to said cutter bar and within the path of travel of said chain cutter, a worm gear concentric with said axis, a motor, power-transmission mechanism between 50 said motor and said chain-cutter to drive the same, and clutch-controlled reversing mechanism comprising two worm gear trains connected to said worm gear within the compass thereof and operable by said power-transmission mechanism 55 to effect reversal of swinging movement of said kerf-cutter on said axis while said motor continues to drive said chain-cutter always in the same direction.

354. In a mining machine, the combination 60 with a supporting frame, of an elongated chain kerf-cutter comprising a cutter bar and a traveling chain cutter thereon, means for pivotally supporting said cutter bar on said frame to swing relatively thereto on an axis at right angles to 65 said cutter bar, power-transmission mechanism comprising a driving shaft on said axis and connected to said chain cutter to drive the same, a worm gear concentric with said axis, a worm meshing with said worm gear, power-transmission 70 gearing connected between said shaft and the opposite ends of said worm, and clutches for controlling said last-named power-transmission gearing to effect reversal in direction of 75 swinging movement of said cutter bar while said

chain cutter continues to be driven in the same direction.

355. In a track-mounted mining machine, the combination with a wheeled truck adapted to travel on a mine track, of a guiding frame mounted thereon, a machine frame slidably mounted on said guiding frame, an elongated kerf-cutter comprising a cutter bar pivotally connected to said machine frame for swinging movement in a vertical plane on an axis at right angles to said cutter bar, a driving motor carried by said machine frame, means for effecting rectilinear feeding movement of said kerf-cutter by sliding said machine frame along said guide frame, and mechanism comprising a power-rotatable feed device and a co-operating feed element coaxial with said right angle axis for swinging said cutter bar in such vertical plane about its pivot while the latter remains stationary. 80 85 90

356. In a mining machine, the combination 95 with a wheeled truck, of a supporting frame mounted thereon, an elongated kerf-cutter comprising a cutter bar and a chain cutter thereon, means for pivotally connecting said cutter bar to said supporting frame for swinging feeding movement on an axis at right angles to the plane of said cutter bar, power-transmission mechanism comprising a drive shaft on said axis for driving said chain cutter, means operable directly from said drive shaft for swinging said cutter bar in opposite 100 directions, and selectively operable reversing clutches for controlling the direction of swinging movement of said cutter bar while said shaft continues to drive said chain cutter always in the same direction. 105 110

357. In a coal mining machine, the combination 115 with a wheeled truck adapted to travel along a mine track and having a width approximately equal to the track gauge, of an elongated kerf-cutter comprising an elongated cutter bar and an endless cutter chain thereon, a turntable having a diameter approximately equal to the width of said truck and mounted thereon to rotate relatively thereto on a vertical axis intermediate the front and rear axles of said wheeled truck, a 120 support extending radially out from said turntable and beyond the periphery thereof, a turnover head swiveled to said support on a horizontal axis confined by said support against change in elevation relative to said turntable, 125 means for pivotally connecting said cutter bar to said head for swinging adjustment in its own plane on an axis permanently at right angles to the plane of said cutter bar, said right angle axis when vertical being parallel to said turntable 130 axis and spaced radially therefrom in a position outside of the boundaries of said truck whether in front thereof or at the sides thereof, means for locking said cutter bar in adjusted angular relation to said head and its horizontal axis, 135 means between said support and said head and comprising self-locking worm gearing for rotating said head on said horizontal axis to adjust the said cutter bar to horizontal or upright planes while parallel to said horizontal axis, 140 means associated with the periphery of said turntable to turn the latter on its vertical axis to swing the kerf-cutter arcuately on such vertical axis from one side of the mine track across the front end thereof to the other side thereof, 145 means for adjusting vertically said turntable relative to said truck to secure adjustment in elevation of said kerf-cutter relative to the mine bottom while said kerf-cutter is parallel to the horizontal axis of said turnover head, and op- 150

erator-controlled self-contained power-operated mechanism comprising a motor supported by said turntable for driving said chain cutter and feeding the kerf-cutter rectilinearly parallel to the mine track either forwardly or rearwardly relative to the mine track while said cutter bar is locked to said head and said head is locked to said support.

358. In a track mounted mining machine, the combination with a wheeled frame adapted to move along a trackway, of an elongated chain kerf-cutter comprising an elongated cutter bar having an endless chain cutter thereon adapted to be presented edgewise to a coal face in advance of the trackway to cut a kerf at right angles to such face in a vertical plane, means for pivotally connecting said cutter bar to said frame for adjustment to vertical planes parallel to the track anywhere between the ribs of the mine entry, means operable while supporting said kerf-cutter to adjust the same to such vertical planes and holding the same in adjusted vertical planes parallel to the trackway, and self-contained power-operated means for feeding said kerf-cutter rectilinearly while being held at an adjusted acute angle relative to the horizontal, feeding the kerf-cutter transversely in the same plane and withdrawing the kerf-cutter rectilinearly while being held at an adjusted acute angle relative to the horizontal to effect the cutting of a vertical parallel ribbed kerf in advance of the trackway at right angles to the coal face extending across the space in advance of the trackway.

359. In a mining machine, the combination with a wheeled truck movable on a trackway, of chain kerf-cutting mechanism comprising an elongated cutter bar adapted to be presented edgewise to the face of a mine vein, means pivotally connecting said cutter bar to said truck for adjustment relative thereto to various parallel vertical planes between the sides of the machine including a vertical plane midway between the sides of the machine, means for supporting the cutter bar and adjusting the same while being supported to any one of such vertical planes and disposing the same at acute angles to the horizontal, and self-contained power-operated means supported on said truck for moving the bar when disposed at an acute angle rectilinearly relative to the trackway, relatively transversely in the same plane, and for moving the bar when disposed at another acute angle reversely rectilinearly relative to the trackway to form a parallel ribbed shearing kerf of a depth substantially equal to the effective length of the cutter bar.

360. In a mining machine, the combination with supporting means movable on a trackway, of cutter mechanism thereon comprising an elongated cutter bar having a chain cutter adapted to cut a kerf for said bar in a mine face when said bar is presented edgewise thereto, means for pivotally mounting said cutter bar on said supporting means for adjustment relatively thereto on angularly related axes one of which is perpendicular to said cutter bar and one of which is parallel thereto and another of which is horizontal, means for supporting and while supported adjusting said cutter bar on said angularly related axes to a predetermined position in an upright plane for shear-cutting parallel to the trackway, means for adjusting the kerf-cutter to vary the radial angular position of said horizontal axis, said adjustments enabling said kerf-cutter to occupy a shear cutting position midway between vertical planes extending through

the sides of the machine as well as in such vertical side planes, and self-contained power-operated means for operating said kerf-cutter including feed thereof bodily rectilinearly of the trackway, transversely in the same plane, and reverse rectilinearly to the trackway to cut a parallel ribbed kerf with the ribs respectively approximately in continuation of the roof and floor of the mine room.

361. In a mining machine, the combination with a wheeled truck adapted to travel along a mine track and be braced thereby of an elongated kerf-cutter comprising an elongated cutter bar with a traveling chain cutter thereon, means for pivotally connecting said cutter bar to said truck for adjustment relative thereto on angularly related axes, means for supporting and while supported adjusting said kerf-cutter on such axes in opposite directions to a plurality of successively adjacent parallel vertical planes through a range equal to at least the width of the machine, and operator-controlled self-contained power-operated mechanism for operating kerf-cutter in any one of said vertical planes including rectilinear sumping feed, transverse arcuate feed in the same plane and rectilinear withdrawal feed to shear a plane kerf having parallel ribs.

362. In a mining machine, the combination with a portable base frame, of a supplemental frame mounted thereon for angular adjustment relative thereto on a vertical axis, means for holding said supplemental frame in adjusted angular relation to said base frame, an elongated kerf-cutter comprising an elongated cutter-bar with an endless chain cutter thereon, means pivotally connecting said cutter-bar to said supplemental frame for adjustment relative thereto on a vertical axis spaced horizontally from said first-named vertical axis while said kerf-cutter occupies a vertical plane in shear cutting position, means for supporting and while supported adjusting said kerf-cutter on such second-named vertical axis transversely of the plane of the kerf-cutter, the adjustments on said vertical axes being in opposite directions to enable said kerf-cutter to occupy various successively adjacent vertical parallel planes, and power operated mechanism for feeding said kerf-cutter rectilinearly in the vertical plane to which it has been adjusted.

363. In a mining machine, the combination with a portable base frame, of a supplemental frame mounted thereon for angular adjustment relative thereto on a vertical axis, means for holding said supplemental frame in adjusted angular relation to said base frame, an elongated kerf-cutter comprising an elongated cutter-bar with an endless chain cutter thereon, means pivotally connecting said cutter bar to said supplemental frame for adjustment relative thereto on a vertical axis spaced horizontally from said first-named vertical axis while said kerf-cutter occupies a vertical plane in shear cutting position, means for supporting and while supported adjusting said kerf-cutter on such second-named vertical axis transversely of the plane of the kerf-cutter to bring the latter into a vertical plane parallel to the path of the machine, the adjustments on said vertical axes being in opposite directions to enable said kerf-cutter to occupy various successively adjacent vertical parallel planes at various distances from the longitudinal center line of the machine, and operator-controlled self-contained power-operated mechanism

for feeding said kerf-cutter rectilinearly in the vertical plane to which it has been adjusted.

364. In a mining machine, the combination with a base frame, of a supplemental frame mounted thereon for angular adjustment thereto on a vertical axis, an elongated kerf-cutter comprising an elongated cutter-bar with a chain cutter thereon, means for pivotally connecting said kerf-cutter to said supplemental frame for adjustment relative thereto on a vertical axis spaced horizontally from said first-named vertical axis and for swinging movement relatively to said supplemental frame on a horizontal axis at right angles to said cutter-bar, means for supporting and while supported adjusting the cutter-bar on said spaced vertical axes in opposite directions and transversely of the plane of the cutter-bar, power-operated mechanism for feeding the kerf-cutter rectilinearly, and power-operated mechanism for swinging the cutter-bar in a vertical plane on its right angle axis.

365. In a mining machine, the combination with a base frame, of a supplemental frame mounted thereon for angular adjustment relative thereto on a vertical axis, an elongated kerf-cutter comprising a cutter-bar with a chain cutter thereon, means for pivotally connecting said cutter-bar to said supplemental frame for adjustment relative thereto on three angularly related axes one of which is horizontal and at right angles to said cutter-bar, means for swinging the kerf-cutter on its right angle axis, means for supporting and while supported adjusting the kerf-cutter on the afore-said axes other than said right angle axis to position said kerf-cutter in any one of various successively adjacent parallel planes, and power-operated mechanism for operating said kerf-cutter including rectilinear feed thereof in its adjusted plane.

366. In a mining machine, the combination with a base frame, of a supplemental frame mounted thereon for adjustment relative thereto on a vertical axis; means for effecting such adjustment and holding the supplemental frame in adjusted angular relation to said base frame, an elongated kerf-cutter comprising an elongated cutter-bar with a chain cutter thereon, means pivotally connecting said cutter-bar to said supplemental frame on angularly related axes one of which is horizontal and parallel to the plane of the cutter-bar and the other of which extends transversely of the cutter-bar, means for adjusting the cutter-bar on the horizontal axis to a shear cutting position in a vertical plane, with said transverse axis vertical and horizontally spaced from said first-named vertical axis, and power-operated means for operating said kerf-cutter including feed thereof in said vertical plane.

367. In a mining machine, the combination with a portable base frame, of a supplemental frame mounted thereon for adjustment relative thereto on a vertical axis, means for effecting such adjustment and holding said supplemental frame in adjusted angular relation to said base frame, a head mounted on said supplemental frame for adjustment relative to the latter on a horizontal axis through an angle of at least 180° , an elongated kerf-cutter comprising an elongated cutter-bar with an endless chain cutter thereon, means connecting said cutter-bar to said head on angularly related axes one of which is at right angles to said cutter-bar and the other of which is vertical when said kerf-cutter is in shear cutting position, means for adjusting the kerf-cutter transversely of its plane on said last-

named vertical axis to a shear cutting position parallel to the ribs of the mine room, the adjustments on both of said vertical axes enabling said kerf-cutter to occupy a shear cutting position parallel to one of the said ribs and closely adjacent thereto, means for turning over the head to enable adjustment on said vertical axes to position said kerf-cutter parallel to the other rib and closely adjacent thereto in shearing position, and power-operated mechanism for summing the kerf-cutter rectilinearly when adjacent either of said ribs, feeding said kerf-cutter arcuately in the same plane and withdrawing the kerf-cutter rectilinearly to cut a parallel ribbed shear kerf with the ribs thereof approximately in continuation of the floor and roof of the mine room.

368. In a mining machine, the combination with a base frame, of a supplemental frame mounted thereon for adjustment relatively thereto on a vertical axis, an elongated cutting tool, means pivotally connecting said cutting tool to said frame for adjustment on a vertical axis parallel to said first-named vertical axis and spaced horizontally therefrom, means for adjusting said supplemental frame on its vertical axis and for supporting and while supported adjusting said cutting tool on its vertical axis to move said cutting tool into various vertical planes successively parallel to each other anywhere between vertical planes outside of the boundaries of said base frame, and power-operated mechanism for operating said cutting tool in any of such vertical planes including the feed thereof.

369. In a mining machine, the combination with a base frame, of a supplemental frame mounted thereon for adjustment relative thereto on a pivot having a vertical axis, an elongated cutting tool, means connecting said cutting tool to said supplemental frame for adjustment relative thereto on two pivots the axis of one of which is horizontal and the axis of the other vertical and spaced horizontally from said first-named vertical axis, means for adjusting said cutting tool on said vertical axes to locate the same in a vertical plane adjacent to one rib of the mine entry, means for inverting said cutting tool and said second-named vertical pivot on said horizontal axis to enable adjustment of the cutting tool on said vertical axes to locate said cutting tool in a vertical plane adjacent to the other mine entry rib, and operator-controlled self-contained power-operated mechanism for operating said cutting tool including the feed thereof to insert incisions in the face in advance of the space in front of the machine along horizontal lines longitudinally of the cutting tool parallel to said ribs and in vertical planes closely adjacent thereto.

370. In a mining machine, the combination with a portable base frame, of an elongated cutting tool, means for pivotally connecting said cutting tool to said base frame for adjustment relative thereto on horizontally spaced vertical axes, means for supporting said cutting tool for adjustment on said vertical axes in opposite directions to position the same in parallel vertical planes extending through said base frame, means for effecting such adjustments, and power-operated mechanism for operating said cutting tool including the feed thereof in any of such vertical planes.

371. In a mining machine, the combination with a base frame, of an elongated kerf-cutter, means for pivotally connecting said kerf-cutter to said base frame for adjustment relative there-

- to on horizontally spaced vertical axes and for swinging movement in a vertical plane on an axis at right angles to the kerf cut by said kerf-cutter, means for supporting and while supported adjusting said kerf-cutter on said vertical axes in opposite directions to position the same in successively adjacent parallel vertical planes, and motor operated mechanism for operating said kerf-cutter including swinging feeding movement thereof. 80
372. In a mining machine, the combination with a base frame, of a cutting tool, a group of members supporting said tool for adjustments relative to said frame on a plurality of pivotal axes two of which are spaced apart and parallel to each other, means for adjusting said cutting tool on said spaced apart parallel pivotal axes to move the tool bodily into parallel positions parallel to the longitudinal center line of the machine and at varying distances therefrom, and power-operated mechanism for driving said cutting tool. 85
373. In a mining machine, the combination with a base frame, of an elongated kerf-cutter, members supporting said kerf-cutter on said base frame for adjustment relative thereto on parallel spaced-apart axes, mechanism operative while said members support said kerf-cutter for effecting adjustments on said axes to move the kerf-cutter into parallel planes at various distances from each other and thereby maintain said kerf-cutter parallel to the path of travel of the machine, and power-operated mechanism for operating said kerf-cutter including the feed thereof. 90
374. In a mining machine, the combination with a base frame, of an elongated kerf-cutter, members comprising an arm and a support pivoted to the outer end thereof for supporting said kerf-cutter on said frame for adjustment relative thereto on spaced-apart parallel axes one of which is the axis of the pivot at the outer end of said arm, means comprising worm gearing for swinging said arm and said support and kerf-cutter on the inner parallel axis spaced from said pivot, means for effecting swinging of said support and said kerf-cutter on the outer pivot in a direction opposite to the swinging of said arm on the inner axis to cause said kerf-cutter to be positioned in various parallel planes at various distances from the longitudinal center line of the machine, a pivotal connection between said support and said kerf-cutter for swinging feeding movement of the latter on an axis at right angles to the kerf cut by said kerf-cutter, and power-transmission mechanism extending along said arm and said support to said kerf-cutter to operate the latter including swinging feeding movement thereof on said right angle axis. 95
375. In a mining machine, the combination with a wheeled base frame adapted to travel along a mine track, of an elongated kerf-cutter, a plurality of pivotally connected members for supporting said kerf-cutter for adjustment on parallel spaced-apart axes to parallel planes parallel to the mine track and at varying distances from the longitudinal center line of the machine, said members comprising an arm pivotally connected to said base frame on one of said axes and a kerf-cutter support pivotally connected to the outer end of said arm on the other axis, means comprising worm gearing for swinging said arm on its pivotal connection to said base frame, means for effecting swinging of said support together with said kerf-cutter on the pivot at the outer end of said arm in a direction opposite to the swinging of said arm to position said kerf-cutter in such parallel planes, a pivotal connection between said kerf-cutter and said support to permit said kerf-cutter to swing on an axis extending transversely of the axis at the outer end of said arm, and power-transmission mechanism extending along said arm and support to said kerf-cutter to drive the latter and effect swinging feeding movement of the kerf cutter in any of such parallel planes. 100
376. In a coal mining machine, the combination with a frame supported on wheels for travel along a mine trackway, of an elongated chain kerf-cutter comprising an elongated cutter bar with a cutter chain traveling thereon, a turnover head mounted on the forward end of said frame for adjustment relative thereto on a horizontal axis confined against change in elevation relative to said frame, means for pivotally connecting said cutter bar to said head for swinging feeding movement on an axis permanently at right angles to the plane of said cutter bar, said cutter bar projecting forwardly in advance of said frame being supported in offset position from said horizontal axis in a plane parallel thereto and parallel to the mine track, means for adjusting said head on said horizontal axis and locking the same in adjusted position with said kerf-cutter in a horizontal undercutting plane 105 or in a horizontal overcutting plane or in upright shearing planes adjacent to the sides of said frame, means for adjusting the elevation of said frame relative to the wheels to adjust the elevation of the kerf-cutter relative to the mine bottom, and operator-controlled self-contained power-operated mechanism comprising an elongated bar movable through said frame for feeding said kerf-cutter rectilinearly parallel to the mine track to present the kerf-cutter edge-wise to the coal face and sump a kerf therein in a plane parallel to said horizontal axis, feeding the kerf-cutter arcuately on said right angle axis and finally feeding the kerf-cutter reversely rectilinearly to effect the cutting of a parallel ribbed kerf of predetermined dimensions, the arcuate feeding mechanism comprising automatic locking means to hold the cutter bar rigidly connected to said head at an acute angle relative to the said horizontal axis when 110 said rectilinear sumping and withdrawal cuts are being effected. 115
377. In a mining machine, the combination with a supporting frame, of a rotatable neck mounted on said frame to occupy a position 120 which is horizontal and parallel to the machine path, means for rotating said neck on a horizontal axis, means for supporting said cutting tool on said neck for bodily movement toward and from the axial line of the neck and for swinging movement on an axis at right angles to the plane of the kerf cut by said cutting tool, means comprising a gear mounted on said neck for rotation relatively thereto on an axis extending transversely relative to said right angle axis and 125 transversely relative to said axial line for moving said cutting tool bodily toward and from said axial line, and self-contained power-operated mechanism for swinging said cutting tool on said right angle axis and for driving said cutting tool. 130
378. In a mining machine, the combination with a supporting frame, of a rotatable neck having an axis which is relatively stationary and horizontal and parallel to the machine path, an 135
- 75

elongated kerf-cutting tool, means for supporting said cutting tool on said neck for bodily movement relatively thereto toward and from the axial line of the neck, means comprising a gear 5 rotatable on an axis extending parallel to the kerf cut by said cutting tool and transversely relative to the said axial line for bodily moving said cutting tool toward and from said axial line, a motor, and power-transmission mechanism between said motor and said cutting tool to drive the same.

379. In a mining machine, the combination with a supporting frame, of a rotatable neck mounted on said frame, means for rotating said 15 neck on a horizontal axis which is parallel to the machine path, an elongated cutting tool mounted on said neck for bodily movement toward and from the axial line of the neck and for swinging movement on an axis at right angles to the plane of the kerf cut by said cutting tool, gearing including an element rotatable on an axis extending transversely relative to said right angle axis and transversely relative to said axial line for moving the cutting tool bodily to- 25 ward and from said axial line, and power driven mechanism for driving the cutting tool and for swinging it on its right angle axis.

380. In a mining machine, the combination with a supporting frame, of a tool support mounted thereon for rotation relatively thereto on a horizontal axis, mechanism for effecting rotation of said tool support on said horizontal axis, an elongated cutting tool, means for supporting said elongated cutting tool on said tool support for movement toward and from the axial line of the tool support and for swinging movement on an axis at right angles to the plane of the kerf cut by said cutting tool, means comprising gearing operable on axes spaced from said right angle axis for moving said cutting tool bodily toward, and from such axial line, and operator-controlled self-contained power-operated transmission gearing for swinging said cutting tool on such right angle axis while in adjusted position 45 relative to said axial line.

381. In a mining machine, the combination with a supporting frame, of a neck mounted on said frame for rotation relatively thereto on a horizontal axis, an elongated cutting tool, means 50 for supporting said cutting tool on said neck for adjustment to positions at varying distances from the axial line of the neck into parallelism to said axial line, means carried by said rotatable neck for adjusting said cutting tool on rectangularly related axes to cutting positions at different distances from and parallel to said axial line and holding said cutting tool in such positions for orbital paths of rotary adjustment on said horizontal axis, and power transmission 55 mechanism extending along the axis of said neck for driving said cutting tool in any of its adjusted positions.

382. In a mining machine, the combination with elongated cutting mechanism, of supporting 60 means comprising a rotatable neck and a bearing therefor, means for rotating said neck and holding the same in adjusted position, means for pivotally connecting said elongated cutting mechanism to said neck to permit adjustment of said cutting mechanism on a plurality of axes into planes at various distances from said axial line and parallel to said axial line at such varying distances therefrom, means for effecting adjustment of said cutting mechanism on such plurality of axes into such planes at varying dis-

tances from said axial line, and power-transmission for operating said cutting mechanism including feed thereof in the plane to which adjusted.

383. In a mining machine, the combination with an elongated cutting tool, of supporting means comprising a neck and a bearing therefor, means for pivotally connecting said elongated cutting tool to said neck for adjustment on a plurality of axes into planes at varying distances from the axial line of said neck and parallel to the axial line and for swinging in such planes, means for adjusting said cutting tool on such plurality of axes to such parallel planes at varying distances from said axial line, and power-transmission mechanism for driving said cutting tool and swinging the same. 80

384. In a mining machine, the combination with a supporting frame, of a rotary neck and a bearing therefor, cutting mechanism plurally articulated to said neck for adjustment to planes parallel to the axial line of said neck and at various distances therefrom, means for adjusting said cutting mechanism on a plurality of axes to such parallel planes at various distances from 100 said axial line, and power-transmission mechanism comprising a rotary shaft on the axis of said neck for driving said cutting mechanism. 95

385. In a mining machine, the combination with a supporting frame, of a rotary neck, a bearing on said frame for supporting said neck for rotation relatively to said frame, cutting mechanism articulated to said neck on a plurality of pivotal axes for movement in a plurality of directions for adjustment of the cutting mechanism into planes parallel to the axial line of the neck and at varying distances therefrom, means for moving said cutting mechanism on said plurality of axes to effect such adjustments, and power-transmission mechanism for operating 115 said cutting mechanism including the feed thereof. 105

386. In a track mounted mining machine, the combination with a wheeled base frame adapted to travel along a mine track and be braced thereby, of an elongated chain kerf-cutter comprising an elongated cutter bar with a chain cutter traveling thereon, an arm pivotally connected to said base frame for adjustment relative thereto on rectangularly related axes one of which is horizontal and parallel to the mine track and the other of which extends transversely of said horizontal axis, a support for pivotally connecting the kerf-cutter to the outer end of said arm on rectangularly related axes one of which is permanently at right angles to the said cutter bar and the other of which extends transversely of said horizontal axis, means comprising worm gearing for swinging said arm on said first-named transverse axis and holding the same in adjusted 135 position, means for turning said arm on said horizontal axis and holding the same in adjusted position, means for effecting movement of said kerf-cutter transversely of its plane on said second-named transverse axis in a direction opposite to the swinging of said arm on said first-named transverse axis, and power-transmission mechanism extending along said horizontal axis and said arm and said support to said kerf-cutter to drive the latter and effect swinging feeding 140 movement thereof on said right angle axis. 125

387. In a track-mounted mining machine, the combination with a supporting frame mounted on wheels for movement along a mine track, of a turnover head mounted on said frame for rota- 150

- tion relatively thereto on a horizontal axis confined against change in elevation relative to said frame, means for effecting rotation of said head on said horizontal axis and holding the same 5 in adjusted position relative to said frame, an elongated chain kerf-cutter comprising an elongated cutter bar with an endless chain cutter traveling thereon in an orbital path, means for pivotally connecting said cutter bar to said head 10 for swinging movement on an axis permanently at right angles to said cutter bar, said right angle axis being within said orbital path, mechanism on said turnover head for moving the kerf-cutter transversely of its plane toward and from 15 said axial line on a pivot spaced from said horizontal axis and extending transversely thereof and holding the said right angle axis in fixed position relative to said frame with the kerf-cutter in a predetermined plane, and operator-controlled 20 self-contained power-operated mechanism for swinging said kerf-cutter on said right angle axis and locking the same at an acute angle relative to the mine track and for sumping said kerf-cutter rectilinearly into a coal face when 25 presented edgewise thereto and after effecting arcuate feeding and locking the cutter bar at another acute angle relative to the mine track withdrawing the kerf-cutter rectilinearly to produce a parallel ribbed kerf. 30 388. In a track-mounted mining machine, the combination with a wheeled truck movable along a trackway, of a kerf-cutting unit comprising a motor operatively connected to a pivoted elongated plane chain kerf-cutter disposable in fixed 35 relation at acute angles to the trackway, means for supporting said kerf-cutting unit with said kerf-cutter at the mine bottom at one side of the trackway, means for adjusting the elevation and inclination of said kerf-cutter when adjacent the 40 mine bottom, and motor operated mechanism separate from said kerf-cutting unit for moving the whole machine along the trackway to effect feeding movement of said kerf-cutter when at the mine bottom at one side of the trackway. 45 389. In a mining machine, the combination with a wheel-supported rigid base frame, adapted to run upon and be braced by the rails of a mine track, of a widely expanded circular turntable mounted on said base frame, means for guiding 50 said turntable upwardly and downwardly rectilinearly relatively to said base frame, mechanism for adjusting said turntable vertically and rectilinearly in relation to said base frame, an endless chain elongated kerf-cutter mounted on said 55 turntable to move bodily therewith, means associated with the periphery of said turntable for rotating the same and locking the turntable in adjusted position relative to said base frame to 60 adjust the angular position of said kerf-cutter and hold the same in adjusted position, and means independent of said elevating mechanism for adjusting on an axis tangential to a circle concentric with the turntable the elevation and inclination of said kerf-cutter relative to said turntable. 65 390. In a mining machine, the combination with a wheel supported base movable along a mine track, of a body turnable horizontally relatively to said base on an upright axis, means for turning said body on said upright axis relatively to 70 said base and holding said body in adjusted position, an elongated kerf-cutting tool, a tool support mounted on said body for rotation relatively thereto on a horizontal axis, means for rotating said tool support on said horizontal axis relatively 75 to said body and holding said tool support in adjusted position, members supporting said elongated tool on said support for movement toward and from the axial line of said tool support to position said cutting tool to cut a vertical kerf between vertical parallel planes extending through the rails of the mine track, means on said rotatable support for actuating said supporting members for moving said tool toward and from said axial line of the rotary support and holding the same in adjusted position between such vertical parallel planes, and means for operating said cutting tool comprising power transmission mechanism extending along the horizontal axis of said support. 80 391. In a mining machine, the combination with a wheel supported frame movable along a mine track, of a neck rotatable on a horizontal axis which is in a horizontal plane having a permanently fixed elevation relative to said frame, means for rotatably adjusting said neck on said horizontal axis, and locking said neck in adjusted position relative to said frame, an elongated chain kerf-cutter comprising a cutter bar pivotally supported on said neck to swing relatively thereto on an axis at right angles to the plane 90 of said kerf-cutter, means for moving said kerf-cutter toward and from the axial line of said neck while said kerf-cutter is supported by said neck and while said kerf-cutter is maintained in vertical planes between vertical parallel planes 95 extending through the rails of the mine track, motor operated mechanism for swinging said kerf-cutter on its right angle axis at a feeding speed, and motor operated mechanism for feeding said kerf-cutter rectilinearly. 100 392. In a mining machine, the combination with a wheel supported frame, of a head mounted thereon to rotate relatively thereto on a horizontal axis having a fixed relation to said frame by being confined against adjustment in elevation 115 relative thereto, an elongated chain kerf-cutter, members supporting said kerf-cutter on said head for movement toward and from said horizontal axis and for movement in its own plane on an axis at right angles to said plane, means for rotating 120 said head on said horizontal axis to position said kerf-cutter in a vertical plane, means for moving said kerf-cutter toward and from said horizontal axis while said members continue to support said kerf-cutter as aforesaid and while said 125 kerf-cutter is maintained in vertical planes, mechanism cooperating with said moving means to afford adjustment of said kerf-cutter to a vertical plane parallel to the mine track and between the rails thereof, and motor operated mechanism 130 for driving said kerf-cutter and swinging the same at a feeding speed. 135 393. In a mining machine, the combination with a portable base, of a horizontal turntable on said base, means associated with the periphery 140 of said turntable for rotating the latter and locking the same in adjusted angular relation to said base, mechanism for adjusting the elevation of said turntable relative to said base, a cutter head mounted at the forward edge of said turntable 145 for rotation relative thereto about a horizontal axis and disposed in advance of said base, a kerf-cutter pivotally mounted on said cutter head, means for rotating said cutter head relatively to said turntable on a horizontal axis, and means 150 for driving said kerf-cutter and swinging the same on its pivot relatively to said head. 394. In a mining machine, the combination with a portable base, of a horizontal turntable mounted thereon for adjustment relative thereto 150

- on a vertical axis, a support rotatable about an axis extending radially with respect to the turn-table axis, a kerf-cutter, a cutter support swingably mounted on said rotatable support about an axis extending transversely of said radial axis and pivotally supporting said kerf-cutter for swinging about an axis at right angles to said transverse axis, and means for operating said kerf-cutter including the driving and the feed thereof while in adjusted position. 80
395. In a mining machine, the combination with a portable base, of a horizontal turntable mounted thereon, a kerf-cutter, adjustable supporting structure intervening said kerf-cutter and said turntable to afford adjustment of said kerf-cutter into various cutting planes relative to the turntable, said adjustable supporting structure including a support rotatable on a horizontal axis and a cutter support swingable relatively to said rotatable support on an axis at right angles to a line parallel with the axis of the rotatable support, said kerf-cutter being pivotally mounted on said cutter support to swing relatively thereto on an axis at right angles to the axis of the cutter support, and means for operating said kerf-cutter including the feed thereof. 85
396. In a mining machine, the combination with a support, of a neck carried by said support for rotation relatively thereto on a horizontal axis, a plane kerf-cutter comprising a plane cutter bar with a cutter chain circulating around the peripheral edge thereof, a member for pivotally supporting said cutter bar to swing in its own plane, means for pivotally supporting said member on said neck on an axis which is spaced from the neck axis and is perpendicular to the axis of pivotal movement of the cutter bar in its plane, and means for operating said kerf-cutter including the feed thereof. 90
397. In a mining machine, the combination with a wheeled truck adapted to move along a trackway, of a pivoted kerf-cutter, adjustable supporting means on the truck for positioning the kerf-cutter to cut a horizontal kerf at the level of the mine bottom outside and below the level of the mine trackway or to cut a vertical kerf extending in the direction of the trackway and midway between the sides of the trackway, and means for operating said kerf-cutter when at the level of the mine bottom or when in such midway position between the sides of the trackway. 100
398. In a mining machine, the combination with a wheeled truck adapted to move along a mine trackway, of a pivoted kerf-cutter, adjustable supporting means for positioning said kerf-cutter to cut a horizontal kerf at the level of the mine bottom outside and below the level of the mine trackway or to cut a vertical kerf extending parallel to the trackway and midway between the track rails or to cut a horizontal kerf at the level of the mine roof, and means for operating said kerf-cutter when at the level of the mine bottom or when in such midway position between the rails of the trackway or when at the level of the mine roof. 110
399. In a track mounted mining machine, the combination with a wheeled truck adapted to move along a trackway, of a pivoted kerf-cutter, adjustable supporting means for positioning said kerf-cutter into different parallel horizontal planes between the mine bottom and the mine roof and in vertical cutting positions between the ribs of the mine entry including a position midway between the track rails and extending 115
- parallel with the latter, said adjustable supporting means including mechanism for positioning the kerf-cutter to cut a horizontal kerf at the level of the mine bottom and below the level of the mine trackway, and motor operated mechanism for driving and feeding said kerf-cutter in any of such adjusted positions. 80
400. In a mining machine, the combination with a support, of a motor thereon, cutting mechanism comprising a cutter bar pivotally mounted on said support for swinging movement relatively thereto, mechanism comprising a worm meshing with a worm gear for swinging said cutter bar in opposite directions, and means operatively connected between said motor and the opposite ends of said worm for rotating the latter in opposite directions to effect operation of the aforesaid swinging mechanism. 85
401. In a mining machine, the combination with a main frame bodily movable relative to a working face, of a supplemental frame pivotally connected to said main frame for rotation relatively thereto on a horizontal axis, a plane kerf-cutter comprising a plane cutter bar, a cutter support pivotally connected to said supplemental frame for adjustment relative thereto on an axis spaced from said horizontal axis, means for pivotally supporting said cutter bar on said cutter support, adjustment of said supplemental frame on said horizontal axis affording adjustment of said kerf-cutter to positions near the floor and near the roof of the mine, and adjustment of said cutter support on said spaced axis effecting a change in position of said cutter bar, and means for operating said kerf-cutter including the feed thereof. 95
402. In a mining machine, the combination with a support, of a motor thereon, cutting mechanism operatively connected to said motor and comprising a cutter bar pivotally mounted on said support for swinging movement relatively thereto, and mechanism driven by said motor for swinging said cutter bar in either of opposite directions and including separate gear trains operatively connected to opposite ends of a single worm for rotating the latter in opposite directions and thereby effect such swinging of the cutter bar. 105
403. In a mining machine, the combination with a portable base, of a horizontal turntable mounted on said base, a kerf-cutter, an adjustable supporting structure intervening said kerf-cutter and said turntable for adjusting the kerf-cutter into various cutting planes with respect to the turntable, said adjustable supporting structure including a support located in advance of the forward edge of the turntable and overhanging the forward end of said base and rotatable about a horizontal axis relatively to the turntable, said adjustable supporting structure including also a cutter support pivotally mounted on said rotatable support to swing about an axis extending at right angles to a line parallel with the said horizontal axis, said kerf-cutter being pivotally mounted on said cutter support to swing relatively thereto on an axis extending at right angles to the aforesaid right angle axis, and motor operated mechanism for operating said kerf-cutter. 125
404. In a mining machine, the combination with a plane kerf-cutter comprising a plane cutter bar and a cutter chain circulating around the peripheral edge thereof, means for driving said kerf-cutter, and supporting means for said kerf-cutter adjustable to vary the plane of cut thereof 130

- and comprising a plurality of supporting members rotatable about spaced axes, said cutter bar being pivotally connected to one of said members for swinging movement about an axis perpendicular to the axis on which the last-named member is rotatable.
405. In a mining machine, the combination with a support, of a neck rotatable thereon about a substantially horizontal axis, a plane kerf-cutter, a cutter support pivotally connected to said neck on an axis which is bodily rotatable about the axis of the neck upon rotation of the latter, means pivotally connecting said kerf-cutter to said cutter support on an axis perpendicular to the plane of the kerf-cutter and also perpendicular to the second-named axis, and means for operating said kerf-cutter.
406. In a bottom cutting mining machine, the combination of a wheeled truck adapted to travel along a mine track, of a turntable mounted thereon, a kerf-cutting unit comprising an elongated chain kerf-cutter pivotally supported to swing on an axis at right angles to the kerf cut and a motor connected to said kerf-cutter to drive the same, means comprising spaced trunnions for pivotally connecting said kerf-cutting unit to said turntable for adjustment relative thereto on a horizontal axis, means for tilting said kerf-cutting unit relatively to said turntable on said horizontal axis and holding said kerf-cutting unit in fixed relation to said turntable, means for locking the kerf-cutter in adjusted angular relation to said horizontal axis, means for effecting adjustment in elevation of the kerf-cutter from a position above the level of the mine track to the floor level at one side of the mine track, and motor operated mechanism separate from said kerf-cutting unit for effecting rectilinear feed of said kerf-cutter while at the floor level at one side of the mine track.
407. In a mining machine, the combination with a support, of a motor thereon, cutting mechanism comprising a cutter bar pivotally mounted on said support for swinging movement relatively thereto, mechanism driven by said motor for swinging said cutter bar in either of opposite directions and comprising a worm extending transversely of the support while meshing with a worm gear with means operatively connected to the opposite ends of said worm for rotating the latter in opposite directions, and means actuated by said motor for driving said cutting mechanism.
408. In mining apparatus, the combination with a truck adapted to travel on a mine track, of a carrier pivoted thereto to rotate on an upright axis, a kerf-cutting unit comprising a pivoted elongated plane chain kerf-cutter with a motor operatively connected thereto, means comprising spaced-apart trunnions, for pivotally supporting said kerf-cutting unit on said carrier to move bodily therewith, means for adjusting said kerf-cutting unit on the axis of said trunnions and holding the same in adjusted position relative to said carrier, means for holding the carrier in adjusted angular relation to said truck, means for holding the kerf-cutter in adjusted angular relation to the axis of said trunnions, and motor operated mechanism separate from said kerf-cutting unit for moving the truck along the mine track to effect feeding of said kerf-cutter while being driven by said motor and while being held in adjusted position relative to the track.
409. In a mining machine, the combination with a truck adapted to travel along a mine track, of a carrier pivoted thereon to rotate relatively thereto on an upright axis, a unitary mining machine comprising an elongated pivoted chain kerf-cutter and a motor operatively connected thereto, mechanism comprising spaced trunnions for pivotally connecting said unitary mining machine to said carrier with the kerf-cutter in bottom cutting position at one side of the mine track, means for tilting said unitary mining machine on its pivotal connection to said carrier to vary the inclination of said kerf-cutter relative to the horizontal, means for holding the carrier in adjusted angular relation to said truck, means for holding said kerf-cutter in adjusted angular relation to said mine track, screw mechanism for effecting adjustment in elevation of said kerf-cutter, and motor operated mechanism separate from said unitary mining machine for moving the said truck along said track to effect rectilinear feed of said kerf-cutter while being driven by said motor.
410. In a mining machine, the combination with a wheeled support movable along a mine track, of a frame mounted thereon for rotation relatively thereto on a horizontal axis, a motor carried by said frame, mechanism for rotating said frame on said horizontal axis, cutting mechanism connected to said motor to be driven thereby and comprising a cutter bar pivotally connected to said frame, mechanism driven by said motor for swinging said cutter bar, mechanism for varying the elevation of said frame bodily to change the plane of swing of said bar, and mechanism for varying the plane of said cutter bar relative to the horizontal.
411. In a mining machine, the combination with a support, of a motor thereon, cutting mechanism including a cutter bar pivotally mounted on said support for swinging movement relatively thereto, and mechanism comprising driving gearing operated by said motor for swinging said cutter bar in either of opposite directions, said swinging mechanism including means operatively connected to opposite ends of one of the gears of said gearing for rotating said gear in opposite directions.
412. In a mining machine, the combination with a support, of a motor thereon, cutting mechanism including a cutter bar pivotally mounted on said support for swinging movement relatively thereto, a circular rack coaxial with the bar pivot, gearing operatively connected to said rack and including a worm, and means connecting said motor to opposite ends of said worm to rotate said worm in opposite directions to secure swinging movement of said cutter bar on its pivot in either of opposite directions.
413. In a mining machine, the combination with a motor, of cutting mechanism operatively connected to said motor, said cutting mechanism comprising a pivoted cutter bar with a circulating cutter chain connected to a drive sprocket, a shaft coaxial with said sprocket for effecting rotation thereof, a gear on said shaft, and means for effecting bar swing comprising a plurality of gear trains each having an initial driving gear driven by the shaft gear and meshing with the latter at different portions of the periphery thereof.
414. In a mining machine, the combination with a motor, of cutting mechanism operatively connected to said motor and comprising a pivoted cutter bar, with a circulating cutter chain thereon meshing with a drive sprocket, a shaft coaxial with said sprocket for effecting rotation thereof, a gear on said shaft, and means for ef-

fecting bar swing including a plurality of gear trains each having an initial gear driven by said shaft gear and meshing with different portions of the periphery thereof, said bar swinging means including also a worm with its opposite ends connected respectively to said gear trains to secure rotation of said worm in opposite directions.

415. In a mining machine, the combination with a motor, of cutting mechanism operatively connected thereto and comprising a pivoted cutter bar with a circulating cutter chain thereon driven by a sprocket, a shaft coaxial with said sprocket for effecting rotation thereof, a gear on said shaft, and means for effecting bar swing including two gear trains each having an initial driving gear driven by said shaft gear and meshing with the latter at different portions of the periphery thereof, said bar swinging means including also a worm disposed on an axis parallel to the plane of the bar swing with the opposite ends of said worm connected respectively to the two gear trains to secure rotation of said worm in opposite directions.

416. In a mining machine, the combination with a portable base, of a kerf-cutter, adjustable supporting structure intervening said kerf-cutter and said base, said supporting structure including supporting elements adjustable both in horizontal and vertical directions relative to said base, one of said supporting elements being rotatable about an axis extending longitudinally of said supporting structure, a second supporting element being swingably mounted on said first element about an axis extending transversely of said supporting structure, a third element serving as the cutter support being pivotally mounted on the second element about an axis at right angles to the axis of the second element, and means for operating said kerf-cutter.

417. In a mining machine, the combination with a portable base, of a support mounted on said base for adjustment in horizontal and vertical directions relative thereto, a frame mounted on said support for rotation relatively thereto about a horizontal axis, a support swingably mounted on said rotatable frame about a transverse axis, a second frame swivelly mounted on said swingable support, a kerf-cutter carried by said swiveled frame, and means for operating said kerf-cutter.

418. In a mining machine, the combination with a portable base, of a kerf-cutter, an adjustable supporting structure intervening said kerf-cutter and said base, said adjustable supporting structure comprising a support rotatable on a horizontal longitudinal axis, a second support swingably mounted on said first support about a horizontal transverse axis, a third support pivotally mounted on said second support for rotation relatively thereto about an axis at right angles to the axis of the second support, and means for operating said kerf-cutter.

419. In a mining machine, the combination with a portable base, of a kerf-cutter, adjustable supporting structure between said base and said kerf-cutter and comprising a support rotatable on a horizontal longitudinal axis, a second support swingably mounted on said first support about a horizontal transverse axis, a third support pivotally mounted on said second support for rotation relatively thereto about an axis at right angles to the axis of the second support and perpendicular to the axial line of the first

support, and means for operating said kerf-cutter.

420. In a mining machine, the combination with a support, of a neck rotatable thereon about a substantially horizontal axis, a member pivoted on said neck about an axis which is bodily rotatable about the axis of said neck upon rotation of the latter, a plane kerf-cutter pivoting about an axis which is respectively perpendicular to the plane of the kerf-cutter and to said second-mentioned axis, and means for operating said kerf-cutter including feed thereof by moving said support, at a feeding speed towards the working face during cutting with the neck axis perpendicular to such face.

421. In a mining machine, the combination with a support, of a neck rotatable thereon about a substantially horizontal axis, a member pivoted on said neck about an axis which is bodily rotatable about an axis of said neck upon rotation of the latter, a plane kerf-cutter pivoted about an axis which is respectively perpendicular to the plane of the kerf-cutter and to said second-mentioned axis, means for changing the plane of said neck axis, and means for operating said kerf-cutter.

422. In a mining machine, the combination with a main frame bodily movable during cutting, a kerf-cutter comprising a plane cutter bar, adjustable supporting means between said supporting frame and said bar, said adjustable supporting means comprising supporting elements rotatable the one about an axis on said main frame and the other about an axis on said first-mentioned element, said axis being disposed a fixed distance apart, said cutter bar being swingable in its own plane about an axis perpendicular to one of said axes, and one of said elements being rotatable both on its own axis and bodily when the other element rotates about its respective axis, and means for operating said kerf-cutter.

423. In a mining machine, the combination with a support having spaced bearing surfaces, of a motor, trunnions at opposite sides of said motor in cooperative relation to said bearing surfaces, mechanism for tilting said motor relative to said support, cutting mechanism supported by said motor including a pivoted cutter bar mounted for swinging movement relatively to said motor, and mechanism driven by said motor for swinging said cutter bar.

424. In a mining machine, the combination with a supporting frame, of a support rotatable relatively to said frame on a horizontal axis, means for rotating said support on said horizontal axis and holding the same in adjusted position, an elongated chain kerf-cutter comprising an elongated cutter bar, members supporting said cutter bar for pivotal movement toward and from the axial line of said support, means for pivotally moving said cutter bar transversely of its plane toward and from said axial line and holding the same in adjusted position, a longitudinally shiftable mounting for said support, and operator-controlled self-contained power-operated mechanism for effecting rectilinear movement of said mounting relatively to said supporting frame to effect rectilinear feeding movement of said kerf-cutter in its own plane.

425. In mining apparatus, the combination with a truck adapted to move along a mine track, of a supporting frame pivoted thereto on an upright axis, an elongated kerf-cutter pivoted to said frame on rectangularly related axes one of which is at right angles to the plane of the kerf cut by

- said kerf-cutter and the other of which is vertical and spaced horizontally from said first-named upright axis, means for rotating said frame on said first-named upright axis and holding said frame in adjusted angular relation to said truck, supporting means for swinging said kerf-cutter on said second-named upright axis and holding the kerf-cutter for feeding movement in a predetermined plane, and self-contained power-operated means for sumping said kerf-cutter rectilinearly, feeding the same arcuately on said right angle axis and withdrawing said kerf-cutter rectilinearly to effect the cutting of a vertical parallel ribbed kerf in the mine vein. 5 80
- 15 426. In a mining machine, the combination with supporting means movable on a trackway, of an elongated chain kerf-cutter comprising an elongated cutter bar and an endless chain-cutter thereon, means for pivotally connecting said kerf-cutter to said supporting means for adjustment to parallel vertical planes parallel to said trackway including vertical planes extending through the sides of the machine and a vertical plane midway between the sides of the machine, means operable while supporting the kerf-cutter to adjust the same to such vertical planes and hold the same in position for operation in such vertical planes, and self-contained power-operated means for operating said kerf-cutter in a predetermined vertical plane including bodily rectilinear feed thereof when said cutter bar is presented edgewise to a working face of a mine vein, transverse feed of said kerf-cutter in the same vertical plane, and reverse rectilinear feed of said kerf-cutter rectilinearly to insert a vertical parallel ribbed kerf in said face. 20 95
- 25 427. In a mining machine, the combination with a base frame, of an elongated kerf-cutter, means for pivotally connecting said kerf-cutter to said base frame for adjustment relative thereto on spaced-apart parallel axes and for swinging movement on another axis at right angles to the plane of the kerf cut by said kerf-cutter, one of said parallel axes being located intermediate the ends 30 100
- 35 of said base frame and the other axis being located outside of the boundary of said base frame, means for adjusting said kerf-cutter on said parallel axes to position the same in successively adjacent parallel planes and holding the kerf-cutter in adjusted position, and power-operated mechanism for operating said kerf-cutter including swinging feeding movement thereof on said right angle axis. 40 110
- 45 428. In a mining machine, the combination with a base frame, of a cutting tool, a group of members extending outwardly beyond the lateral boundaries of said frame for supporting said cutting tool on said base frame for adjustment relative thereto on a plurality of pivoted axes two 50 115
- 55 of which are parallel and one of the latter outside of the boundaries of said frame, means for effecting adjustments on said parallel axes to cause the cutting tool while entirely beyond the boundaries of said frame to be moved bodily toward and from and into a medial vertical plane extending longitudinally through the machine, and power-operated mechanism for operating said cutting tool. 60 120
- 65 429. In a mining machine, the combination with a base frame, of an elongated kerf-cutter, a group of members for supporting said kerf-cutter on said base frame for adjustment relative thereto on parallel spaced-apart vertical axes one of which is permanently within the boundaries 70 125
- 75 of said frame and the other of which is permanently without said boundaries, mechanism operative while said members support said kerf-cutter for effecting adjustments on said vertical axes to move the kerf-cutter into parallel planes at various distances from each other and thereby maintain said kerf-cutter parallel to the path of travel of the machine, and power-operated mechanism for operating said kerf-cutter including the feed thereof to cut a vertical kerf in any one of such parallel planes to which adjusted. 80 85
430. In a mining machine, the combination with a wheeled truck movable along a trackway, of cutting mechanism including a cutter bar, means for pivotally supporting said cutter bar on a vertical axis in a vertical plane extending through the longitudinal center line of the track, said cutter bar being supported in a horizontal plane below all other parts of the machine, means for swinging said cutter bar to acute angle positions relative to the trackway and locking the same in such positions, and self-contained power-operated means supported by said truck and including said swinging means for moving the cutter bar rectilinearly relative to the trackway, relatively transversely in the same plane, and reversely rectilinearly to form a parallel ribbed kerf of a depth substantially equal to the active length of the cutter bar. 90 95
431. In a track-mounted mining machine, the combination with a wheel supported frame movable along a mine trackway and widely expanded to span the trackway and to span the wheel axes, of a rotatable head swiveled to said frame on a horizontal axis confined to a fixed elevation relative to such frame, an elongated chain kerf-cutter comprising an elongated cutter bar with an endless chain cutter mounted on the periphery thereof for travel in an orbital path, means for supporting said cutter bar on said head for adjustment toward and from the axial line of said head and for swinging movement in its own plane on an axis permanently at right angles to the plane of said cutter bar and at the rear end portion thereof within said orbital path, mechanism associated with said supporting means for adjusting said cutter bar toward and from said axial line and holding the same in adjusted position, and operator-controlled self-contained power-operated mechanism for effecting either a forward feeding movement rectilinearly or a reverse feeding movement rectilinearly or a swinging feeding movement on said right angle axis of said elongated kerf-cutter. 100 105
432. In a track-mounted mining machine, the combination with a wheeled truck movable along a mine trackway, of a supporting frame thereon and widely expanded to span the said trackway and the axes of the truck, an elongated chain kerf-cutter, a turnover head mounted on said frame on a horizontal axis confined to a fixed elevation relative to said frame, means for turning over said head on said horizontal axis and holding the same in adjusted position, means connecting said kerf-cutter to said head for adjustment toward and from the axial line of said head and for swinging movement on an axis permanently at right angles to the plane of the kerf cut by said kerf-cutter, means for effecting adjustment of said kerf-cutter toward and from said axial line and the holding of the same in adjusted position, and operator-controlled power-operated mechanism for effecting rectilinear feeding movements of said kerf-cutter bodily in forward and reverse directions or for effecting swinging feeding movement of said kerf-cutter on said right angle axis. 110 115
- 120 125
- 130 135
- 140 145
- 150

433. In a mining machine, the combination with a wheeled truck movable along a mine trackway, of cutting mechanism including a cutter bar, a turnover head, means for pivotally supporting said cutter bar on said head on a vertical axis in a vertical plane extending through the longitudinal center line of the trackway, means for turning said head on a horizontal axis in such vertical plane to adjust the cutter bar to a shear cutting position, means for swinging said cutter bar to acute angle positions relative to the horizontal and locking the same in such positions, and self-contained power-operated mechanism supported on said truck and including said swinging means for feeding the cutter bar rectilinearly relative to the trackway, relatively transversely in the same plane, and reversely rectilinearly to form a parallel ribbed kerf of a depth substantially equal to the active length of said cutter bar.
434. In a mining machine, the combination with a base frame, of a longitudinally shiftable mounting supported by said base frame for reciprocating movements relatively thereto, an elongated kerf-cutter pivotally connected to said longitudinally shiftable mounting for swinging movements relatively thereto, a motor, operator-controlled reversing mechanism driven by said motor for swinging said kerf-cutter on its pivot in opposite directions without changing the direction of rotation of said motor, and operator-controlled reversing mechanism separate and independent of said first-named reversing mechanism for effecting reciprocation of said longitudinally shiftable mounting to feed said kerf-cutter rectilinearly in opposite directions without changing the direction of rotation of said motor.
435. In a mining machine, the combination with a base frame, of a longitudinally shiftable mounting supported by said base frame for reciprocation relatively thereto, an elongated kerf-cutter, a motor connected to said kerf-cutter to drive the same, reversing mechanism driven by said motor for swinging said kerf-cutter in opposite directions without changing the direction of rotation of said motor, an additional motor, and reversing mechanism driven by said additional motor for moving said longitudinally shiftable mounting rectilinearly in opposite directions relatively to said base frame without changing the direction of rotation of said additional motor, whereby the swinging of said kerf-cutter in opposite directions and the reciprocation thereof rectilinearly may be effected independently.
436. In a track mounted mining machine, the combination with a wheeled truck movable along a mine track, of a supporting frame widely expanded in length and breadth to span the mine track and overlie the axles of the truck, an elongated chain kerf-cutter comprising an elongated cutter bar with an endless chain cutter mounted on the periphery thereof for travel in an orbital path, a rotatable head swiveled to said frame on a horizontal axis confined to a fixed elevation relative to such frame, mechanism for supporting said cutter bar on said head for adjustment toward and from the axial line of said head, means for adjusting said cutter bar toward and from said axial line and holding the same in adjusted position, and operator-controlled motor-operated mechanism for effecting rectilinear feeding movements of said kerf-cutter bodily while held rigidly in adjusted position and confined against up or down movements relatively to said frame by the connection of said head thereto.
437. In a track mounted mining machine, the combination with a wheeled truck movable along a mine trackway, of a supporting frame thereon widely expanded in length and breadth to span the trackway and to overlie the axes of the wheels, a rotatable head swiveled to said frame on a horizontal axis confined to a fixed elevation relative to such frame, an elongated chain kerf-cutter comprising an elongated cutter-bar with an endless chain cutter mounted on the periphery thereof for travel in an orbital path, means for supporting said cutter-bar on said head for adjustment toward and from the axial line of said head and for swinging movement in its own plane on an axis permanently at right angles to the plane of said cutter-bar and at the rear end portion thereof within said orbital path, means for adjusting said cutter-bar toward and from said axial line and holding the same in adjusted position, and operator-controlled self-contained power-operated mechanism for effecting either forward and reverse rectilinear feeding movements of said kerf-cutter bodily relative to the trackway or a swinging feeding movement of said kerf-cutter on its right angle axis.
